UNITED STATES PATENT OFFICE.

ALBERT M. BULLARD, OF NEW YORK, N. Y., ASSIGNOR TO WESTERN ELECTRIC COMPANY, OF CHICAGO, ILLINOIS, A CORPORATION OF ILLINOIS.

SEMI-MECHANICAL TELEPHONE SYSTEM.

1,126,952.

Specification of Letters Patent.

Patented Feb. 2, 1915.

Application filed April 3, 1907. Serial No. 366,197.

To all whom it may concern:

Be it known that I, ALBERT M. BULLARD, citizen of the United States, residing at New York, in the county of New York and State of New York, have invented a certain new and useful Improvement in Semi-Mechanical Telephone Systems, of which the following is a full, clear, concise, and exact description.

10 My invention relates to a telephone exchange system of, for example, the semi-mechanical type, wherein the operator answers the call of a subscriber in the usual way by uniting her connecting circuit with the line of such subscriber, and mechanical switching mechanism completes the connection by uniting the operator's connecting circuit with the called line, the operation of the switching mechanism being controlled 20 by sending apparatus adapted to be actuated by the operator to selectively operate said switching mechanism.

In a telephone exchange system embodying my invention, connectors are provided 25 at the central office adapted to complete connection with different groups of lines. A distributor or primary selector is provided, adapted to unite a given talking circuit or operator's connecting circuit with a connector serving a given group of lines, or with an idle connector in a set of connectors serving the same group.

The grouping of telephone lines at the connectors and of trunking lines leading to the 35 connectors may be on a non-decimal basis, the total number of telephone lines at each connector being evenly divisible into the decimal number 1000, said quotient being a multiple of 10, thereby permitting a decimal 40 arrangement of digit keys representing the digits of subscribers' line numbers, so that when keys representing a particular line are depressed, they operate without intervention of translating devices, line switching 45 mechanism being adapted to select the group of lines containing the called line, and to connect with the desired line in such group. For example, lines may be arranged in groups of 500, and keys representing the 50 thousands, hundreds, tens and units digits of subscribers' lines selectively operate the line switching mechanism.

The operator's connecting circuit is adapted to be connected with a distributor or primary selector in either the local or a distant

office, said selector being arranged to connect with an idle connector adapted to reach the line of the called party. Each connector may be arranged to reach, for example, five hundred lines. The operator is provided 60 with a sending apparatus having, for example, thousands, hundreds, tens and units digit keys, which control the operation of the primary selector and a connector selected thereby to complete the connection of the 65 operator's connecting circuit with a desired line.

Heretofore, it has been customary always to provide the connectors with relays for testing and ringing the called lines. In an 70 exchange where the total number of connectors exceeds the total number of distributors or primary selectors there is obviously economy in transferring said relays to the latter, and one feature of my invention 75 consists in providing for this transfer, so that the relays act upon any line chosen by the connector selected by the primary selector.

When a connector is selected by the distributor or primary selector, a normally 80 open test conductor extends from the test brush of the connector arm back through the distributor, where the establishment of its continuity is controlled. Said test conductor is completed when the connector 85 unites with the desired line, and may include at the distributor mechanism adapted, in case the line of the called party is busy, to apply a busy signal to the talking circuit of the distributor; and also may effect the automatic restoration of the distributor and connector to normal condition. The said test 90 conductor is preferably normally open at two points,—at the connector and at the distributor, and preferably extends from the test brush of the connector over the local wire therefrom, through normally-open contacts to one of the line conductors leading back to the primary selector, and at said selector a local conductor may lead from the line wire 95 through normally open contacts to one pole of a source of current, the other pole whereof is connected with the local line terminals upon the connector. A pair of continuity 100 relays may be provided for closing said two sets of normally open contacts, and a relay at the selector is arranged to be operated when the connector has united with the desired line to operate said pair of relays and close the test conductor. 105

Within the test conductor may be included relays at the connector and the primary selector, said relays being arranged to be unresponsive in case the called line is busy, 5 preferably by means of a shunt existing around said conductor, due to the busy condition of the called line, the relay at the connector responding in case the called line is free to disconnect the local wire of the connector and the circuits of its operating mechanism from the line conductors. The relay at the primary selector is adapted, in case the called line is busy to effect the connection of the busy signal apparatus with 10 the talking circuit or operator's connecting circuit. If, however, the called line is free, said relay when operated disconnects the local conductor at the primary selector, which forms a part of the testing conductor, from the line circuit, and may also serve to establish the continuity of the talking conductors. Said connecting relays may in attracting their armatures include themselves in locking circuits under the 15 control of the retaining magnets of the connector and primary selector.

Another feature of the invention relates to the provision of automatic signaling apparatus at the primary selector, which is 20 brought into service when connection is completed by the connector with a free line, to signal the called party. I preferably employ the connecting relay at the distributor to operate when energized a ringing relay which severs the line conductors and connects the portions thereof leading through the distributor and connector to the called line, with the poles of the ringing generator. A relay may also be provided 25 in the ringing circuit which responds when the called party answers and effects the deenergization of the ringing relay. The circuit of the ringing relay as completed by the connecting relay may be controlled in normally closed contacts of the 30 continuity relay of the primary selector, and the relay in the ringing circuit before referred to may when energized complete a circuit for said continuity relay, to cause 35 the same to open the circuit of the ringing relay and lock itself up under the control of the retaining magnet of the primary selector.

I also provide at the primary selector 40 means for automatically signaling a called station of a party line. The testing circuit may include a relay at the selector adapted to control the character of current, for example, negative and positive, to be applied through the selector and connector, to the called line. Said relay may be arranged to be unresponsive to the current in the testing circuit in case the called station is a member of a party line that requires signaling current of a given polarity, for example,

negative, and said relay may respond in case the called station is a member of a party line and requires signaling current of an opposite polarity, for example, positive. I preferably employ a relay for this purpose having two windings, one of said windings being included in the testing circuit and the other of said windings, which I will term the "holding" winding, being short circuited at the armature and back contact of said relay. Therefore, when the relay is initially energized, its armature is attracted and in its movement opens the short circuit about the holding winding of said relay, whereupon said winding is included in a locking circuit with the connecting relay; said circuit, in case the relay had not been initially energized, would include only the armature and back contact of said relay. The said relay may control the application of the current of different character to the contacts operated by the ringing relay above referred to.

Where private branch exchanges are associated with a system, such as I have referred to, connectors serving a given group of lines may include a set of terminals representing a group of trunk lines leading from the main exchange to the private branch exchange. The operation of line selection by the primary selector and connector, as governed by the controlling mechanism or sending apparatus associated with the connecting circuit, would simply advance the connector brushes to terminals of the first trunk line. Now, if this trunk line is busy, it is necessary to advance the brushes to the next trunk line terminals and so on until an idle trunk line is reached, and this must be done, of course, independently of the original controlling mechanism or sending apparatus. I have provided, therefore, at the primary selector, mechanism which is brought into service when the connector brushes reach the terminals of a busy trunk line leading to a private exchange, to advance the connector brushes to the next trunk line terminals. The test terminals of all the trunk lines but the last, leading to a given branch exchange, may be supplied with current of a polarity opposite to the polarity of the current supplied to the test terminals of the subscribers' lines terminating at the same connector, and a polarized relay may be provided at the selector in the testing circuit, responsive to the polarity of current present at the said trunk line terminals, except the last. Thus, in case the first trunk line tested were in use, the polarized relay referred to would operate while the connecting relay would be inert, and such combination of relays would effect the application of proper current to the lifting magnet of the connector to move the brushes to the next trunk line terminals. When an idle trunk line termi- 120 125 130 135 140 145 150 155 160 165 170 175 180

nal was reached, both the connecting relay and polarized relay would operate and said polarized relay when operating would complete a locking circuit for the said relays from a source of current of proper polarity to maintain itself energized. In case all the trunk lines were busy, when the last one was tested, the current thereto would not maintain the polarized relay energized, and both the connecting relay and polarized relay would be inert and the usual busy signal applied to the talking circuit.

A further feature of my invention relates to the manner of controlling the different selecting operations of both the primary selector and the connector selected thereby. I provide a bridge of the line conductors leading to the selector, and include in said bridge a polarized relay which in response to currents of different character operates the different stepping magnets of the selector. Said selector may employ a stepping magnet to rotate its arm to bring the brushes thereof into operative relation to a row of terminals representing a group of connectors adapted to unite with a given group of telephone lines. Said selector may also be equipped with a lifting magnet adapted to move the contact brushes along the terminals of a selected row to pick out a trunk line leading to an idle connector of the group represented by said terminals. Said polarized relay in the selecting bridge may therefore be double-acting, and in attracting its armature in one direction may effect the operation of the rotary magnet of the primary selector, and in rocking its armature in the opposite direction may effect the operation of said lifting magnet. The said selecting bridge may include another relay which is adapted to control the operation of the stepping magnets of the selected connector, in conjunction with the first-mentioned relay. The connector may be provided with banks of terminals representing groups of, for example, 100 lines each, and the contact carrying arm thereof may be provided with a long step magnet adapted to advance the contact carrying arm in long steps from bank to bank; said arm may be advanced from row to row of terminals of a selected bank by a short step magnet, and along the terminals of a selected row by a lifting magnet. The said first mentioned polarized relay in the selecting bridge at the primary selector may control the operation of the long-step and lifting magnets of the connector, the other relay in the bridge being adapted to operate the short step magnet prior to the operation of the lifting magnet. The first polarized relay in said bridge, in operating, renders ineffective the other relay to prevent confusion in the application of selecting currents. The said second polarized relay in the selecting

bridge may be a double-acting relay, and when its armature is moved in one direction it may operate one of the stepping magnets of the connector, and when rocked in the opposite direction when the connector has united with the desired line, it may effect the operation of the continuity relays of both the distributor and connector to establish the continuity of the testing conductor.

A further feature of my invention consists in the provision of means for maintaining the selecting bridge open at all times when it might interfere with the proper operation of the system. Said bridge is maintained open during the process of testing the called line, preferably by the continuity relay of the primary selector, and during the application of ringing current to the called line, the ringing relay may maintain the bridge open. When the called party has responded and the ringing relay has become inert, the continuity relay may again be called into service to maintain said bridge open during the conversation. Said relay is operated, upon the response of the called party, to effect the de-energization of the ringing relay. The selector may be provided with rows of terminals, each row representing a group of connectors serving a given group of telephone lines, and after the selector arm has advanced to the row representing connectors serving the called line, said arm is adapted to hunt automatically along the selected row to locate an idle connector. I provide means for maintaining said bridge at the selector open during the hunt for an idle connector, said bridge when re-established upon the selection of such connector, being adapted to complete a circuit for mechanism of the sending apparatus, which causes said sending apparatus to operate the selected connector. Said selector may have a lifting magnet adapted to move the arm along a selected row, and a relay may be provided for completing a pulsating current circuit for said magnet. The said bridge may be provided with means for completing a momentary circuit for said relay, which causes the magnet to move the arm to the first set of terminals in the row, and if the connector represented by such trunk line is in use, said relay will receive current from the test terminal of the first set, and will maintain the circuit of the lifting magnet, which will advance the arm to the next set of terminals, and so on until the terminals of an idle connector are reached. The connector may be provided with groups of terminals, and the mechanism at the sending apparatus, operated upon the re-establishment of said bridge, when an idle connector is located, may control the movement of the connector arm from group to group of terminals to the

group containing the terminals of the desired line. Finally, it is necessary to maintain said bridge open during the return of the selector arm from operated position to normal position. To this end I employ a relay which is operated during the return of said arm to maintain said bridge open. The circuit of said relay may be established upon the deenergization of the retaining magnet of the selector, and may include contacts which are closed while the selector arm is away from normal position, so that when the said arm is completely restored the said relay will be deprived of current.

15 A further feature of the present invention relates to the provision of improved means for effecting the notification of the operator of the fact that a called party is a member of a party line, whereof the calling party is also a member. To this end I provide a relay having a pair of windings, one winding whereof is included preferably in the circuits of the relays which control the operative condition of the sending apparatus and the association thereof with the connecting circuit, said winding receiving insufficient current to operate the relay armatures until the connector has united with a desired line, whereupon an increased amount of current is supplied to said winding, and it thereupon effects the attraction of said armatures. Said relay in operating connects its other winding in a branch from the connecting circuit, and in case the subscriber with whom conversation is desired is a party on the line which includes the calling subscriber, said winding will receive sufficient current to maintain the armatures of the relay attracted and a peculiar signal will be applied to the connecting circuit to indicate to the operator the character of the call.

Another feature of my invention relates to the sending apparatus and consists in the arrangement whereby the particular thousands and hundreds keys representing the digits of a called line coöperate directly with the primary controller in the sending apparatus, to actuate the primary selector at the selected office, and cause the same to unite the operator's connecting circuit with a connector adapted to unite with a desired line. Each of the connectors may have its terminals arranged in groups or banks, for example, in banks of one hundred terminals, which may be each subdivided into rows, for example, ten rows, each having ten line terminals. Thus if each connector served five hundred lines, there would be five banks of one hundred terminals.

Another feature of my invention consists in the arrangement whereby an auxiliary controller in the sending apparatus co-operates directly with the depressed hundreds key representing the hundreds digit of the

called line to move the arm of the selected connector into operative relation to the bank of terminals in which is located the terminals of the called line, and when the auxiliary controller has performed the work above outlined, it brings into service again the primary controller, which thereupon cooperates with the depressed tens key representing the tens digit of the called line to move the connector arm along the selected bank of terminals into operative relation to the row of terminals in such bank, wherein is located the terminals of the called line. The primary controller, after operating the second time, switches into service again the auxiliary controller, which now operates in conjunction with the depressed units key representing the units digit of the called line to move the connector arm along the selected row to the line terminals of the called party. Thus the primary and auxiliary controllers each operate twice, and each switches the other into service.

Another feature of the present invention is concerned in the arrangement whereby the digit mechanism of the sending apparatus, after being associated with the connecting circuit, is not permitted to operate until the keys representing the digits of the called party's number have been actuated. 90 95

I will describe my invention more particularly by reference to the accompanying drawings, which represent a telephone exchange system equipped with an embodiment of my invention, and wherein— 100

fied diagram of a portion of the primary selector, showing the manner in which the polarized relay in the selecting bridge controls the operation of the stepping magnets of the selector, and also the means employed for maintaining said bridge open during the return of the selector arm from an operated to normal position; and Fig. 15 is a simplified view to illustrate the operation of the 10 reverting call signal controlling mechanism.

Like parts are designated by similar letters of reference throughout the several views.

Referring generally to the system shown 15 as embodying my invention, the operator may be provided with the usual plug for connecting her connecting circuit with the calling line, and said connecting circuit leads to a district selector adapted to pick out the district wherein is located the office where the called line terminates, and to connect said connecting circuit with a trunk line leading to an office selector in such district, which picks out a trunk selector adapted 20 to select a trunk line leading to a primary selector at the particular office where the called line terminates. Said primary selector thereupon picks out a trunk line leading to an idle connector adapted to reach 25 the line of the called party. The operation of the said selecting mechanism is controlled by the sending apparatus, which is adapted to be associated with the operator's connecting circuit after she has answered a call.

The sending apparatus is controlled by 30 office thousands, hundreds, tens and units keys. If the line desired were No. 1465 in the office No. 8, the operator would depress key No. 8 of the office keys, key I of the 35 thousands keys, key IV of the hundreds keys, key VI of the tens keys and key V of the units keys. The office key depressed would operate both the district and office selectors and connect the connecting circuit with a 40 trunk line leading to a primary selector at office VIII, whereupon the thousands and hundreds keys depressed would cause the primary selector to select a connector adapted to reach the called line, and the tens and 45 units keys would operate such connector to finally unite the connecting circuit with the called line.

We will assume that subscriber No. 999, 50 whose line is shown in Fig. 1, as terminating in office No. 1, desires connection with the line of subscriber No. 1465 shown in Fig. 4, whose line terminates at exchange No. 8 in district No. 9. The line of subscriber No. 999, Fig. 1, extends in two limbs from the 55 substation to the central office No. 1, where the line extends through the usual line signal apparatus to the poles of a central battery. At the central office, the usual answering 60 jack 15 is provided for the line, the thimble 65 16 of said jack being connected with a con-

ductor 17 which leads through the usual cut-off relay to the free pole of a grounded battery 18. The operator is provided with an answering plug 19 with which to unite her connecting circuit with a calling line, the 70 plug 19 and jack 15 constituting a manual connection switch.

The link conductors 20, 21 of the operator's connecting circuit lead from the tip and ring respectively of the answering plug, 75 through the windings of the usual repeating coil, between which is bridged the battery 22 in the usual manner, to the line brushes 23, 24 of a district selector 25, supervisory relays being included in the link conductor 21 80 on opposite sides of the battery for controlling the usual supervisory signals. The sleeve of the answering plug is connected with a conductor 26 which leads to earth through the winding of a relay 27; said relay 27, whose circuit 26, 17 is completed upon the closure of the connection switch, is provided with an armature 28 controlling the application of current from a battery 29 through the supervisory lamps and contacts 90 of the supervisory relays, which control the display of said lamps, to earth.

Association of sending apparatus with connecting circuit.—A sending apparatus for selectively actuating the line switching 95 mechanism provided for the connecting circuit, is automatically associated with said connecting circuit when the operator closes her connecting switch to unite the connecting circuit with a calling line, and said 100 sending apparatus is automatically disconnected from said connecting circuit when it has completed its work and the switching mechanism has united the connecting circuit with a called line.

The armature 30 of relay 27 in the system shown, controls the association of a sending apparatus with the operator's connecting circuit. Said armature is connected with earth, while a front contact thereof is connected with a conductor 31 which leads through contacts of a key 32 to the district selector, thence through the retaining magnet 36 of the district selector, winding 33 of relay 34, contacts 38 of the selector arm, to the free pole of a grounded battery 35. The retaining magnet 36 is operated by current in this circuit and at its armature 37 and front contact connects the battery 35 with conductor 31 independently of the springs 38, closed only while the selector is in normal condition. Current now flows from the battery 35 through the contacts 37 of the retaining magnet, winding of said magnet, conductor 31 to earth. It should be noted that springs 38, when operated at the initial movement of the selector arm, open the portion of conductor 31 including the winding 33 of relay 34. The relay 34 when initially energized, as previously described, attracted 120 125 130

its armature 39 and completed a locking circuit for itself independent of the circuit of the retaining magnet, by means of its winding 40. The armature 39 is connected with a conductor 41 which leads in multiple through 5 the winding 40 of the relay 34, and the winding 42 of the switching relay 43 to a wire 44, passing through a winding 45 of relay 46 to the armature 47 of the switching relay 43; 10 said armature 39 when attracted is adapted to engage a contact spring 48 which is connected by a wire 49 with the conductor 31 leading through the armature 30 and front contact of relay 27 to earth. The armature 15 47 of switching relay 43 controls the connection of the grounded conductors including the said windings of the relays 34, 43 and 46, with common wires 50, 50', leading respectively to a pair of sending apparatuses 20 F F', said armature 47 while resting against its back contact connecting said conductor 44 with common wire 50; and when attracted connecting said conductor 44 with common wire 50'. 25 Assuming that the sending apparatus F is free, and relay 34 has received its initial energization as above described, armature 39 of said relay in attracting, causes current to flow from the free pole of grounded battery 52 associated with sending apparatus F (Fig. 7) through winding of the controlling relay 53 of said sending apparatus, over the common wire 50 to the connecting circuit, and thence through the armature 47 and 30 back contact of relay 43, conductor 44, winding 45 of relay 46 (without operating the same) thence by way of conductor 41 through the windings 40, 42 of relays 34, 43, respectively in multiple (without operating relay 43) through the armature 39 and contact 48 of relay 34, wire 49 to the conductor 31, which is grounded at the armature 30 and front contact of relay 27. Relay 34 is now 35 locked in circuit with the controlling relay at sending apparatus F. The relay 34 is provided with a grounded armature 54 adapted when attracted to engage a front contact connected by a conductor 55 with the tip strand 20 of the connecting circuit, 40 in order to provide a metallic circuit for selecting current as will be later described. The armature 56 of relay 34 is connected with a conductor 57 leading to the armature 58 of switching relay 43, the back contact of 45 said armature being connected with the common wire 59 leading to sending apparatus F. The armature 56 of said relay 34 in its attractive movement is adapted to separate a pair of normally closed springs 50 serially included in the ring strand 21 of the connecting circuit, said armature engaging the member of said springs connected with the portion of the ring strand 60 leading directly to the district selector. The 65 leads to sending apparatus F are now placed in operative connection with the connecting circuit. The relay 53 at the sending apparatus F in attracting its armature 61 applies current from the free pole of grounded battery 52 to the feed wire 62, a branch 70 from said feed wire leading through a signal lamp to earth in order that the operator may be kept informed as to the condition of the sending apparatus. Said feed wire supplies current for the operation of the mechanism of the sending apparatus. In case the sending apparatus F had been serving another cord circuit, the particular connecting circuit now in use would have been shifted to the sending apparatus F'. It will be 75 noted that the feed wire of sending apparatus F has a branch 62a which leads through the winding 63 of the switching relay 43 to a contact spring 64 against which the spring 48 of relay 34 normally rests. Now, if under these conditions the operator had 80 plugged into answer a call, thereby effecting the energization of relay 27, current would have passed from the branch 62a of the feed wire (which would have been connected 85 with battery 52 of the busy sending apparatus) through contacts 64, 48 of relay 34, to the wire 31 which is grounded at the armature 30 of relay 27, operating relay 43. The armatures 47, 58 of the switching 90 relay would thereupon have been attracted and have switched the wires 57, 44, respectively, to the common wires 59', 50', respectively, leading to the sending apparatus F'. Furthermore, when the armature 39 of relay 95 34 had been attracted and the winding 40 of said relay had found a circuit by way of the battery at sending apparatus F', the holding winding 42 of the switching relay would have received current and maintain 100 105 the switching relay energized.

Operation of office keys and district selector.—In the present system, which is designed for use in a large city, there would be a number of districts in each of which would be located a number of central offices. I have accordingly employed a district selector arranged to pick out the district in which is located the office desired, and an office selector belonging to said district capable of picking out a trunk line leading to the particular office desired. I have arranged the office keys so that when a given key is operated it will cause the district selector to locate the proper district, and also actuate 110 an office selector in such selected district to select the proper office.

Referring now to the sending apparatus, and to the portion thereof known as the office keyboard, Fig. 5, I will describe the process of picking out a trunk line leading to a primary selector or distributor in office No. 8, in which office we have assumed the line of the called party terminates. In this connection, it should be stated that the office 115 120 125 130

keyboard is normally in operative relation to the sending apparatus F in order to serve a connecting circuit with which said sending apparatus may be associated; and, when the office keyboard has completed its work in conjunction with the sending apparatus F, it automatically transfers itself into operative relation to the sending apparatus F', and if the sending apparatus F' is taken for use before the first-mentioned sending apparatus has completed its work, said office keyboard will be locked in its operative relation to the apparatus F'. However, assuming that the second sending apparatus is not taken for use, the office keyboard will, after the sending apparatus F has completed its work, be re-associated with sending apparatus F.

The office keys are provided with a pair of controllers G G', which govern the operation of the district selector and the office selector which it selects. The office keys are each adapted when depressed to effect the successive operation of the controllers G and G' to cause the same to effect the operation of the district selector and pick out a district determined by the particular office key depressed; and thereupon the controllers are again successively operated to actuate the selected office selector in said district.

Referring first to controller G, there is provided a row of contacts *c* numbered from 0 to 9, these contacts representing the "tens" digits of the numbers of the districts. From each one of said terminals a conductor 65 leads to the springs 66 of the particular office keys representing offices lying in the district whose tens digit corresponds to the number of said terminal. In the present case, I have shown springs 66 of office keys Nos. 0, 7 and 8 as connected with the 0 terminal of the row *c* of contacts.

The controller G is provided with a rotary arm 70 carrying a brush 71 adapted to sweep over the row *c* of contacts, said arm being provided with a ratchet adapted to be operated by stepping and retaining magnets 72, 73, respectively. The brush 71 is connected with a conductor 74 which leads through springs 75 associated with a cut-off relay 76, winding of said relay to the feed wire 77 of the office keyboard, which is normally connected through the armature 78 and back contact of a switching relay 79 with the feed wire 62 of the sending apparatus F.

Each office key, when operated, is arranged to bring into electrical engagement springs 67, 68, 69, which control the starting of the office controller or keyboard after the sending apparatus with which it is associated has been connected with a particular connecting circuit. The spring 68 is connected with the feed wire 77 and so with the battery of the sending apparatus, and in

engaging spring 69 supplies current to a signal lamp 80, which indicates to the operator the condition of the office keyboard. The spring 67, supplied with current from the feed wire by spring 68, is connected with a conductor 81, which supplies current to the operating magnets of the controller G, said conductor leading through the retaining and stepping magnets 73, 72, respectively of arm 70, through contact springs 82 associated with the cut-off relay 76, to a contact of a grounded vibrating arm or pulsator 83. The stepping magnet 72 responds to this current and advances the contact arm 70, the retaining magnet being sluggish, so that its armature when once attracted, is unresponsive to the pulsations. When the controller arm has taken one step and the brush 71 has engaged the first terminal of the row *c*, the cut-off relay 76 is operated to open the circuit of the magnets 72, 73, of the controller, current to operate relay 76, passing from the feed wire 77, conductor 74, winding of relay 76, contact springs 75 associated with said relay, brush 71 and terminal "0", to conductor 65, which leads to earth through the contact springs 66, 84, of the office key No. 8, which is the key we have assumed to be operated. The relay 76 is provided with a pair of armatures 85, 86, the armature 86, when attracted, separating springs 82 to open the circuit through the magnets of the controller, said armature engaging the member of said spring connected directly with the pulsator 83. The other armature 85 is grounded, and in its attractive movement separates springs 75, engaging the member thereof connected directly with the winding of relay 76, thereby locking relay 76 to earth from the feed wire.

The stepping magnet 72, in operating, is adapted to make and break a pair of contacts 87, which control the application of current from the free pole of a grounded positive battery 88 to a conductor 89 leading to a common wire 90, which is normally connected at the armature 91 and back contact of a switching relay 79 with the common wire 59 of the sending apparatus F. In the present case, since this contact arm advanced but one step, but one impulse of current would be supplied by contacts 87 from battery 88 to the common wires 90, 59; the common wire 59 being as before described, connected by the armature 56 and front contact of relay 34, Fig. 1, with the portion of the ring strand of the connecting circuit leading to the district selector.

Turning now to the district selector, a number of groups of terminals are provided, each group representing the terminals of office selectors capable of reaching offices in a given number of districts. Thus the selector may have its terminals divided into

groups of 100 terminals subdivided into ten rows, each row representing a number of selectors representing a particular office, and the total number of rows in the group representing the office selectors in ten districts. A brush-carrying arm 92, mounted to rotate and to move longitudinally, is provided, having a long step magnet 93 adapted to rotate the arm in long steps, for example, over ten rows of terminals at a step in correspondence with the tens digits of the desired numbers; the stepping magnet 94 is arranged to advance the arm from row to row of a selected group, while the stepping magnet 95^a is adapted to move the arm upwardly to bring the brushes carried thereby into connection with a set of terminals in the selected row connected with an idle office selector. From the strand 21 of the connecting circuit, the conductor 95 leads through a pair of contacts 96 closed by the arm while in its normal and rotary positions, through the winding of the short step magnet 94, armature 96' and back contact of polarized relay 97, through the contacts 98 of the retaining magnet 36, to earth. A conductor 98^a extends in shunt of the stepping magnet 94, said conductor including the long step magnet 93 and the armature and back contact of the stepping magnet 94.

The stepping magnets 93, 94 are so arranged that the magnet 93 requires for its operation a smaller amount of current than magnet 94, so that magnet 93 may be operated in the same circuit with the magnet 94, without, however, affecting the latter. When current suitable to operate magnet 94 is impressed upon the circuit, magnet 94 in attracting its armature opens the branch 98^a including the stepping magnet 93, so preventing the operation of said magnet. In the present case, I employ a battery of 24 volts to operate the magnet 93; such current being without effect upon the magnet 94; and in order to operate magnet 94, I use a battery of 48 volts, whereupon magnet 94 operates and opens the branch containing its mate.

When the impulse from the 24 volt battery 88 was applied to common wires 90, 59, and ring strand 21, as previously described, the stepping magnet 93 received sufficient current for its operation and rotated the arm 92 of the selector through one long step, to the first bank of ten rows of terminals of the district selector, said bank representing the first ten districts.

Returning now to the office keyboard, the second controller G' is at this point brought into play to complete the selection of a district by causing the district selector arm to advance to the row of terminals in the first bank determined by the units digit of the district in which the particular office desired is located. The controller G' is provided

with a row c' of ten terminals representing the units digits of the districts. From each of said terminals a conductor 98^b leads to the springs 99 of the office keys representing units digits of offices which lie in the districts whose units digits correspond to the numbers of the terminals in the row c'; that is to say, taking the case of office No. 8, the spring 99 of such office key is connected with the terminal "9" of the row c'; which indicates that the units digit of the district in which is located office No. 8 is 9. It should be stated, however, that this arrangement is purely arbitrary, since spring 99 of office key No. 8 could exactly as well have been connected with another terminal of the row c', depending of course on how the offices are distributed.

The spring 99 of office key No. 8 rests in engagement with spring 84, due to the operation of key "8," and by means of said spring applies a ground to terminal "9" of controller G'. The controller G' is provided with a stepping magnet 102^a and a retaining magnet 103. Now, when the cut-off relay 76 was operated to stop the operation of controller G, as before described, it started the operation of the controller G'. The armature 86 of relay 76 is connected with a conductor 102, which leads through the contact springs 103' of the cut-off relay 104 of controller G', through the stepping magnet 102^a of controller G', contacts 105 closed by the controller arm while in normal position, through the free pole of a grounded battery 106. Since the front contact of the armature 86 of cut-off relay 76 is connected with conductor 81 and grounded pulsator 83, a circuit 102, 81 will be completed for the magnets 103, 102^a of the controller G', and pulsations of current from battery 106 will pass through said circuit, causing the stepping magnet 102^a to advance the arm 100.

It should be stated at this point that the contacts 105 are for the purpose of preventing access to the controller arm 100 unless the same is in normal position. The contacts are opened as soon as the arm has taken one step, but a branch 107 about said contacts is closed by the armature of the retaining magnet 103, which is sluggish and maintains its armature attracted regardless of the pulsating character of the current in its circuit, said armature when attracted closing a pair of contacts 108 which control the said branch 107.

The armature of the stepping magnet 102^a in its vibration, makes and breaks a pair of contacts 108^a, which intermittently applies current from a grounded battery 109 to a conductor 110 which leads to the back contact of the armature 111 of a relay 112, said armature being connected by a conductor 113 with the common wires 90, 59, and so

with the ring strand 21 of the connecting circuit. Impulses from battery 109 therefore pass to the conductor 95 at the district selector, and thence through the stepping magnet 94 of the arm 92 to earth. This current is of proper strength to operate magnet 94, being preferably 48 volts. Said magnet 94 in operating advances the arm in short steps from row to row of the first group of terminals, and in addition, opens the branch 98^a containing the long step magnet in order to prevent its operation. This current is of improper polarity to operate polarized relay 94 of the selector.

15 The brush 101 of the arm 100 of controller G' is connected with a conductor 114 which leads through a winding 115 of a sluggish relay 112, through contact springs 116 of a cut-off relay 104, winding of said relay, to the feed wire 77. Now when the arm 100 has been given a like number of steps, so that its brushes lie below the row of terminals representing office selectors adapted to reach offices in district No. 9, 20 the brush 101 will be in engagement with the grounded terminal "9" of the row c', and current will flow from the feed wire 77 through the winding of a cut-off relay 104, winding 115 of sluggish relay 112, brush 30 101, terminal "9," to earth by way of springs 99, 84 of office key No. 8.

The cut-off relay 104 is provided with a pair of armatures 117, 118; the armature 118, when attracted separates the springs 103' to open the circuit of the operating magnets of the controller G', while the armature 117, which is grounded, in its attractive movement separates springs 116, engaging the member thereof connected directly with the winding of the cut-off relay 104, and so completing a locking circuit for said relay from the feed wire. The separation of said contacts 116 also breaks the circuit of the brush 101, including the winding 115 of the sluggish relay 112, which, however, has had time to attract its armatures.

25 *Automatic selection by district selector of idle office selector.*—The front contact of armature 111 of the sluggish relay 112 is connected with a conductor 119 which leads to the free pole of a battery 120 of opposite polarity to battery 109,—in the present case a grounded negative battery. Current from this battery is of proper polarity to operate the polarized relay 97 at the district selector, which controls the hunt of the arm 92 for an idle office selector capable of reaching the offices in district No. 9. Current from said negative battery passes over 30 the common wires 90, 59, and ring strand 21 to the district selector, where said current traverses conductor 95 to one of the members of contacts 96, which is normally connected with a spring 121, and thence 35 over a conductor 122, through the armature

123 and front contact of the retaining magnet 36, winding of relay 97 and contacts 124, closed by the arm 92 while away from normal condition, to earth. The stepping magnets 93, 94, do not respond to this current on account of the rapid attractive movement of the armature 96' of relay 97, which controls the circuit of said magnets. Relay 97, when thus operated, attracts its armatures 125, 126, 96' and 127. The armatures 125, 126, simply maintain the line brushes of the district selector dead during the hunt for an idle office selector; the armature 96' in its attractive movement completes a circuit for the lifting magnet 95^a 40 and the source of pulsating current 128 by way of conductors 129 and 95, whereupon the arm is lifted to bring its brushes into engagement with the first trunk line terminals in the selected row. When the arm 45 has taken its first upward step, it separates spring 121 from the contacts 96 and moves said spring into engagement with a contact 130, which is connected with a conductor 131, leading to the front contact of the 50 armature 127 of relay 97, which armature, in turn, is connected by a conductor 132 with the local brush 133 carried by the selector arm. The relay 97 is now connected directly to earth from the local brush 133 55 by way of conductors 132, 131, 122, and in case the said first trunk line is in use, battery will be present at the local terminal 134 thereof, of a proper polarity to maintain relay 97 energized, whereupon the circuit of 60 the stepping magnet 95^a will be maintained intact, and the arm 92 lifted another step to bring its brushes into engagement with the terminals of a second trunk line leading to a selector serving offices in district No. 9. 65 This operation will be continued until the contact brushes of the arm 92 reach the terminals of an idle trunk line, at which time battery will not be present upon the local terminal 134 of such trunk line, and the relay 97 will be deprived of current and will release its armatures; armature 96' 70 opening the circuit of the lifting magnet 95^a, and armature 127 applying at its back contact current from a battery 135 to conductor 132 and the local brush 133, in order to lock out other district selectors attempting to make connection with the trunk line in question.

75 *Operation of office selector under the control of the depressed office key.*—The trunk line selected by the district selector leads in three limbs 136, 137 and 138 to an office selector, Fig. 2, adapted to make connection with a trunk line leading to a primary selector at any desired office in district 9, or, as shown, with an idle trunk selector adapted to pick out a trunk leading to the desired office. Said office selector is provided with 80 rows of terminals representing trunk lines 139

leading to the offices in district No. 9, each office having a row of terminals in said office selector. The said office selector is constructed similar to the district selector, its 5 rows of terminals being arranged in groups, for example, ten rows to a group, and the arm of the selector being adapted to be moved in long steps from group to group, in short steps to select a particular row of 10 said group, and longitudinally along the selected row to an idle terminal therein.

When current was applied at the district selector from battery 135 to the local brush 133 and terminal 134 of the trunk line selected, the retaining magnet 139 of the office selector arm 140 was operated by said current passing over conductor 138 and through said magnet to earth by way of springs closed while the selector is in normal 15 condition; said magnet, when energized, attracting its armature 141, locking itself to earth from conductor 138, independent of the said springs. The office selector arm is arranged to have a rotary movement by 20 long and short steps, and an upward movement in a manner similar to the district selector before described, and said arm is provided with a long step magnet 142 and a short step magnet 143 included in parallel 25 branches 144, 144^a, of a conductor 145, which leads from the line conductor 137, through contacts 146 closed by the arm until it starts its upward movement to earth through the armature 147 and back contact of a polarized 30 relay 148, which is unresponsive to the current employed to operate the stepping magnets 142, 143. As in the case of the district selector, the long step magnet is responsive to current of low voltage, for example, 24 volts, while the short step magnet is unresponsive to such current but requires for its operation current of higher voltage, for example, 48 volts, and in attracting its 35 armature opens the branch 144 containing the long step magnet to prevent its operation. The upward movement of the selector arm is controlled by a lifting magnet 148'.

After an office selector of district No. 9 has been selected, the controllers G G' successively coöperate with the depressed office key No. 8 to actuate the office selector and pick out an idle trunk selector adapted to 50 select a trunk line leading to the office desired. The controller G is provided with a row d of ten terminals corresponding to the "tens" digits of the office numbers, and said terminals are connected with the conductors 149, which lead to the springs 150 of the keys representing offices whose tens digits correspond with the numbers of such terminals in row d. Each of said springs 150 is adapted when operated to engage a grounded spring 151; thus in the present case, since office key No. 8 is depressed, its tens digit being "0," a ground is applied by

the springs 150, 151 to the first or "0" terminal of the row d. The arm 70 of controller G carries a second brush 152 adapted to sweep over the row of terminals d, said brush being connected with a conductor 153 which leads through contacts 154 closed by the retaining magnet 73 of controller G when energized, through contacts 155 closed by the cut-off relay 104 of controller G' (which relay is now locked to the feed wire) 75 through contact springs 156 of relay 157, winding of said relay, to the feed wire 77.

The operation of controller G to advance the office selector arm is controlled by relays 112, 158. The relay 112, when deenergized, after controller G operates, places relay 158 in condition to have a circuit therefor completed at the selected office selector, said relay 158 when operated starting controller G. The relay 112 was operated momentarily to start the automatic selection by the district selector of a trunk line leading to an idle office selector, and when said relay retracted its armature 159, it applied current from a positive battery 160 (for example) to a conductor 161, which leads through said armature 159 and back contact of relay 112, through the normally closed contacts 163 of cutoff relay 157 associated with the controller G, through normally closed contacts 164 opened by the retaining magnet 73 of controller G when energized, through the relay 158, to the common wire 90. Now when the district selector has picked out a trunk line leading to 100 an office selector and relay 97 has become deenergized and has retracted its armatures 125, 126, current from said battery 160 at the office keyboard finds a path over conductor 161 through the winding of relay 105 158 (relay 112 having now retracted its armature 159) to common wires 90, 5^a, ring strand 21, through the line contacts of the district selector to the line or trunk conductor 137 and thence to the office selector and through conductor 145 and stepping magnets of the office selector, to earth. The long step magnet of the selector is operated by this current and advances the selector arm a step, which is merely incidental 110 to the operation.

The relay 158 of the controller G in attracting its armature 165 completes a circuit for the operating magnets of the controller G, said circuit extending from the 120 feed wire 77 through springs 67, 68 closed by the office key when operated, conductor 81, retaining magnet 73, and stepping magnet 72, of the arm 70, through contacts 166, which are closed while the arm 70 is in 125 normal position, conductor 167, armature 165 and front contact of the relay 158, contact springs 168 of the cut-off relay 157 of the controller G, to the armature 118 of the cut-off relay 104 of controller G' (which 130

is now energized in a locking circuit from the feed wire) thence by way of the front contact of said armature 118 to conductor 102, armature 83 and front contact of the 5 cut-off relay 76 of controller G (which is also energized in a locking circuit from the feed wire) to conductor 81 and the vibrating grounded arm. The retaining magnet 73 attracts its armature, which remains attracted regardless of the pulsatory character of the current in its circuit, said armature opening at contacts 164 the circuit of relay 158, and closing at contacts 169 a branch conductor 170 about the armature 155 and front contact of relay 158 and the contacts 166 of the controller arm, both of which sets of contacts are now open. The contacts 166, which are initially in the circuit of the stepping magnet 72, are for the 20 purpose of preventing the operation of the controller arm unless it is in its normal position.

The stepping magnet 72 in vibrating its armature operates the contacts 87 to apply 25 current from the 24 volt battery 88 of positive polarity to conductor 89 and common wires 90, 59, cord strand 21, through the district selector line contacts, trunk conductor 137, to the office selector, and thence 30 by way of conductor 145, through the stepping magnets 142, 143, in parallel, to earth. This current operates simply the long step magnet, which is adapted to advance the selector arm in long steps from bank to 35 bank of the terminals.

When the controller arm 70 has taken one step, and the office selector arm has been rotated through one long step into operative relation to the first bank of terminals, the 40 brush 152 of controller G engages the first terminal "0" in the row *d*, and a circuit is completed from the feed wire 77 through the cut-off relay 157, conductor 153, contacts 155 closed by the cut-off relay 104 of controller G', contacts 154 closed by the retaining magnet 73 of the controller G, brush 152, "0" terminal, conductor 149 to ground through the contacts 150, 151 of office key No. 8. The relay 157 is now energized, and 45 attracts its armatures 171, 172; the armature 171 separating springs 156 and engaging the member thereof connected directly with relay 157, said armature being grounded and completing a locking circuit 50 for the relay from the feed wire. The armature 172 in its attractive movement separates springs 168, opening the circuit through the operating magnets of controller G, said armature also serving to bring into 55 play the controller G', which causes the office selector to advance to the row of terminals of the selected bank representing the trunk selectors adapted to pick out an idle primary selector at the desired office.

The controller G' is provided with a row 65 *d'* of ten terminals representing the units digits of the office numbers, and from said terminals conductors 173 lead to contact springs 174 of the office keys representing the offices whose units digits correspond to 70 the numbers of such terminals of said row *d'*. Thus in the present case, contact spring 174 of key No. 8, is connected with the terminal "8" in said row *d'*, said spring, owing to the operation of key No. 8, engaging 75 spring 151 which is grounded. The controller arm 100 carries a brush 175 which is adapted to sweep over said row *d'* of terminals until it engages the terminal which is grounded, at which point the circuit of the 80 operating magnets of the controller is broken. The said brush 175 is connected with a conductor 176 which leads through normally open contacts 177 closed by the armature of the retaining magnet 103 of controller G' when attracted, through contacts 178 closed by cut-off relay 157 of controller G, winding 179 of sluggish relay 112, contact springs 180 of a cut-off relay 181, to 85 the feed wire 77.

As before stated, the armature 172 of the cut-off relay 157 of controller G controls the operation of the controller G' in its relation to the office selector. When said armature is 90 attracted, a circuit is completed from the free pole of battery 106 by way of conductor 102 through the retaining magnet 103 of controller G', contacts 105 closed when the arm 100 is in normal condition, stepping magnet 102^a, conductor 102, normally closed contacts 183 of cut-off relay 181 of controller G', through armature 172 and front contact of the operated cut-off relay 157 of controller G, conductor 167, armature 118 and front contact of operated relay 104, back to conductor 102 and thence by way of armature 86 and front contact of cut-off relay 76, conductor 81, to ground pulsator 83. The retaining magnet 103 in said circuit, 100 when energized, attracts its armature, which closes contacts 177, completing the connection of brush 175 by way of conductor 176, with the feed wire, said conductor including the cut-off relay 181 and winding 179 of sluggish relay 112; said retaining magnet 103 also closes contacts 108, completing the branch 107 about the contacts 105, so as to 105 maintain the stepping magnet circuit independent of contacts 105.

The armature of the stepping magnet 102^a, in its vibration, operates the contacts 108^a, applying impulses from the positive 48-volt battery 109 by way of conductors 110, 113, to common wires 90, 59, cord strand 21, trunk conductor 137 to the office selector, and thence to earth through conductors 145 and 144^a, including the short step magnet 143 of the selector, which rotates the selector 115 120 125

arm in short steps from row to row of terminals, and maintains open the branch including the long step magnet.

When both the controller arm 100 and the office selector arm have taken nine steps and the office selector arm is in operative relation to the row of terminals representing trunk lines leading to trunk selectors adapted to pick out an idle primary selector at office No. 8, in district No. 9, a circuit is completed for the cut-off relay 181 of controller G' and sluggish relay 112, said circuit extending from the feed wire 77 over conductor 176, brush 175 and terminal "8" in row d', conductor 173 to ground at office key No. 8. The cut-off relay 181, when thus energized, attracts its grounded armature 183, which separates springs 180, breaking the connection of battery with sluggish relay 112 and brush 175, and engaging the member of said spring connected directly with the relay 181, to include said relay in a locking circuit from the feed wire. The armature 183 when attracted opens the circuit including the operating magnets of the controller G'.

Automatic selection by office selector.—The relay 112, which operates after the controller G' has completed its work, serves to start the "hunting" of the selector arm for an idle trunk line in the selected row, said relay applying current of proper polarity to relay 148 at the office selector, said relay 148 controlling the operation of the lifting magnet 148'. The relay 112, which was 35 momentarily operated, as above described, in attracting its armature 111, applied current from the negative battery 120, by way of conductors 119, 113 to common wires 90, 59, cord strand 21, trunk conductor 137, 40 through one member of contacts 146, controlled by the selector arm, to a spring 184' connected with a conductor 185' leading to earth through the winding of a polarized relay 148, which responds only to negative 45 current. Relay 148 is now energized and attracts its armatures 186, 187, 147 and 188. The armatures 186, 187 interrupt the continuity of the trunk conductors 136, 137, leading to the line brushes upon the selector 50 arm, to maintain the said line brushes dead during the upward hunt of the arm for an idle trunk line. The armature 147 when attracted completes a circuit 189, including the lifting magnet 148' and a source of pulsating current 190, whereupon the arm is 55 lifted to bring the brushes thereof into engagement with the terminals of the first trunk line in row "8" in the first bank of terminals. At this point, the contacts 146 60 are separated and the spring 184' is thrown into engagement with the spring 191 connected with the conductor 192 leading to the front contact of the armature 188, and through said armature to the local brush 65 193 of the selector arm.

The relay 148 is now connected directly with earth from the local brush 193 of the selector arm through its own armature 188 and front contact, springs 191, 184'. Assuming that the first trunk line is engaged, 70 negative battery will be present at the local terminal thereof, and relay 148 will be maintained energized, and in turn will continue the continuity of the circuit 189 including the lifting magnet, which will advance the selector arm to the next set of terminals, and so on until an idle trunk line is reached, in which case, no potential will be present upon the local terminal of such trunk line, and relay 148 will become de- 75 energized, retracting its armatures, armature 188, when retracted, engaging a back contact connected with conductor 194 leading through the armature 195 and front contact of retaining magnet 139 to the free pole 80 of a grounded battery 196, such current applying a test potential to the multiple local terminals of the selected trunk line to lock out other office selectors.

Operation of the trunk selector.—The 90 brushes of the office selector now rest upon terminals connected with trunk conductors 197, 198 and 199 leading to a trunk selector, which is automatically operated as soon as such connection is made, to pick out a trunk 95 line leading to an idle primary selector at the office No. 8. The conductors 197 and 198 lead through the armatures 200, 201, respectively, of a relay 202, to the line brushes carried by the rotary arm 203 of the trunk 100 selector, said arm being adapted to be rotated by a stepping magnet 204 to advance the brushes over the terminals representing inter-office trunk lines leading to office No. 8. The conductor 199 which leads from the 105 local terminal of said trunk line upon the office selector, passes through normally closed contacts 205 of the retaining magnet 206^a of said arm, thence through contacts 206, 207 and 208 to earth through the winding of such retaining magnet. The retaining magnet when thus energized attracts its armature, which forces a spring 209 connected with the portion of conductor 199 leading directly to earth through the retaining magnet 206, into engagement with the member 205^a of contacts 205, separating said contacts, and completing a circuit for the retaining magnet 206^a independent of contacts 205 and the contacts closed by the 110 selector arm while in normal position. The spring 207 associated with the selector arm is connected with a conductor 210 which leads to earth through the winding of the said relay 202, so that when the current is 115 applied to the local wire 199 by an office selector, the relay 202 receives current therefrom by means of conductor 210 and springs 206, 207. Relay 202 is thereupon energized and attracts its armatures 200, 201, 211, 212. 120 125 130 135 140 145 150 155 160 165 170 175 180 185 190 195 200 205 210 215 220 225 230 235 240 245 250 255 260 265 5 armature 212 when attracted completing a circuit 213 for the stepping magnet 204 including a battery 214 and a grounded pulsator. Said magnet thereupon advances the selector arm to the terminals of the first

5 trunk line leading to office No. 8.

10 The armature 211 of relay 202 is connected by a conductor 215 with the local brush of the selector arm, and in engaging its front contact connects the said relay 202 directly to earth from said local brush—its initial circuit being now broken at the contacts which are opened as soon as the selector arm leaves its normal position. In

15 case the first trunk line is busy, current will be present at the local terminal thereof, and will maintain the relay 202 energized, which in turn continues the completion of the circuit 213 of the stepping magnet 204, whereupon the arm 203 will be advanced to the terminals of the next trunk line, and so on until an idle trunk line is reached, when no current will be found at the local trunk terminal, and relay 202 will become deenergized, retracting its armatures; armature 212 opening the stepping magnet circuit; and armature 211 engaging its back contact connected with a conductor 216 leading to a contact spring against which the spring 205*

20 now rests, in order to apply by way of conductors 194, 192, 199, 216 and 215, current to the local terminals of the selected trunk line, so as to lock out other trunk selectors attempting to connect with said trunk line.

25 *Disconnection of office keyboard from sending apparatus F.*—When the office keyboard completed its work in connection with sending apparatus F, it was automatically transferred into operative relation to sending apparatus F', and the depressed office key and mechanism of the keyboard restored to normal condition. It will be remembered that after the short step magnet of the office selector had operated, the relay 112 was momentarily energized to start the automatic selection by the selector arm. Said relay in retracting its armature 159 supplies current from battery 160 to conductor 161, armature 159 and back contact 30 of relay 112, armature 162 and front contact of cut-off relay 104, to conductor 254, which leads through the armature 255 and front contact of cut-off relay 181, to conductor 161, winding of test relay 158 to the common wire 90. Now when an idle primary selector has been selected, current from said battery 160 flows through the relay 158 over the common wires 90, 59, conductors 21, 137, 198, 218, through the bridge 230 at the selected selector (Fig. 3) and back by way of line conductors 217, 197, 136, 20, to earth at the armature 54 and front contact of relay 34 (Fig. 1). Test relay 158 when energized in the said circuit serves to complete a circuit for the switching relay 79 which trans-

fers the feed wire 77 and common wire 90 to the feed wire 62' and common wire 59' of the sending apparatus F' Fig. 6. The said circuit for relay 79 extends from the feed wire 62 of sending apparatus F, conductor 70 257, through the winding 256 of switching relay 79, spring 258 and its back contact of a polarized relay 259 responsive for example to positive current only, through contacts 260 of the cut-off relay 181 of controller G', through contacts 261 of said test relay 158, to earth through contacts 262 of the relay 263 at the sending apparatus F' (Fig. 6), which relay controls the starting of the primary controller of such sending apparatus. 30

The switching relay 79 is adapted to transfer for the office keyboard to the sending apparatus F' in such manner that should sending apparatus F' be taken for use before apparatus F completes its work, the keyboard will be locked in association with sending apparatus F'. If, however, the sending apparatus F' is not taken for use before its mate is through serving a given cord circuit, the keyboard will be restored to 85 its normal association with sending apparatus F.

The switching relay 79 when energized by current in its winding 256, attracts its armatures 264, 78, 91 and 265. The armatures 78 95 and 91 connect the wires 77, 90 of the keyboard with the wires 62' 59' of sending apparatus F'; the armature 264 engages a spring connected directly with the feed wire 62 and completes by way of conductors 266, 100 257, a locking circuit for the said switching relay controlled by relay 263 of the sending apparatus F'. The armature 265 of the said switching relay is also connected with conductors 266, 257 leading through the contacts 262 to earth, and said armature in its attractive movement engages a spring connected with a conductor leading through a winding 267 of the switching relay to the wire 62' of sending apparatus F', so that 105 when current is applied to the feed wire by the armature 61' of the controlling relay 53' of sending apparatus F' (Fig. 7) said switching relay will maintain the association of the office keyboard with the sending apparatus F' independent of the condition of the sending apparatus F. 110

115 *Restoration of depressed office keys.*—The office key No. 8 when depressed, was locked in such position preferably by means of a locking bar having openings therein through which all the key plungers project, each key carrying a conical latch member adapted when the key is depressed to engage the under side of the said locking bar. 125 Said bar is adapted to be moved by a release magnet 266' to release the depressed key. Said magnet is included in a conductor 267' which leads to a pair of contacts 268, one member whereof is adapted to be engaged 130

by the armature 269 of a sluggish relay 270, said armature being connected with the free pole of a grounded battery 271. Said armature 269 in its retractive movement is adapted to effect momentary electrical engagement between itself and both members of the contacts 268 to apply current to conductor 267' and operate said release magnet. The said relay 270 is included in a conductor 272 which leads to normal resting contact of a spring 272' adapted to be operated by the armature of the polarized relay 259, said spring being connected with the feed wire 77 of the office keyboard.

15 When current is applied to the feed wire of sending apparatus F, it passes by way of the feed wire 77, of the office keyboard, through the spring 272' and back contact of relay 259 to conductor 272 and relay 270 to earth. Relay 270 attracts its armature 269, separating springs 268. An impulse of current is thereby delivered from battery 271 to conductor 267' and release magnet 266' to earth, so that in case an office 20 key has been accidentally depressed, it will be restored. Now when the office keyboard has performed its work in connection with sending apparatus F, the switching relay 79 is operated as before described, and re- 25 moves at its armature 78 and back contact current from the office feed wire 77, whereupon the relay 270 is deprived of current, and its armature 269 in retracting applies current to operate the release magnet 266' 30 and restore the depressed key.

35 *Restoration of office key when keyboard serving sending apparatus F'.*—Assume for a moment that the office keyboard is serving the sending apparatus F' and that current from the battery 52^a at said sending apparatus has been applied to the feed wire 62'. This current being of opposite polarity from corresponding battery at sending apparatus F will operate the polarized relay 259, said current passing from the feed wire 62' through the armature 78 and front contact of the switching relay 79, to the feed wire 77 of the office keyboard and thence to earth through a branch including said polarized relay. Said relay in attracting its armature moves spring 272' into engagement with a contact connected with a conductor 272'' leading to earth through a relay 270', said relay being thereupon energized, since the spring 272' is connected with the feed wire 77. Said relay is provided with an armature 269' adapted to operate a pair of contacts, one member whereof is connected with conductor 267', said armature being connected with the free pole of a grounded battery 273' and serving to apply impulses to the conductor 267' to operate the release magnet 266'.

60 *Restoration of keyboard to sending apparatus F after serving sending apparatus F'.*—When the office keyboard is through serving the sending apparatus F', the relay 263 is operated to deenergize relays 79 and 259, which thereupon restore the association of the office keyboard with the sending apparatus F. Said relay 158 when operated, at the completion of the service of the keyboard, completes a circuit from the feed wire 62' of sending apparatus F', 75 through the winding of relay 263, contacts 274 of said relay, to a conductor 275 which leads to the front contact of spring 258 of polarized relay 259, and thence by way of conductor 257, contacts 260 of cut-off relay 80 181, contacts 261 closed by the relay 158, contacts 262 of said relay 263 to earth. Relay 263 is energized in the said circuit and attracts its armature 276, which is grounded, said armature opening springs 274 and 85 engaging a member thereof connected directly with the winding of relay 263, thereby locking said relay to earth from the feed wire 62'. The armature 262 of said relay 263 opens the locking circuit of the switching relay 79 from said feed wire 62', whereupon said switching relay restores at its armatures 78, 91 the connection of wires 77, 90 of the office keyboard with the wires 62', 59 of sending apparatus F. The armature 95 78 of said switching relay in its retractive movement disconnects the feed wire 62' from the circuit of the polarized relay 259, which thereupon releases its armature, moving spring 272' to break the circuit of relay 100 270', which retracts its armature 269', causing an impulse of current to pass through the release magnet 266' of the office keys.

Primary selector and sending apparatus.—The armature 276' of the relay 270 when retracted, after the office keyboard has been disconnected from the sending apparatus and the office key restored, serves to start the operation of the primary controller, Fig. 6, which operates in conjunction with the distant selected primary selector at office No. 8 to pick out a connector adapted to reach the line of the party desired. When the trunk selector, Fig. 2, found an idle inter-office trunk line, its brushes rested in engagement with terminals connected with conductors 217, 218, 219 of a trunk line leading to office No. 8 where a primary selector, Fig. 3, forms its terminal. While I have shown a three-wire inter-office trunk, it will be understood that a two-wire trunk line may be equally as well employed.

The line conductors 217, 218 lead to the line brushes upon the arm 220 of the primary selector. Said primary selector may be provided with twenty vertical rows of terminals as shown in Fig. 8, each row representing trunk lines leading to connectors adapted to reach a given group of five hundred lines; said arm may be rotated into

operative relation to any particular row by means of a stepping magnet 221, and be lifted along the terminals of a particular row by means of a stepping magnet 222, a retaining magnet 223 being provided for said arm and included in the conductor 219, which leads from the terminal of the trunk line upon the trunk selector, through contacts 224, of a busy test relay 225, contact 19 springs 226, closed by the selector arm when in normal position, to earth. The retaining magnet in attracting its armature closes contacts 227 to complete a locking circuit for said magnet independent of the contacts 226. 15 The operation of the said stepping magnets of the selector and the selected connector is controlled by a pair of relays 228, 229 (Fig. 14) which are included in a bridge 230 of the trunk conductors 217, 218, said bridge 20 extending from conductor 217 through the relay 229, armature 231 and back contact of a relay 232, armature 233 and back contact of a relay 234, armature 235 and back contact of a relay 236, through the relay 228 25 to the trunk conductor 218. The relay 228 is responsive to a current of lower voltage than that required to operate relay 229,—for example, relay 228 may require 24 volts for its operation and relay 229, 48 volts,—30 and relay 228 in response to positive current may rock its armature in a contra-clock wise direction, while relay 229 in response to current of such polarity may rock its armature in a clockwise direction, said 35 armatures operating reversely when supplied with negative current. It should also be stated that relay 229 in operating renders ineffective all operated contacts of the relay 228, which relay of course responds to 40 the higher voltage.

When the armature of relay 229 is rocked in a contra-clockwise direction, it applies, for example, current from a high voltage grounded battery 237, for example 48 volts, 45 through contacts 238 closed by said armature to a conductor 239 which leads through contacts 240 closed by the selector arm until it begins its upward journey, through the rotary stepping magnet 221 to earth. The 50 armature of relay 229 when tilted in a clockwise direction closes a pair of contacts 240', which connect a battery 241 with a conductor 242, which leads through spring 243 and its normal contact closed by the selector 55 arm until it starts its upward movement, through the armature 244 and front contact of the retaining magnet, relay 236 to earth through contacts 245 closed by the selector arm while away from normal position. 60 Said relay 236 controls at its armature 246 and front contact a circuit leading from the free pole of a battery 247 by way of conductor 248, through normally closed contacts 249 opened by the armature of relay 65 229 when rocked in a contra-clockwise direc-

tion, contacts 250 opened by the armature of said relay when rocked in the opposite direction, armature 251 and front contact of retaining magnet 223, to a feed wire 252, from which a conductor 253 leads through the 70 armature 246 and front contact of relay 236 through said lifting magnet to a ground pulsator.

Turning now to the sending apparatus F, Figs. 6 and 7, I will describe the manner 75 in which the thousands and hundreds keys coöperate with the primary controller, to cause the selected primary selector to pick out terminals representing connectors adapted to reach the line desired. Assuming 80 that line 1465 was desired, the key I of the thousands keys and the key IV of the hundreds keys would be operated.

Each of the thousands keys is provided with a pair of springs 277, 278, adapted to 85 be forced into engagement by a plunger, which when depressed is locked in such position by means of a locking bar, controlled by a release magnet 280. Each of the springs 278 is connected with earth, and 90 its mate contact 277 is connected with a conductor 281 leading to corresponding terminals in the rows *a a'* in the primary controller which represent the two groups of 95 500 following a given thousands digit. That is to say, key I of the thousands keys, which is depressed in calling the number we have selected, serves to ground terminals "1" "1'" in the rows *a a'* respectively; the terminal "1" of row *a* controlling the advance 100 of the selector arm into operative relation to the group of connectors adapted to unite with lines 1000 to 1499, while the terminal "1'" of row *a'* (assuming its brush to be in operative condition) controls the advance of 105 the stepper arm three steps to the row of terminals representing connectors adapted to reach lines 1500 to 1999.

Normally the brush *b* of the row *a* is in circuit, said brush being cut out and the 110 brush *b'* brought into service only when the line desired is a number whose hundreds digit falls within the numbers 5 to 9 inclusive. In the present case, since I of the thousands keys and key IV of the hundreds keys are depressed, the brush *b* is in 115 operative condition. When the armature 276' of the relay 270 of the office keyboard is retracted, as above described, current flows from the feed wire 62 to a conductor 282 120 which leads through the contacts 12, 13, respectively operated by the depressed thousands and hundreds digit keys, through the armature 276' and back contact of the relay 270, retaining magnet 283 of the primary 125 controller arm 1, contacts 284 closed by the controller arm when in normal position, winding of the stepping magnet 285 of said controller, through contact springs 286 of the cut-off relay 10, to a ground pulsator 130

287. The controller arm is now advanced by the stepping magnet 285, which responds to the pulsating current in said circuit, and the retaining magnet in attracting its armature closed a pair of springs 288, which complete a branch 289, about the contacts 284 which are separated by the controller arm when it leaves normal position. These contacts 284 are for the purpose of insuring 5 the start of the controller arm from normal position. The retaining magnet is sluggish in its operation and does not respond to the pulsating character of current but remains steadily excited.
- 10 15 The armature of the stepping magnet 285 in its vibrations operates a pair of contacts 290, which applies current from a negative grounded battery 291 of for example 48 volts, to a conductor 292, which leads to the 20 back contacts of the armature 294 of relay 295, said armature being connected with a conductor 296, leading to the common wire 59. Impulses of current are thus caused to flow from battery 291 over the common 25 wire 59, ring strand 21 of the connecting circuit, trunk conductors 137, 198, 218, to the primary selector at office No. 8, thence over the bridge 230, through the relays 228, 229 to trunk conductor 217 and thence back 30 by way of trunk conductors 197, 136, link conductor 20, to ground at the armature 54 and front contact of the relay 34. This current being of 48 volts negative polarity, operates relay 229, and causes the same to 35 rock its armature in a contra-clockwise direction, said armature at the contacts 249 cutting off current from the operated contacts of the relay 228 (which also responds to this current); and said armature at its 40 contacts 238 applying current from battery 237 to conductor 239 which leads through the stepping magnet 221 of the selector arm to earth; said magnet 221 thereupon advancing the said arm.
- 45 When the controller arm 1 has taken three steps, and the selector arm three steps into operative relation to the row of terminals representing connectors capable of reaching lines 1000 to 1499, the brush *b* of the controller arm (Fig. 6) engages the terminal of row *a* which is grounded by the 1 thousands key. When said brush reaches this grounded contact, mechanism is brought into service to stop the movement of the controller arm 50 and cause the selector arm to hunt through the selected row for an idle connector. The brush *b* is connected with a conductor 296', which leads through normally closed contacts 297, 298 of each of the hundreds keys 55 and cause the selector arm to hunt through the selected row for an idle connector. The brush *b* is connected with a conductor 296', which leads through normally closed contacts 297, 298 of each of the hundreds keys 60 V to IX, through the winding of a relay 295, contact springs 299 of the cut-off relay 10, to the feed wire 62. Therefore, when the brush *b* engages the grounded terminal "1" 65 after the controller arm has taken three steps, a circuit is completed for the relays 10, 295, said circuit extending from the feed wire by way of conductor 296', normally closed contacts 297, 298, of the lower half of the hundreds keys, brush *b*, terminal "1" of the row *a* of the primary controller, conductor 281, to earth at the contacts of key 1 of the thousands keys. The cut-off relay 10 in said circuit is operated and in attracting its armature 300 separates springs 286 to open the circuit of the operating magnets of 70 the primary controller; the armature 301 of said relay is grounded and in its attractive movement separates springs 299, disconnecting brush *b* from the feed wire and engaging the member of said springs connected 75 directly with the winding of the relay 10 to include said relay in a locking circuit from the feed wire 62.
- Automatic selection of idle connector by primary selector.*—The selector arm now 80 rests in operative relation to the row of terminals connected with trunk lines leading to connectors each adapted to unite with lines numbered from 1000 to 1499. The relay 295, which is sluggish in its operation 85 and was momentarily excited by the circuit which operated the cut-off relay 10, controls the movement of the selector arm along the selected row of terminals to the terminals of an idle trunk line. The armature 294 of 90 said relay, which is connected with the common wire 59, is adapted in its attracted position to engage a front contact connected with a conductor 302 leading to the free pole of a grounded battery of, for example, 95 48 volts positive polarity 303. Thereupon an impulse of positive current flows from battery 303 by way of link conductor 21, trunk conductors 137, 198, 218, to the primary selector, through the bridge 230 and 100 the polarized relays 229, 228 and back over the line conductors, through the armature 54 and front contact of relay 34 to earth. This current is of proper voltage to operate the relay 229 and is of a polarity to cause 105 the same to rock its armature in a clockwise direction. Said armature of relay 229 in operating its contacts 250, removes current from the contacts of the relay 228 (which also responds to this current); and in closing its contacts 240' applies current from battery 241 to conductor 242, which leads through the contacts 244 closed by the retaining magnet of the selector arm when energized, through the relay 236 to earth at 110 contacts 245 which are now closed due to the operated position of the selector arm. The relay 236 now attracts its armatures 246, 247, and 304; the armature 235 maintains the bridge 230 open during the selection of 115 an idle trunk line for purposes of test to be later explained, while the armature 246 completes the connection of conductor 253 including the lifting magnet 222 of the selector and a ground pulsator with the feed wire 120 125 130 135

252, which receives current at the armature 251 and front contact of the retaining magnet of the selector. Said lifting magnet moves the selector arm upwardly to the terminals of the first trunk line leading to a connector adapted to reach the desired line. When the arm has taken the said initial step, contacts 240 are opened to disconnect the stepping magnet 221 from the battery lead of conductor 239, and contact spring 243 is separated from its anvil and brought into engagement with a contact spring connected with a conductor 305 leading through the armature 304 and front contact of the relay 236 to the local brush of the selector arm.

The relay 236 is now connected directly to earth from the local brush of the selector arm independent of its initial circuit which was opened at one point at the spring 243 and its back contact, said ground branch including the relay 236 being formed by conductor 305, armature 304 and front contact of said relay, spring 243 and its front contact, conductor 242, winding of relay 236, and contacts 245. Now if the first trunk line be in use, current will be present at its local terminal 306, and the relay 236 will be maintained energized, thereby continuing the circuit of the stepping magnet 222, which will lift the selector arm another step to the terminals of a second trunk line and so on until an idle trunk line is reached. Such idle trunk line will have no potential present at its local terminal, and relay 236 will be deprived of current, releasing its armatures; armature 246 opening the circuit of the lifting magnet, armature 235 restoring the continuity of the bridge 230; and armature 304 breaking the connection of relay 236 with the local brush of the selector arm, and in engaging its back contact applying current from a grounded battery 307 to the portion of conductor 305 leading to said local brush, to apply a test potential to the multiples of terminal 306. The brushes of the selector are now in engagement with the terminals 308, 309, 306 of trunk conductors 310, 311 and 312 leading to a connector adapted to unite with the line of subscriber No. 1465.

I will now describe the manner in which the arm of the selected connector is first moved into operative relation to the bank of terminals in which is located the terminals of line 1465; second, the movement of said arm under the control of the depressed key, representing the tens digit "6" of the called line, to the row of terminals in which the called line terminals are located; and third, the movement of the connector arm along the selected row, under the control of the units key representing the units digit "5", to the desired line terminal.

65 The connector, Fig. 4, may be provided

with five banks of line terminals, each bank being preferably provided with the terminals of 100 lines. Said connector is provided with an arm 315 carrying line brushes 316, 317 and a local brush 318, said arm being adapted to be rotated in long steps by a magnet 319 from group to group of terminals, and in short steps from row to row of a particular group by a stepping magnet 320. The upward movement of the arm along the terminals of a particular row is effected by lifting magnet 321, a retaining magnet 322 being provided for holding the arm in any of its operated positions. When the local brush of the selector arm engaged the local terminal 306 leading to the connector current from the battery 307 passed over conductor 312, through the winding of the retaining magnet 322 of the connector, contacts 323 closed by the connector arm in its normal position, to earth. The retaining magnet thereupon attracted its armature 324, which operated contacts to complete a locking circuit for the retaining magnet independent of the contacts 323.

Operation of auxiliary controller under the control of the depressed hundreds key.—The advance of the connector arm into operative relation to the bank of terminals in which are located the called line terminals, is effected by means of the depressed hundreds key, and the auxiliary controller E, Fig. 7. Said controller is provided with a row of five terminals representing the five banks of contacts of any connector, this arrangement depending, of course, upon the number of banks in the connector. Each terminal is connected by a conductor 325 with the contact springs 326 of the two hundreds keys whose numbers represent the hundreds digits of lines which would fall in the particular bank represented by said terminal upon the auxiliary controller; that is to say, keys O and V represent the hundreds digits of all lines which would terminate in the first banks of connectors serving both groups of 100 of any particular thousand lines; therefore, the springs 326 of said hundreds keys would be connected with the first or 0 terminal of the auxiliary controller. In the case of the line with which we are seeking connection, No. 1465, the terminals of such line would be found in the fifth group of 100 lines of the selected connector, and key JV of the hundreds keys would have its spring 326 connected with the last terminal "4" of the auxiliary controller.

The starting of the auxiliary controller is effected by means of a relay 328, said relay being connected at the armature 329 and back contact of the sluggish relay 295 (which was momentarily operated to start the automatic selection of the primary selector) in a conductor 330 leading from the

free pole of a positive 24 volt battery 331, through the armature 332 and front contact of the cut-off relay 10 (which is now energized) winding 333 of the test relay 328, 5 armature 334 and back contact of the cut-off relay 335 of the auxiliary controller, through normally closed contacts 335, opened by the armature of the retaining magnet 336' of the auxiliary controller 10 when operated, to the common wire 59 which is connected through the link conductor 21 and trunk conductors 137, 198, 218, with the bridge 230 at the primary selector. This bridge as before described is maintained 15 opened, during the selection, by the primary selector of an idle connector, at the armature 235 and back contact of the relay 236. When, however, an idle trunk line is secured the relay 236 is deenergized and 20 closes at its armature 235 the bridge 230. Current from the battery 331 may now flow through the test relay 328, over the line conductors, through the said bridge, and back over the trunk conductors to earth at the 25 armature 54 and front contact of the relay 34 in the connecting circuit. The starting relay 328 at the sending apparatus is now operated and the polarized relay 228 at the primary selector is also energized. This 30 current being of low voltage and of positive polarity, causes the polarized relay 228 to rock its armature in a contra-clockwise direction, closing contacts 336, thereby applying current from battery 247 to conductor 248 which leads through the contacts 249 and 250 of relay 229 (which is unresponsive to current in the testing circuit) to conductor 337 and thence through the said contacts 336 to conductor 239, thence by way 35 of conductor 338 of connecting relay 340, to the back contact of armature 339 of said relay, said armature being connected through back contact of armature 447 with the portion of trunk conductor 217 leading 40 directly to the line brush of the selector which rests in connection with the terminal of trunk conductor 310 leading to the connector. Said conductor 310 leads to a contact spring 341, which normally rests in 45 engagement with a contact connected with a conductor 342 leading through the armature 343 and back contact of a relay 344, through branch conductors 345 and 346 to earth. The branch 345 includes the short step magnet 320 of the connector which may be responsive to current only of high voltage, for example 48 volts, while the branch 346 includes the long step magnet 319, responsive to a current of lower voltage, for example, 50 24 volts. When the short step magnet is operated in response to a high voltage current, it opens at its armature and back contact the branch including the long step magnet, to prevent the operation thereof. 55 Therefore, when the polarized relay 228 at the selector responded to the testing current, its armature was rocked in a direction to close contacts 336 and apply current from battery 247 to the connector stepping magnets. This current operates the magnet 319, 70 which gives the connector arm a long step, which however is simply incidental to the operation.

The relay 328, when operated in the testing circuit before traced, serves to start the 75 operation of the auxiliary controller. Said relay closes at its armature 348 and front contact a circuit for the retaining magnet 336' of the auxiliary controller arm 349 and the stepping magnet 350 thereof, from the 80 free pole of a grounded battery 351, conductor 352, through contact springs 353 closed while the controller arm is in normal position, through said armature 348 and front contact of the starting relay, 85 through the normally closed contact springs 354 of the cut-off relay 335' of said auxiliary controller, to the armature 300 of the cut-off relay 10 of the primary controller (which relay is at this time energized in a 90 locking circuit from the feed wire) said armature being connected with a member of contacts 286 connected with conductor 282 and the ground pulsator 287. The stepping and retaining magnets of the auxiliary controller respond to the pulsating current in 95 this circuit and the stepping magnet advances the controller arm. The retaining magnet, after attracting its armature, does not respond to the pulsating character of the current in its circuit, but maintains its armature steadily energized, the armature of said relay opening contacts 335 to disconnect the test relay 328 from the common wire 59, and also closing a pair of contacts 355, which completes a branch conductor 356 about the contacts 353, separated due to the advance of the controller arm, said contacts 355 maintaining the circuit of the operating magnets of the controller independent of the said contacts controlled by the controller arm. 100

The armature of the stepping magnet 350 in its vibration, makes and breaks a pair of contacts 357, which connects a battery 331 with the common wire 59 by means of a conductor 360 which leads through the armature 361 and back contact of a relay 362 associated with the primary controller, through the said contacts 357 operated by the stepping magnet of the auxiliary controller, armature 363 and back contact of the cut-off relay 364 associated with the auxiliary controller, to the common wire 59, and thence by way of link conductor 21, 110 trunk conductors 137, 198 and 218 to the primary selector, through the bridge 230 thereof, including the polarized relays 228 and 229, back over the line conductors to earth at the armature 54 and front contact 115 120 125 130

of the relay 34 associated with the connecting circuit. Battery 331 being of positive polarity and 24 volts, operates merely the relay 228 in the bridge 230, which relay rocks its armature in a contra-clockwise direction to close the contacts 336. Each time the said contacts are closed an impulse is supplied from the battery 247 at the primary selector to conductors 248, 337, 239, 10 trunk conductor 217, through the contacts of the primary selector, trunk conductor 310 leading to the selected connector, and at said connector over conductor 342 and the branches 345, 346 thereof to earth, such 15 current, however, operating only the stepping magnet 319, which advances the connector arm 315 in long steps from bank to bank.

In the present case the line desired lies 20 in the fifth bank of terminals of the selected connector and when the connector arm has taken five steps into operative relation to the desired bank, and the auxiliary controller arm has taken five steps, the cut-off 25 relay 335' of the auxiliary controller is operated, which opens the circuit of the operating magnets of the controller. From the brush 365 of the controller arm, which sweeps over the set of five terminals a^2 30 thereof, a conductor 366 leads through the contact springs 367 of the cut-off relay 335' of said controller to the feed wire. Therefore, when the controller arm has taken five steps, its brush 365 will engage the terminal 35 rail "4" grounded by the key IV of the hundreds keys, whereupon a circuit will be completed for said cut-off relay 335', whose grounded armature 368 in its attractive movement separates springs 367 to open the 40 circuit of the brush 365, said armature engaging the member of said springs connected directly with the winding of the cut-off relay to include said relay in a locking circuit from the feed wire. Said relay 335' is 45 provided with a second armature 369, which in its attractive movement breaks the connection of the test relay 328 with the common wire, this break taking the place of contacts 335, which are now closed due to the 50 deenergization of the retaining magnet of the auxiliary controller.

Operation of primary controller under control of tens key to select row in connector containing desired line terminals.—
55 The relay 335' serves to switch into service the primary controller, which co-operates with the depressed tens key to move the connector arm along the rows of terminals in the selected bank to pick out the row 60 wherein is located the called party's line terminals. The primary controller is provided with a row a^2 of ten terminals representing the "tens digits" of subscribers' lines, and each of the tens keys is provided 65 with a contact spring 370 connected with

earth and adapted when operated to engage a contact 371 connected with a conductor 372 leading to the terminal in the row a^2 representing the number corresponding to the digit represented by the particular tens key. Each of the tens keys is adapted when depressed to effect the operation of a pair of contact springs 373 in order to prevent the operation of the primary controller in its association with the tens keys before one of their number is depressed; and each key when operated is locked in such position under the control of a release magnet 374.

In the present case, calling line 1465, key VI of the tens keys would be depressed, thereby applying a ground to the terminal "6" of the row a^2 of said primary controller. The controller arm is provided with a brush 375 adapted to sweep over said row until it reaches the terminal whose electrical condition has been changed by the depression of its corresponding tens key. When, therefore, the springs 373 have been closed by the depression of the key VI of the tens keys, and the armature 369 of the cut-off relay 335' of the auxiliary controller has been operated, a circuit is completed from the feed wire 62 to operate the stepping and retaining magnets of the primary controller, said circuit extending by way of conductor 282 through the contacts 42 and 43 of the thousands and hundreds keys respectively, which are now closed, armature 276' and back contact of the starting relay of the sending apparatus (Fig. 5) through the retaining magnet 283 of the primary controller arm, contacts 284 closed by the controller arm in its normal position, stepping magnet 285 of said controller to a conductor 376, which leads through the contacts 373 closed by the depressed tens key (Fig. 7) contact springs 377 of the relay 362 of said primary controller, to the armature 369 of the cut-off relay 335' of the auxiliary controller, which is now energized, through a member of the contacts 354, to a conductor 352, armature 300 and front contact of the cut-off relay 40 of the primary controller, to conductor 282 and pulsator 287 to earth. As before described, the contacts 284 are for the purpose of insuring the start of the controller arm from normal position, the armature of the retaining magnet closing at its contacts 288, a branch 289 about said contacts 284 after the arm has started. The stepping and retaining magnets of the primary controller respond to the current in the circuit last traced and advance the controller arm 1, whose brush 375 sweeps over the terminals in the row a^2 . The stepping magnet of this controller serves to operate the contacts 290 which supply current from the 48 volt negative battery 291 by way of conductors 292 and 296 to the common wire 59, and thence over the line conductors to the bridge 230 at 136

the selector and back over the line conductors to earth at the contacts of relay 34. This current operates the polarized relay 229, which rocks its armature in a counter-clockwise direction, removing at its contacts 230 current from the actuated contacts of the polarized relay 228, and at its contacts 238 connecting a 48 volt battery 237 with conductor 239, said current thereupon passing by way of conductor 338 through the armature 339 and back contact of the relay 340 to conductor 217, through the contacts of the selector conductor 310, and thence by way of conductor 342 to earth through the branch 345 including the short step magnet 320 of the connector. Said magnet 320 thereupon rotates the connector arm in short steps from row to row of the selected bank, and at its armature and back contact maintaining open the circuit of the stepping magnet 319.

When the connector arm has taken seven long steps into operative relation to the row of terminals representing lines 1460 to 1469, 25 and the controller arm has taken seven steps to bring its brush 375 into engagement with the terminal "6" which is grounded by key VI of the tens keys, relay 362 will be operated to open the circuit of the primary controller stepping magnet and stop the movement of said arm. From the brush 375 a conductor 378 leads through contacts 379 closed by the armature of the retaining magnet of the controller when in its attracted position, through the armature 380 and front contact of the cut-off relay 335' of the auxiliary controller, which is now operated, through contact springs 381 to the point 382', where said conductor divides into two 35 branches 383, 384; branch 383 leading through the cut-off relay 362 to the feed wire 62, while the branch 384 leads through contact springs 381 of relay 362, a winding 385 of the starting relay 328 to said feed 40 wire. Now when the brush 375 engages the terminal grounded by the key VI of the tens keys, both the relays 362 and 328 are operated. The armature 385' of the cut-off relay 362 is grounded, and in its attractive 45 movement separates springs 381, opening the connection of brush 375 with the feed wire and engaging the member of said springs connected with point 382' to complete a locking circuit for the cut-off relay 362 and 50 the test relay 328 from the feed wire. The armature 386 of said cut-off relay in its attractive movement separates springs 377, thereby opening the circuit of the operating magnets of the primary controller. 55

60 Operation of depressed units key in conjunction with auxiliary controller to select desired line terminals in selected row.—The relay 328 now serves to bring into service the auxiliary controller, which operates in 60 conjunction with the depressed units key

representing the units digit of the line desired, namely 1465, to move the connector arm upwardly along the selected row of terminals to the desired line terminals. The auxiliary controller is provided with an additional row a^1 of ten terminals representing the units digits of subscribers' lines, said terminals being connected with conductors 387 leading to the contact springs 388 of the units keys corresponding to the numbers of the said terminals. Each units digit key is provided with a grounded contact spring 389 adapted when the key is depressed to engage said spring 388, thereby applying a ground or changing the electrical condition of the terminal in a row a^1 corresponding to the digit of a key depressed; said key when operated being locked in such position under control of a release magnet 390. The auxiliary controller arm carries a brush 391 adapted to sweep over said terminals until the grounded terminal is reached, when the cut-off relay 364 is operated to open the circuit of the operating magnets, the stepping magnet during this movement of the controller arm sending impulses out to the connector to actuate the lifting magnet thereof. Each units key when operated closes a pair of springs 392 (which are provided to prevent the operation of the auxiliary controller in this connection until a units key has been depressed) and when the said springs are closed and the test relay 328 has been operated after the primary controller has served the depressed tens key, a circuit is completed from the free pole of battery 351, conductor 352, retaining and stepping magnets of the auxiliary controller, through the contact springs 353 controlled by the controller when in normal position, through the armature 348 and front contact of the starting relay, to a conductor 393 which leads through the contacts 392 closed by the depressed units key, through the armature 386 and front contact of the cut-off relay 362 of the primary controller (which has been previously energized) to a conductor 376, which leads through the armature 369 and front contact of the energized cut-off relay 335' of the auxiliary controller, to conductor 352, which leads through the armature 300 and front contact of the operated cut-off relay 10 of the primary controller to conductor 282 and ground pulsator. The operating magnets of the auxiliary controller respond to this pulsating current, the armature of the retaining magnet closing at contacts 355 the branch 356 about the now open contacts 353 of the controller arm; maintaining the circuit of said operating magnets independent of the contacts 353. 110

The armature of the stepping magnet 350 of the auxiliary controller in vibrating to advance the controller arm, applies current 115

at its contacts 357 intermittently from the 48 volt battery 303 to the common wire 59, said current flowing from the free pole of said battery by way of conductor 394, armature 361 and front contact of the operated cut-off relay 362 of the primary controller, to conductor 360, which leads through the contacts 357 operated by the stepping magnet, armature 363 and back contact of the inert cut-off relay 364 of the auxiliary controller, to the common wire 59. Said current passes out over the line conductors through the bridge 230 at the primary selector, and back over the line conductors to ground at the armature and front contact of relay 34 at the connecting circuit. This current operates the polarized relay 229 in the bridge 230 at the primary selector, and being positive in character causes said relay 20 to rock its armature in a clockwise direction, said armature opening its contacts 250 to remove current from the operated contacts of relay 228, and applying at its contacts 240' current from the battery 241 to conductor 242, said current passing from said conductor by way of wire 396 through the armature 397 and back contact of the relay 340, to the portion of trunk conductor 218 leading through contacts of the selector to the trunk conductor 311. Said trunk conductor 311 includes a spring 398, which normally rests against a contact connected with a conductor 399 leading through the lifting magnet 321 to earth, whereupon said magnet 35 is operated to move the connector arm along the terminals of a selected row. A branch 401 also leads from said conductor 399 through contact springs 402 and the polarized relay 344, normally closed contacts 403 of a marginal relay 404, armature 324 and front contact of the retaining magnet to earth. Current from the battery 241 which is supplied to the lifting magnet 321 also passes through the branch including the polarized relay 344, but said battery is of improper polarity to actuate the said polarized relay.

When the connector arm has been lifted through six steps to bring its brushes into engagement with the terminals of line 1465, and the auxiliary controller arm has taken six steps to bring its brush 391 into engagement with the terminal of row *a* grounded by the depressed units key V, the cut-off relay 364 is operated to open the circuit of the operating magnets of the auxiliary controller and stop the movement of the controller arm. When the cut-off relay 362 of the primary controller was operated, after said controller had served the tens keys, and the armature of the retaining magnet of the auxiliary controller had been operated to close contacts 405, the brush 391 of the auxiliary controller was connected with the feed wire 65 by way of conductor 406, contacts 405 closed

by the armature of the retaining magnet 336, through the armature 407 and front contact of the operated cut-off relay 362 of the primary controller, through the contact springs 408 of the cut-off relay 364 of the auxiliary controller, to the feed wire 62; thus when brush 391 of the auxiliary controller engages the grounded terminal, said cut-off relay 364 is operated. The armature 363 of said cut-off relay in its attractive movement disconnects the contacts 357 operated by the stepping magnet of the auxiliary controller from the common wire 59, while the armature 409 of said cut-off relay, which is grounded, separates springs 408, disconnecting the brush 391 of the auxiliary controller arm from the feed wire, and engages the member of said springs connected directly with the winding of said cut-off relay, to complete a locking circuit for said cut-off relay from the feed wire.

Restoration of sending apparatus and disassociation of same from connecting circuit.—It will be remembered that the relay 34 at the connecting circuit, which controlled the association of the sending apparatus therewith, is locked up in a circuit leading from the battery 52 at the sending apparatus through the controlling relay 53 of the sending apparatus, conductor 50, through the armature 47 and back contact of the switching relay 43, conductor 44, through the relay 46, in multiple through the winding 40 of relay 34 and winding 42 of the switching relay 43, through the armature 39 and front contact of said relay 34, to earth. The relay 46 and winding 42 of relay 43 in this circuit are not energized, due to the lack of sufficient current strength in said circuit. When, however, the cut-off relay 364 of the auxiliary controller is operated, after the connector has completed connection with the desired line, the armature 410 of said relay 364 completes a short circuit 411 about the controlling relay 53 of the sending apparatus. Increased current is thus caused to flow from battery 52 over conductor 50 through the specified windings of the relays 46, 43 and 34 to earth. This current has no effect on the switching relay 43, but does cause the relay 46 to attract its armature. The armature 412 of said relay 46 is connected to earth, and in its attracted position engages a contact connected with conductor 413 leading to the portion of conductor 44 between the relay 46 and the other two relays, thereby short circuiting relay 34, causing the same to retract its armatures, thereby disconnecting the sending apparatus from the connecting circuit and restoring the normal circuit conditions of the link conductors 20, 21 leading to the district selector. The controlling relay 53 of the sending apparatus, when short circuited, as previously described, retracted its armature

- 61, which removed the current of battery 52 from the feed wire 62, whereupon the relays which were locked in circuit with the feed wire were deenergized, and the mechanism of the sending apparatus restored to normal condition. The said controlling relay is also provided with an armature 414 connected with the free pole of battery 52 said armature in its attractive movement 10 making a momentary electrical contact with a pair of springs 415, one member whereof is connected with a conductor 416 leading in multiple to earth through the release magnets 390, 374, 417, 280, of the digit keys, 15 which are thereupon operated to restore the depressed digit keys to normal position. The sending apparatus is now in position to serve other connecting circuits, and the office keyboard, unless taken by another 20 sending apparatus for use is reassociated with the same.
- Test of the called line.*—In the system shown, the testing apparatus is located at the primary selector, which enables a large saving in apparatus, for there are a considerably less number of primary selectors employed in a given exchange than there are connectors, and it is a matter of considerable expense to provide each connector 25 with individual testing apparatus. The testing conductor may be said to extend from the local brush 318 of the connector arm over conductor 418 through the winding of a marginal relay 404, through the armature 343 and front contact of the polarized relay 314, which contacts are open up to the moment of test, to conductor 342 and trunk conductor 310, back to the primary selector, through contacts thereof to trunk conductor 35 217, through the armature 339 and back contact of the connecting relay 340, to conductor 338 and to a wire 419, which leads through the armature 420 and normally open contact of a relay 232, winding 421 40 of a relay 422, through a polarized relay 423, winding of a marginal connecting relay 340, to ground at the contacts 227 closed by the retaining magnet. When connection is made with a called line, this testing conductor is open at two points, namely, the armature 420 and front contact of the relay 232 of the selector, and the armature 343 and front contact of the polarized relay 314 of the connector. (See Fig. 11.)
- 45 From the local terminal 424 of the called line, with which connection has been made, a conductor 425 leads to the test thimble of the answering jack and to the free pole of a grounded battery 426'. As before stated, the relay 404 at the connector and the relay 340 at the selector are marginal in their operation. Now in case the line called for has been made busy either at its answering jack by a connecting circuit united with 50 said jack, or at another connector uniting
- with the terminals of such line, a shunt will be established around the test conductor before traced, when completed, and the said marginal relays will not receive sufficient current for their operation, whereupon the busy test will be applied to the operator's connecting circuit.
- I will now describe the method of closing the said test conductor when the brushes of the connector arm have made connection 75 with the terminals of the called line.
- After the "units key" and the auxiliary controller, operated, as above described, the cut-off relay 364 was operated, and at its armature 363, applied an impulse of current from the battery 52 to the common wire 59, such current passing out over the trunk conductors and through the bridge 230 at the primary selector and back over the trunk conductors to earth. This current 80 being of negative polarity and 24 volts, operates merely the relay 228 in said bridge 230, said relay thereupon rocking its armature in a clockwise direction, thereby closing a pair of contacts 425 to complete a circuit 85 for the polarized relay 344 at the connector, and closing a pair of contacts 426 to complete a circuit for the relay 232 at the selector. These two relays control, as previously described, the continuity of the 90 test conductor.
- I will first trace the circuit completed by contacts 425 of the relay 228 for the polarized relay at the connector. Said polarized relay is responsive only to negative current, 100 and when the said contacts 425 are closed by relay 228 (relay 229 remaining unresponsive) current flows from the battery 247 of negative polarity over conductor 337 to conductor 427, which leads through the contacts 425 to conductor 242, and thence by way of wire 396, through the armature 397 and back contact of the relay 340 to the trunk conductor 218, through contacts of the selector to trunk conductor 311 leading to the connector, and thence by way of conductor 399, through contacts 402 of relay 344, winding of said relay, through the contact springs 403 of relay 404, to earth at the armature 324 and front contact of the 110 retaining magnet of the connector. The polarized relay 344 is now energized and attracts its armatures 343, 428; armature 343 completing at its front contact one break in the test conductor; and the armature 428, which is connected with the free pole of a grounded battery 429 of negative polarity, in its attractive movement separates the springs 402, engaging the member thereof connected with the winding of the relay 344, thereby completing a locking circuit for said relay, extending through the contact springs 403 controlled by the relay 404 to earth through the armature 324 and front contact 115 of the retaining magnet of the connector.
- 120
- 125
- 130

The contacts 426 at the selector complete a circuit for the relay 232, said circuit extending from the feed wire 252 connected with battery 247 to a conductor 428' leading through the armature 429' and back contact of a connecting relay 340, through the winding 430 of the relay 232, to earth. The armature 231 of relay 232 in its attractive movement maintains the bridge 230 open during the test. The testing circuit is now complete, current flowing from the local terminal of the called line by way of conductors 418, 342, 310, 217, 338, 419, to earth. The relay 404 at the connector and the relay 340 at the selector do not respond in case the called line is busy, due to the shunt about the testing conductor established at some other connector or connecting circuit, and the combination provided by the operated condition of the relay 232 and the inert condition of the relay 340 serves to operate a sluggish relay 225, which applies a busy signal to the connecting circuit and effects the restoration of the primary selector and the connector. The circuit to operate the said relay 225 extends from the feed wire 252 over a conductor 431, through contacts 432 of polarized relay 423, through normally closed contact springs 433 of the marginal connecting relay 340, through the armature 434 and front contact of the relay 232, through the winding 435 of said busy test relay, through contact spring 436 and its resting contact of said relay 423, through the armature 435' and back contact of the ringing relay 234, to the contact of a pulsator 436' connected with the free pole of a battery 437 of opposite polarity to the battery 247. The relay 225 is operated by current in the circuit traced and attracts its armatures 438 and 439; armature 438 being connected through the winding 440 of said busy test relay to earth. In its attractive movement separates springs 224, engaging the member thereof connected with the portion of conductor 219 leading to the trunk selector and battery, whereupon said relay is locked up under the control of the trunk selector. The separation of contacts 224 breaks the locking circuit of the retaining magnet 223 of the primary selector, which permits the selector arm to return to normal position, whereupon the retaining magnet of the connector is de-energized and the arm restored.

The armature 439 of said busy test relay, in engaging its front contact connects a busy test apparatus with a conductor 441 leading to bridge 230 and the trunk conductor 218. Said busy test apparatus may comprise a vibrating arm adapted to intermittently engage a ground contact and cause an intermittent excitation of the supervisory relay in the connecting circuit representing the called line, whereby the supervisory lamp signal gives a distinctive indication of the busy

condition of the called line. Said vibrating arm also intermittently engages a contact connected with a busy tone apparatus, which will indicate to the operator when she listens in by means of her telephone set the busy condition of the called line. The operator upon noting the busy condition of the called line, would so inform the calling party, and thereupon remove her answering plug from the jack of the calling line, whereupon the selecting mechanism would be automatically restored to normal condition.

Signaling the called party.—I will now assume that the line of the called party is free, so that when the line brushes of the connector rest in engagement with the terminals of line 1465 and the testing conductor is completed, there will be no shunt present about said testing conductor, and the marginal relays 404 and 340 will be energized. The relay 404 at the connector, when thus operated, attracts its armatures 442, 443 and 444; the armature 442 separates the springs 403 to open the circuit of the polarized relay 344, engaging the member of said springs connected directly with earth to complete a locking circuit for the relay 404, independent of the polarized relay 344 and under the control of the armature 324 of the retaining magnet. The armatures 443 and 444 of said relay 404, in their attractive movement, separate springs 398 and 341 from their anvils, completing the continuity of trunk conductors 310, 311 between the primary selector and connector, and disconnecting from said trunk conductors the local apparatus of the connector.

The relay 340 at the selector, when operated, completes a circuit for the ringing relay 234, opens the circuit of the busy test relay to prevent its operation, and locks itself in a circuit under the control of the retaining magnet of the primary selector. The armatures 339, 397 of relay 340, in their attractive movement, complete the continuity of the portions of the trunk conductors 217, 218, between the trunk selector and the contacts of the ringing relay, and disconnect the conductors 396, 338 used in selection from the trunk conductors. The armature 445 of the relay 340 is connected by conductor 485 with conductor 419 between the winding 421 of the relay 422, and the polarized relay 423, and said armature 445 in its attractive movement separates contact springs 433 to prevent the operation of the busy test relay, and engages the member thereof connected with the feed wire 252 by means of conductor 431, so completing the locking circuit for said relay 340 from the feed wire, conductor 419, winding of said relay 340, to earth at the contacts closed by the armature of the retaining magnet 223. (See Figs. 11 and 12.) The armature 429' of said relay 340, which is connected by con-

ductor 428' with the feed wire 252, in engaging its front contact, completes a circuit for the ringing relay 234, said circuit extending from the feed wire through said 5 armature and front contact to a conductor 446, which leads through the winding of said ringing relay, through contact springs 442' of the relay 232, to earth. The ringing relay is now energized, and serves to 10 automatically apply ringing current to the line of the called party, and also to maintain open at its armature 233 the bridge 230 to prevent the operation of the supervisory relay at the connecting circuit. The 15 armature 447 of said ringing relay is connected directly with the portion of conductor 217 leading to the primary selector arm, and the front contact of said armature is connected with a conductor 448 leading 20 through a winding of a relay 449 to the free pole of a ringing generator 450. The armature 451 of said ringing relay is connected directly with a portion of a trunk conductor 218 leading to the primary selector 25 arm, said armature being adapted to engage a front contact connected with a conductor 452 leading to earth through a winding of said relay 449. Therefore, when the ringing relay is energized, current 30 from the ringing generator 450 flows over conductor 448, through the armature 447 and front contact of the ringing relay, to trunk conductor 217, through the contacts of the primary selector to trunk conductor 35 310, and through the line brush 316 of the connector arm and a line terminal of the called line, out over a limb of the called line, through the bell at the substation thereof and back over the opposite limb 40 of said line, through the brush 317 and the other line terminal of the called line, over trunk conductors 311 and 218 through the armature 451 and front contact of the ringing relay, conductor 452 and a winding of 45 the relay 449 to earth. The relay 449 is arranged to be unresponsive to said ringing current, owing to the resistance of the bell bridge at the substation, but said relay is adapted to respond when a called subscriber 50 in response to the signal removes his telephone from its hook, thereby reducing by the shunt about the bell bridge the resistance in circuit with said relay. The relay 449, when operated, completes 55 a circuit for the relay 232 which in turn completes a locking circuit for itself under the control of the retaining magnet 223 and also opens the circuit of the ringing relay 234. The armature of the relay 449 in its attracted position completes a circuit for said relay 232 from the feed wire 252 over the conductor 428' to the armature 429' and front contact of the relay 340, thence to a conductor 453, which leads through the 60 winding 454 of said relay 232, to conductor 428', from which the branch 455 leads through the armature and front contact of relay 449 to earth. The relay 232 is now energized and attracts its armatures; armature 475 separating springs 442' to open the circuit of the ringing relay 234, said armature engaging the member of said springs which is connected directly to earth; and being itself connected with conductor 428' and the winding of relay 232, completes a locking circuit for said relay 232 from the feed wire 252 by way of conductor 428', through the armature 429' and front contact of the relay 340, conductors 446, 453, winding 454 of said relay 232, armature 455' and front contact of said relay to earth. The armature 231 of said relay in its attractive movement opens the bridge 230, which has been opened during ringing at the armature 233 of the ringing relay, so 85 as to maintain said bridge open during the conversation and cause no interference with the transmission of talking current or signaling current. The armatures 447, 451 of the ringing relay in their retractive movement complete the continuity of conductors 217, 218, so bringing the supervisory relay representing the called line under the control of the called party to enable the same to respond to current from the central office battery 22 in response to the movement of the called party's telephone hook.

Selective signaling of multi-station lines.— Let us now assume that the subscriber with whom conversation is desired, is one of a number of parties on the same line, for example, subscriber No. 4 on the party line shown in Fig. 9. In said figure are shown the connector terminals of the stations of the party line, it being understood that the brushes of the connector arm before referred to would sweep over said terminals. The operation of the selecting proceeds as before described up to the moment when the connector brushes stop at the terminals representing station No. 4.

I preferably control the application of ringing current to the proper limb of the party line by the interconnection of the terminals as shown. Thus the terminal 473 representing station No. 1 of the party-line, which is connected by conductor 474 with the limb 475 of the party line, is connected with a conductor 476, which leads to the terminal 477 in station No. 2, terminal 473 of station No. 3, to terminal 477 of station No. 4. In like manner, the terminal 477 of station No. 1, which is connected by conductor 478 with the limb 479 of the party line, is connected with a wire 480 leading through the terminal 473 of station No. 2, terminal 477 of station No. 3, terminal 473 of station No. 4. Four local terminals 481 of the stations of the party line are con-

nected by conductor 482, a resistance 483 being included in said conductor between the terminals 481 of the second and third stations. The conductor 482 is connected 5 with the thimble of the answering jack of the party line and with the free pole of the battery associated with said line, and the resistance 483 is adapted when placed in series with the testing conductor before traced to 10 prevent the operation of the relay 422 at the distributor, which controls the character of current to be applied to the line conductors. When the connector arm reaches the terminals 477, 473 and 481 representing station No. 4, the contact brush 316 of the connector arm will rest upon the terminal 477, which is connected by conductors 476, 474 with the limb 475 of the line, and contact brush 317 of the connector-arm will rest 15 upon terminal 473 which is connected by conductors 480, 478 with the limb 479 of the line.

The third terminal 481 will be engaged by the local or test brush of the connector 20 arm, and a circuit will be completed from the free pole of the battery associated with the party line over wire 482, resistance 483, local brush 318 and local terminal 481, local wire 418 to the armature 343 and front contact 25 of relay 344, thence to the line wire 310, thence through the contacts of the primary selector, through the armature 339 and back contact of the connecting relay 340, conductor 419, armature 420 and front contact of 30 the continuity relay 232, winding 421 of the selective ringing relay 422, through the polarized relay 423, winding of the connecting relay 340, to earth at the contacts 35 227 controlled by the retaining magnet of the selector (see Fig. 12). The relay 422 will be unresponsive to this current, due to the inclusion of the resistance 483 in its circuit, and its armature 422' remaining in its retracted position, current from the negative 40 battery 450 will be applied to the limb 475 of the party line and operate the signal bell at station No. 4 of said line. Relay 449 will respond when the called party answers, as 45 in the case of the single station line.

50 Assume that station No. 2 were desired: In such event, resistance 483 would be excluded from the circuit of the winding 421 of the relay 422 at the distributor, and said relay would attract its armatures 422' and 421', the relay 340 also responding to this current to complete a circuit for the ringing relay which applies the current determined by relay 422 to the called line by way of the distributor and connector. The armature 422' in its attracted movement connects a positive ringing generator with conductor 448, which is united by the relay 234 with the line conductor 217, to effect the operation of the bell at station No. 2.

65 The relay 422 is provided with a holding

winding 484 included in a conductor 485, leading from the local wire 419, to the armature 445 of the relay 340, which in its attracted movement engages a contact spring connected with the feed wire 252 by way of 70 conductor 431. Said winding 484 is normally short-circuited at the armature 421' and back contact. But when said relay is initially energized as above described by means of the winding 421, the short circuit 75 is broken by the attraction of said armature 421' and the winding 484 is included in a locking circuit from the feed wire 252 by way of the conductor 431, armature 445 and front contact of relay 340, polarized relay 423, which is not responsive to this current, connecting relay 340, to earth at the contacts controlled by the retaining magnet. It will thus be seen that first the circuit of 80 relay 422 extends through the initial energizing or main winding 421 from the feed wire, and when said relay operates, a circuit from the feed wire 252 through the winding 484 is substituted, said circuit being under the control of the retaining magnet. (See Fig. 12.)

90 *Calling a private branch exchange.*—A private branch exchange will be represented upon a given connector by a number of sets of terminals, as shown in Fig. 10, and when the connector arm has been advanced to bring its brushes into engagement with the terminals representing the first trunk line, in case such line is busy, means must be provided to be automatically operated at such 95 time to advance the arm to the next terminals. I provide mechanism at the primary selector (see Fig. 13) which controls such operation. The local terminals of the trunk lines, as shown, may all, except the last, be connected with a source of current of opposite polarity to that associated with the subscribers' lines terminating in the connector. For example, the first four of the trunk 100 lines shown may have their local terminals connected with the free pole of a positive battery, the last trunk line being connected in the same manner as the subscriber's line.

105 At the distributor I preferably provide the polarized relay 423, which controls the advance of the connector arm from a busy trunk line terminal to the next trunk line terminal, and so on, until an idle trunk line is reached. Said relay is responsive only 110 to positive current and the combination provided by the inert condition of the connecting relay 340 and the responsive condition of the polarized relay 423 effects the completion of the pulsating current circuit from the battery 437 to operate the lifting magnet of the connector and advance the brushes to the terminals of the next trunk line. Thus, when the connector brushes reach the 115 first trunk line terminals and such line is found to be busy, relay 423 alone responds, 120 125

and moves its contact spring 436, which is connected with the pulsator 436' and battery 487, into engagement with a contact connected with conductor 485' leading to conductors 242 and 396, whereupon an impulse of current passes out over line wires 218 and 311, through the lifting magnet 321 said magnet thereupon advancing the connector arm to the terminals of the next 10 trunk line. (See Fig. 13.) If such second trunk line is busy, the relay 423 will remain energized and the relay 340 inert, and another impulse will be delivered to the lifting magnet and cause the same to advance 15 the connector arm. When, however, the connector arm reaches the terminals of an idle trunk line, the relay 340 will be energized and relay 423 will remain operated, whereupon relay 340 will open the selecting 20 circuit above traced at its armature 397 and front contact and complete a circuit for the ringing relay in the usual manner. The relay 423 will now complete a locking circuit for the connecting relay and itself from a 25 positive battery, to which it alone responds, such current passing from the battery 486 through a conductor 487, spring 432 and front contact operated by the relay 423, to conductor 431, thence through the armature 30 445 and front contact of the connecting relay 340, conductors 485 and 419, windings of relays 423 and 340, through the contacts 227 operated by the retaining magnet, to earth.

35 In case all the trunk lines are tested and found busy, when the connector brushes reach the terminals of the last trunk line, negative current will be found thereat, instead of positive current, as before, and the 40 relay 423 will retract its armature, relay 340, of course, remaining inert, and the busy signal apparatus will be connected to the line as in case of a local subscriber.

Reverting calls.—It often happens that 45 the subscriber on the party line asks for communication with another subscriber on the same line, ordering the connection without knowledge of the relation between the parties. I provide improved means for 50 drawing the operator's attention to the fact that such reverting call is requested, and I may do this by providing an improved arrangement for effecting a peculiar flashing of the supervisory lamp representing the 55 called party when the connector units with the calling line terminals.

Turning now to Figs. 1 and 15, the relay 46 controls the reverting call signal. The winding 45 of said relay, as before described, is included in the locking circuit with the relay 34 and the controlling relay 50 of the sending apparatus, said relay being normally unresponsive to the current flowing in this circuit. When, however, the 65 sending apparatus has completed its work

and the connector brushes have united with the terminals of the called line, the relay 53 at the sending apparatus is short-circuited, and an increased amount of current caused to flow in the circuit including winding 45 70 of relay 46, which thereupon attracts its armatures 487', 412 and 489.

The armature 412 serves to prevent the distributor and connector from testing the called line, which, in the case I am describing, is the calling line, and, owing to its busy condition, returning to normal condition. It will be observed that owing to the presence of the operator's answering plug in the jack of the party line, which is both 75 the calling and called line, a shunt will be present about the testing conductor, said shunt comprising the grounded sleeve-strand of the answering plug. Within this sleeve strand is a high resistance 490 which 80 is normally short circuited by the armature 412, and when the relay 46 is operated, as before described, the armature 412 opens said short circuit, including said resistance in the said shunt about the testing conductor. This resistance is so great that the 85 marginal relays at the connector and distributor are not prevented from operating, and they thereupon establish the continuity 90 of the talking circuit through the connecting circuit to the connector and terminal of the called party-line. It should be stated that thereafter other connectors are locked out from the line by means of the testing conductor at the connector united with the 95 line.

A resistance 491 is included in the ring strand of the connecting circuit of the battery 22, and the ring of the answering plug, said resistance being normally short circuited at the armature 487' of the said relay, said armature being connected with a conductor 491' leading from the terminal 492 of the resistance to the armature 487' and front contact of the relay 46, winding 100 493 of said relay, to earth. It will thus be seen that the winding 493 is momentarily legged off from the point 492 each time a call is made, but said relay will not respond to the current from battery 22 passing 105 through the high resistance. When, however, the connector makes connection with the calling line, the potential at point 492 is raised, since current from the free pole 110 of battery 22 may flow out over the ring strand, through the trunk conductors, selectors and connectors, through the terminals of the connector and back to the long spring of the jack, and thence by way of the ring strand of the plug through the 115 winding 493 to earth. This current maintains the relay 46 energized independently 120 of the winding 45, a sufficient interval to cause the armature 489 to render operative 125 the reverting signaling apparatus 494, 130

which intermittently short-circuits the supervisory relay controlling the usual supervisory lamp, whereupon said lamp gives a peculiar signal. Relay 46 may be a "quick approach" and "slow release" relay, to bridge the interval between the successive energization of windings 45 and 493. It should be stated that the ringing relay at the distributor is sluggish in its approach to provide a proper interval for the excitation of winding 493 of the relay 46. This special signal means to the operator a special procedure on her part for ringing the desired subscriber, since relay 449 at the distributor opens the ringing circuit immediately upon the completion of the same by the ringing relay. The operator may now withdraw the answering plug, which disconnects the train of selectors, and insert a special plug in the answering jack having a cord equipped with a supervisory lamp and manual ringing key.

Restoration of the line switching mechanism.—When the conversation is completed, and the subscribers hang up their telephones, the supervisory signals before the operator are displayed and the operator removes her answering plug from the jack of the calling line. The circuit of relay 27 is now broken and said relay breaks the circuit 21 of the retaining magnet 36 of the district selector, which thereupon retracts its armatures to permit the return of the selector arm to normal position. The armature 123 of the retaining magnet in its retracted position engages a contact connected with a grounded battery 456, thereby completing a circuit for the relay 97 by way of conductor 422, winding of said relay, through the contact springs 124 closed while the selector arm is away from normal position, to earth. Said relay 97 is thereupon operated and attracts its armatures 125 126, reuniting the line brushes of the selector during the return movement thereof. When the selector arm reaches normal position, the contacts 124 are opened and relay 27 deenergized.

It should be noted that during the return movement of the selector arm, the circuit of the retaining magnet is opened at contacts 28 and 29 of the contacts opened by the armature of said magnet, so that the district selector cannot be taken for use until it has returned to normal position.

When the district selector arm left the terminals of the selected office selector, it removed current from the local wire 138, whereupon the retaining magnet 139 of the office selector arm was deenergized, permitting the return of the selector arm to normal position. The armature 195 of the retaining magnet in its retracted position engages a contact connected with a conductor 457 leading through contact springs 458 to

the said local wire 138, whereby a test potential is applied to the local terminals of the office selector on the several district selectors until the office selector arm has reached normal position and the contacts 458 thereupon are opened. This placing of the test potential upon the third wire locks out a district selector attempting to make connection with the said office selector before the same has reached its normal position.

When the brushes of the office selector left the terminals of the trunk selector employed in setting up the connection, current was removed from the local wire 199 of the said trunk selector, causing the deenergization of the retaining magnet 206^a of the trunk selector, which released the selector arm, permitting its restoration to normal position. As in the case of the office selector a test potential is applied to the terminals of the trunk selector until the same has reached normal condition, said potential being applied to the local wire 199 by the spring 206 and its front contact from battery 214, until the trunk selector moves said spring out of engagement with its anvil on reaching normal condition. In like manner, when the trunk selector removes current from the local wire 219 of the primary selector, the retaining magnet of said selector is deenergized and releases the selector arm. The armature 244 of the retaining magnet in its retracted position applies current from the battery 247 by way of conductor 248, through the winding of relay 236, and contacts 245, closed while the selector arm is away from normal position, to earth. Relay 236 is thereupon operated and at its armature 235 maintains open the bridge 230 containing the controlling magnets of the selector until the selector arm reaches normal position, when the contacts 245 are closed thereby and the relay 236 deenergized, whereupon the continuity of the bridge 230 is restored. It will be at once seen that the primary selector cannot be taken for use while the bridge is open and until the selector is returned to normal condition. When the selector arm left the terminals leading to the selected connector, current was removed from the local wire 312 and the retaining magnet of the connector became inert, permitting the restoration of the connector arm. The armature 458^a of the retaining magnet in its retracted position applies current from a battery 459 to a conductor 460 leading through contact springs 461 closed while the connector arm is away from normal position, to the local wire 312. Thus, during the return movement of the connector arm, a test potential is present at the local terminals of the trunk lines leading from said connector, but when the connector arm has reached its normal position

position it opens contact springs 461, whereupon the local terminals become dead.

Summary of operation.—Having now described in detail the circuits shown as embodying my said invention, I will now endeavor to give an outline of the complete operation of the system as briefly as possible.

- I will assume that the subscriber No. 999 shown in Fig. 1 desires connection with a subscriber No. 2749 whose line terminates in office "07" in district No. 09. The operator upon observing the display of the line signal of line No. 999, inserts her answering plug into the jack of such line, and depresses the listening key of her connecting circuit to inquire the number wanted. When the answering plug is inserted in the jack of the calling line, the sending apparatus F is automatically associated with the connecting circuit by means of the relays 27 and 34. The relay 27 is operated in the circuit completed by the operator's connection switch, and in turn completes an initial circuit for the relay 34, which thereupon at its armature 39 completes a locking circuit for itself, said relay 34 at its armature 56 connecting the common wire leading to the sending apparatus with the link conductor 21. The controlling relay 53 of the sending apparatus is included in the locking circuit before referred to, and when operated applies current from the battery 52 to the feed wire 62, whereupon the sending apparatus is placed in operative condition. The operator, upon ascertaining the number of the subscriber desired, which we have assumed to be No. 2749, in office 07 of district 09, depresses office key No. 7, thousands key II, hundreds key VII, tens key IV and units key IX of the sending apparatus. The office key depressed starts the operation of the office keyboard to actuate the district selector associated with the connecting circuit and pick out an office selector in district 09. The retaining magnet of the district selector is included in a circuit controlled by the relay 27 of the connecting circuit.
- Office No. 07 being located in district No. 09, the office key No. 7, when depressed, applies a ground to the "0" terminal of the row *c* of controller G and to the terminal "9" of the row *c'* of terminals of controller G', these terminals representing respectively the tens and units digits of the district in which the desired office is located. The office key when depressed, operated contacts 67, 68, 69 to start the operation of controller G, said contacts completing a circuit for the operating magnets 72, 73 of said controller, which advance the controller arm, said stepping magnet 72 applying current from battery 88 out to the district selector to operate the long step magnet 93 thereof, thereby advancing the selector arm in long steps from bank to bank of terminals, each bank representing ten districts. When the controller arm has taken one step and the brush 71 reaches the grounded terminal in row *c*, the district selector arm lies in operative relation to the first bank of terminals representing the first ten districts. At this point the cut-off relay 76 of controller G is operated and stops the movement of the controller G, permitting its return to normal position. Said relay 76 in operating switches into service the controller G', completing an operating circuit for its operating magnet 102^a and retaining magnet 103, whereupon the arm of the said controller G' is advanced and its brush 101 sweeps over the row of terminals *c'*. The stepping magnet of the controller serves to apply impulses of current from the battery 109 to the circuit of the short step magnet 94 of the district selector arm in short steps from row to row of the selected bank. When the brush 101 of the controller G' reaches the terminal grounded by the depressed office key, the selector arm will have advanced to the last row of terminals in the first bank representing district 09. Thereupon the cut-off relay 104 of controller G' will operate to stop the movement of the controller arm and interrupt the impulses supplied to the district selector.
- A relay 112 was operated in conjunction with the cut-off relay referred to and applies a momentary impulse from battery 120 to the conductors leading to the district selector, said current passing through the polarized relay 97 at the district selector and being of proper polarity to operate the same. Said relay thereupon starts the operation of the lifting magnet 95^a, which lifts the district selector arm along the selected row to pick out an idle trunk line leading to an office selector in district 09; the polarized relay receiving current from the local conductors of the busy selectors to maintain the circuit of the lifting magnet. When, however, an idle selector has been found, the relay 97 is deenergized, breaking the circuit of the lifting magnet and applying a test potential to the row of terminals of the trunk line leading to the office selector.
- The depressed office key No. 7 applies a ground to the "0" terminal of the row *d* of contacts of controller G, and the "7" terminal of the row *d'* of the contacts of controller G', said two terminals representing the tens and units digits of the desired office. The said relay 112 when deenergized, connected a test relay 158 in a conductor leading from battery 160, to common wire 90, and said relay 158 found a complete circuit when the district selector had united with the terminals leading to an idle office selector, said current passing to earth

through the stepping magnets of the office selector and serving merely to give the selector arm an incidental long step. The relay 158, when thus operated, brings into play the controller G, which causes the selector arm to advance into operative relation to the bank of terminals in which is located the terminals representing the desired office, each bank comprising ten rows of terminals representing ten offices. Said relay 158 serves to complete a circuit for the stepping magnet 72 and retaining magnet 73 of controller G, the retaining magnet in operating completing said circuit independent of the test relay and rendering operative the brush 152 which sweeps over the row of terminals *d* under the control of the stepping magnet. The stepping magnet 72 in its operation applies impulses of current from the battery 88 over the trunk conductors to the office selector, where said current passes through the stepping magnet 142 to earth, advancing the arm in long steps. When the arm has taken one long step into operative relation to the first bank of terminals in which is located the desired office terminal, the brush 152 of the controller G will have engaged the terminal grounded by the depressed office key, and the cut-off relay 157 will operate and open the circuit of the operating magnets of the controller, thereby cutting off the supply of current to the office selector.

The cut-off relay 157 in operating, starts the controller G', which causes the office selector arm to advance in short steps from row to row of terminals in the selected bank into operative relation to the row of terminals representing office No. 07. Said relay 40 in operating completes a circuit for the stepping magnet 102^a and retaining magnet 103 of the arm of the controller G', said retaining magnet rendering operative the brush 175 which sweeps over the row of terminals representing the units digits of the office numbers.

The stepping magnet of the controller G', in operating applies impulses of current from the battery 109 to the trunk conductors to operate the short-step magnet 143 of the office selector. When the office selector arm has advanced into operative relation to the row "7" of terminals in the first bank, representing office No. 07, the brush 175 will have advanced to the terminal grounded by the office key depressed, and the cut-off relay 181 will have operated, opening the circuit of the operating magnets of the controller and removing current from the operating magnet of the selector. The starting relay 112 again operates, this time in conjunction with the cut-off relay 181, and applies a momentary impulse from the battery 120 to the trunk conductors to operate the polarized relay 148 at the office selector,

which completes a circuit for the lifting magnet 148', and thereafter receives current from the local wires of busy trunk lines to continue the upward movement of the selector arm until an idle trunk line is reached, when said relay becomes deenergized, opening the circuit of the lifting magnet and applying a test potential to the local terminals of the selected trunk line. The office selector arm has now brought its brushes into engagement with the terminals of a trunk line leading to a trunk selector adapted to pick out automatically an idle trunk line leading to the desired office, and to a primary selector thereof adapted to pick out a connector capable of uniting with the called line. When connection was made with said trunk line leading to said trunk selector, the retaining magnet of said selector was operated and in addition a relay 202, which completed a circuit for the stepping magnet of said selector arm, to advance the arm one step and thereafter receive current from the terminals of busy trunk lines to continue the advance of the selector arm by the stepping magnet until an idle trunk line was reached, whereupon said relay 202 was deenergized, opening the circuit of the stepping magnet and applying a test potential to the local terminals of the selected inter-office and trunk line.

When an idle inter-office trunk has been secured, the relay 158 is again operated by current from battery 160 passing out over the trunk conductors through the bridge 230 at the primary selector of the selected office, and back over the trunk conductors to earth, said relay 158, in operating causing the operation of the switching relay 79, which locks itself to the feed wire of sending apparatus F, and transfers the leads of the office keyboard into association with the leads of the sending apparatus F'. Said switching relay in operating also breaks the circuit of the relay 270, which was energized during the operation of the office keyboard, and said relay effects the operation of the release magnet of the office keys to restore the depressed office key to normal position.

The relay 270 when deenergized serves to start the operation of the primary controller in conjunction with the depressed thousands and hundreds keys to cause the primary selector at the distant office to select a group of trunk lines leading to connectors adapted to reach the line desired. The line desired, No. 2749, it will be apparent, terminates in the sixth group of five hundred lines, or in the third group of one thousand lines. The primary selector arm will, therefore, be required to take six steps to lie in operative relation to the row of trunk lines representing connectors each adapted to reach links 2500 to 2999. The depressed thousands key II applied a ground to the terminals "2" 130

and "2'" of the rows a a' of the primary controller, and the key VII of the hundreds keys rendered operative the brush b' which sweeps over the row a' . Therefore, when 5 the relay 270 of the office keyboard was de-energized, a circuit was completed for the operating magnets of the primary controller, which thereupon advanced the controller arm, the stepping magnet of the controller in the meantime, sending impulses of current from battery 291 out to the primary selector and through the bridge 230 thereat, operating relay 229 in said bridge, and causing the same to apply current from 10 battery 237 to the around-stepping magnet 221 of the selector arm. Said stepping magnet thereupon advances the selector arm from row to row of terminals representing groups of connectors. When the selector 15 arm has been given six steps, and lies in operative relation to the row of terminals representing trunk lines leading to connectors adapted to unite with the desired line, the brush b' of the primary controller will 20 engage the terminal 2', grounded by the depressed thousands key, and the cut-off relay 10 of the primary controller will operate, opening the circuit of the stepping magnets thereof.

30 An impulse relay 295 was operated by the circuit of the cut-off relay and applied an impulse of current from battery 303 to the conductors leading to the primary selector, and through the bridge 230 thereat, 35 operating the polarized relay 229, and causing the same to apply current from battery 241 to the circuit of relay 236. Said relay 236 thereupon completes a circuit for the lifting magnet 222 of the selector arm to 40 advance the selector arm to the terminals of the first trunk line leading to a connector serving the selected group. In case such trunk line is busy, the relay 236 will be maintained energized by current from 45 the local wire of such busy trunk, and will continue the energization of the lifting magnet, which will advance the selector arm until a trunk line leading to an idle connector is reached, whereupon the relay 50 236 will be deprived of current. The brushes of the selector arm now rest in engagement with the terminals of a trunk line leading to a connector adapted to reach the terminals of line 2749, the retaining 55 magnet of said connector receiving current when the selector arm brings its brushes into engagement with the said terminals of the trunk line.

Returning to the primary controller, 60 when the cut-off relay 10 was energized, and the impulse relay 295 de-energized, the starting relay 328 was connected from a battery 331 to the common wire 59, and when the selector had completed its selection of an idle trunk line and the bridge 65 230 was restored to its normal condition by the de-energization of the relay 236, a circuit was completed through the said bridge for the relay 328. It should be stated at this point that the testing current operated 70 polarized relay 228 at the selector, which applied current from battery 247, out through the contacts of the primary selector, through the stepping magnets of the connector to earth. This current operated merely the long step magnet of the connector and caused the same to give the connector arm an incidental step. The said starting relay controls the operation of the auxiliary controller in association with the 80 depressed hundreds key to cause the connector arm to advance into operative relation to the particular group of the five groups of terminals of the connector in which is located the terminals of the called 85 party's line. Line 2749 would fall within the third group of one hundred of the connector, namely, within the group 2700 to 2799. The depressed hundreds key VII would therefore apply a ground to the third 90 terminal "2" of the row a^2 of the auxiliary controller, the brush 365 of the auxiliary controller arm being arranged to sweep over said row of terminals. The starting relay 328, in operating, completes a circuit 95 for the stepping and retaining magnets of the auxiliary controller, which serve to advance the arm thereof, the stepping magnet of the controller, in operating applying current from the battery 331 over trunk 100 conductors to the primary selector and through the bridge 230 thereat to earth, whereupon the relay 228 in said bridge is operated intermittently and applies impulses of current from the battery 247 out 105 over the trunk conductors and through the stepping magnets 319, 320 of the connector to earth. The magnet 320 of the connector alone responds to this current and advances the connector arm in long steps from group 110 to group of terminals.

When the connector arm has been advanced into operative relation with the third bank of terminals, the brush 365 of the auxiliary controller will engage the terminal "2" grounded by the depressed hundreds key, and the cut-off relay 335' will operate, opening the circuit of the operating magnets of the auxiliary controller. Said relay also serves to bring into service 115 the primary controller in association with the depressed tens key, to move the connector arm in short steps from row to row in the selected bank into operative relation to the row of terminals representing lines 120 2740 to 2749.

The depressed tens key IV changes the electrical condition of its corresponding terminal in the row a^2 of the primary controller by placing a ground thereon, the 125 130

brush 375 of the primary controller being adapted to sweep over said row of terminals. The cut-off relay 335' of the auxiliary controller in operating completes a circuit for the operating magnets of the primary controller which advance the arm thereof, the retaining magnet, when operated, coöperating with the cut-off relay 335' to bring the cut-off relay 362 of primary controller and starting relay 328 into operative relation to said brush 375. The stepping magnet of the controller in operating, applies impulses of current from the battery 291 to the trunk conductors and through the bridge 230 at the primary selector to earth. The polarized relay 229 included in said bridge, in responding to said impulses, applies current from battery 237 out through the trunk conductors to the connector and through the short step magnet of the connector to earth, said magnet advancing the connector arm in short steps from row to row of terminals.

When the connector arm has been given five short steps and lies in operative relation to the row of terminals representing lines 2740 to 2749, the brush 375 of the primary controller will have engaged the terminal grounded by the depressed tens key IV, and the cut-off relay 362 will operate, opening the circuit of the operating magnets of the controller. The starting relay 328 and cut-off relay 362 now coöperate to cause the auxiliary controller to operate in conjunction with the depressed units key to move the connector arm along the terminals in the selected row to the last terminal representing line 2749.

The auxiliary controller arm carries a brush 391 adapted to sweep over a row of terminals representing the units digits of lines in the exchange. In the present case, the last terminal thereof, No. 9 is grounded by the depressed units key IX. When the said relays 328 and 362 are operated, a circuit is completed for the operating magnets of the auxiliary controller, including contacts which are closed by a depressed units key, and the auxiliary controller arm is advanced. The retaining magnet of the controller arm, when operated, coöperates with the relay 362 to bring the cut-off relay 364 of the auxiliary controller into operative relation to the brush 391 of said controller, while the stepping magnet in operating applies impulses of current from the battery 303 over the trunk conductors and through the bridge 230 to earth, operating the relay 229. Said relay 229 in response to this current applies current from a battery 241 out through the trunk conductors to the connector, and thence through the lifting magnet 321 to earth, whereupon the brushes of said connector arm move along the terminals in a selected row.

When the brushes of the connector arm engage the last set of terminals in the row representing line No. 2749, the brush 391 of the auxiliary controller will have engaged the terminal grounded by the depressed units key, and the cut-off relay 364 will have operated. Said relay in operating opens the circuit of the operating magnets of the auxiliary controller. The said cut-off relay in operating short circuits the controlling relay of the sending apparatus, which thereupon becomes deenergized and removes current from the feed wire, and also applies a momentary impulse to the release magnets of the keys. Another effect of said short circuit is to increase the flow of current in the circuit including the relays 34 and 46 sufficiently to cause the energization of relay 46, which thereupon short-circuits the relay 34, causing its deenergization and the consequent restoration of the continuity of the link conductors 20, 21, the sending apparatus being now disassociated from the connecting circuit and in position to serve other connecting circuits.

When the cut-off relay 364 operated, as before described, it applied an impulse from battery 52 to the trunk conductors and bridge 230 to earth. This current operated the relay 228 and caused the same to complete a momentary circuit for the relay 232 at the selector and also a circuit for the polarized relay 344 at the connector, said relay 344 completing a locking circuit for itself under the control of the relay 404. The said relays 232 and 344 complete the continuity of a test conductor leading from the local brush of the collector arm through a marginal relay 404 at the connector, through line conductors and contacts of the selector, conductors 338, 419 to earth through the marginal connecting relay 340 at the selector, the relay 232 during the test maintaining the bridge 230 open to prevent the improper operation of the supervisory signal representing the called line.

Now in case the called line is busy, insufficient current will flow through the test conductor to operate the marginal relays, owing to the shunt about said test conductor established at switching mechanism already united with the line, and a circuit will be completed by the relays 340 and 232 for a busy test relay 225, which will apply a busy signal to the trunk conductors and operator's connecting circuit, and also open the circuit of the retaining magnet of the selector, causing the restoration of the selector and connector to normal condition. The bridge 230 is maintained open during the return of the selector arm by the relay 236, which operates during the interval between the start of the selector arm on its return movement, and the end of such movement.

Assuming that the line with which con-

nection is desired is free, relay 404 at the connector will receive sufficient current for its operation, and will complete the continuity of the line conductors leading to the 5 connector brushes and will open the locking circuit of the polarized relay 344. Marginal relay 340 at the selector in operating completes a locking circuit for itself under the control of the retaining magnet of the selector, and completes a circuit for the ringing relay 234, said connecting relay also completing the continuity of the trunk conductors between the trunk selector and the contacts of the ringing relay. The ringing 10 relay when operated opens the trunk conductors 217, 218, and connects the portions thereof leading to the primary selector with the poles of a ringing generator, whereby ringing current is applied to the line of the 15 called party. A relay 449 is included in said ringing circuit and is unresponsive to the said ringing current until the called subscriber responds to the call by removing his telephone from its hook, and said relay 20 thereupon completes a circuit for the relay 232, which completes a locking circuit for itself under the control of the retaining magnet of the selector and opens the circuit of the ringing relay. During the 25 operation of ringing, the ringing relay maintains the bridge 230 opened; during the conversation the relay 232 maintains said bridge open. The two subscribers are now 30 in connection with each other, current for transmission purposes being supplied to both lines from the battery 22 in the connecting circuit, and the supervisory relays respond to such current under the control 35 of the switch-hooks at the respective stations. When the conversation is concluded and the subscribers hang up their telephones, the supervisory signals are displayed and the operator removes her answering plug from the jack of the calling line, whereupon 40 the selecting mechanism is restored to normal condition, access to said members of the selecting mechanism being prevented until they are restored to normal condition.

If the called subscriber had been a member 50 of a party line, relay 422 would have controlled the character of current to be applied to the party line by the ringing relay 234, said relay responding in case the station of the party line requires one character 55 of current, and being inert in case the other character is required, said relay being provided with a holding winding normally short-circuited at the armature and back contact of said relay. When said relay is initially 60 energized, the short circuit is broken and the holding winding is locked in a circuit with the connecting relay under the control of the retaining magnet.

In case a private branch exchange were 65 being called, and the first trunk line leading

thereto were busy, the polarized relay 423 would operate, the connecting relay remaining unresponsive, and such combination of relays would effect the operation of the lifting magnet of the connector to advance the 70 brushes thereof to the terminals of the next trunk line; when a free trunk line was secured both the relays 340 and 423 would operate, relay 423 supplying current of proper polarity to maintain itself energized in the 75 locking circuit through the connecting relay and the contacts with the retaining magnet.

In case of a reverting call: Relay 46 is momentarily operated when the connector reaches a called line, and if the called line 80 is the calling line, the connector brushes are caused to settle upon the terminals of the called but busy line, and said relay receives current to maintain itself energized through the connector contacts and manual connection switch, thereupon causing the supervisory signal to display a characteristic reverting call signal.

The features claimed herein are improvements or modifications of a system the general characteristics of which have been claimed in other applications as follows: joint applications of James L. McQuarrie and myself Serial No. 336,401, filed September 27th, 1906; Serial No. 355,884, filed February 5th, 1907; Serial No. 350,848, filed January 2nd, 1907, and sole applications of myself, Serial No. 355,896, filed February 5th, 1907; Serial No. 366,198, filed April 3rd, 1907; Serial No. 366,199, filed April 3rd, 100 1907; Serial No. 366,200, filed April 3rd, 1907.

I claim:—

1. In a telephone exchange system, the combination with a number of telephone lines extending from substations to a central office, of connectors at the central office adapted to serve different groups of said lines, a talking circuit, a distributor adapted to unite said talking circuit with a connector adapted to reach the line desired, and automatic busy signal apparatus at the distributor adapted to test the line with which the connector unites, said apparatus in case such line is busy applying a busy signal to the talking circuit.

2. In a telephone exchange system, the combination with a number of lines extending from substations to a central office, of connectors at the central office adapted to unite with different groups of said lines, a talking circuit, a distributor, means for operating said distributor to unite said talking circuit with a connector adapted to reach a desired line, means for operating said connector to unite the talking circuit with said line, busy signal apparatus at the distributor adapted to test the called line, said apparatus being adapted in case the called line is busy to apply a busy signal to said talking circuit, and means automatically operated in case the line is busy, for 130

effecting the restoration of said distributor and selected connector to normal condition.

3. In a telephone exchange system, the combination with telephone lines, of connectors adapted to unite with said lines, a talking circuit, a distributor adapted to unite said talking circuit with a connector serving the desired line, such connector being adapted to unite said talking circuit with said line, line testing mechanism at the distributor, and means actuated by said mechanism, in case the called line is busy, for applying a busy signal to said talking circuit and restoring said distributor and connector to normal condition.

4. In a telephone exchange system, the combination with a number of groups of telephone lines, of connectors for each group, a talking circuit, a distributor adapted to select a group of connectors adapted to serve the called line, said distributor being thereupon adapted to unite said talking circuit with an idle connector of such group, means for operating the selected connector to unite said talking circuit with the desired line, and busy signal apparatus at said distributor adapted to apply a busy signal to the talking circuit in case the called line is busy.

5. In a telephone exchange system, the combination with a number of telephone lines, of connectors adapted to unite with said lines, a distributor adapted to select a connector adapted to reach a desired line, a testing conductor extending from said connector through the distributor, means for completing the continuity of said conductor when the connector unites with the desired line, and mechanism in said testing conductor adapted in case the called line is busy, to apply a busy signal to said talking circuit.

6. The combination with telephone lines, of a pair of automatic line switching devices adapted to be successively and serially employed in establishing a connection with a line, a testing conductor leading from the called line through both switching devices, means for establishing the continuity of said testing conductor when connection is made with a line, and busy signal apparatus at the first switching device, in association with said testing conductor, actuated in case the called line is busy.

7. The combination with telephone lines, of a pair of automatic line switching devices adapted to be successively and serially employed in establishing a connection with a line, a testing conductor leading from the called line through both switching devices, said testing conductor being open at both switching devices, electromagnetic mechanism at each device, operated when connection is made with a desired line, for establishing the continuity of said testing con-

ductor, and busy signal apparatus at the first switching device in association with said testing conductor, actuated in case the called line is busy.

8. In a telephone system, the combination with telephone lines, of connectors adapted to unite with said lines, a distributor, a talking circuit, trunk lines leading from said distributor to said connectors, said distributor being adapted to unite said talking circuit with a trunk line leading to a desired connector, a testing conductor leading from said connector through the distributor, the continuity of said testing conductor being interrupted at both said distributor and connector, means actuated when the connector is united with a desired line for completing the continuity of said testing conductor at both points, a busy signal apparatus, and a relay in said testing conductor adapted in case the line called is busy to associate said busy signal apparatus with the talking circuit.

9. In a telephone system, the combination with telephone lines, of connectors adapted to unite with said lines, a distributor, a talking circuit, trunk lines leading from said distributor to said connectors, said distributor being adapted to unite said talking circuit with a trunk line leading to a desired connector, a testing conductor leading from said connector through the distributor, the continuity of said testing conductor being interrupted at both said distributor and connector, means actuated when the connector is united with a desired line for completing the continuity of said testing conductor at both points, a relay in said testing conductor at the distributor unresponsive, on the completion of said testing conductor, in case the called line is busy, a busy test relay at said distributor, a circuit for said relay controlled by said first-mentioned relay, and a busy signal apparatus adapted to be applied by said busy test relay in said talking circuit.

10. In a telephone system, the combination with telephone lines, of connectors adapted to unite with said lines, a distributor, a talking circuit, trunk lines leading from said distributor to said connectors, said distributor being adapted to unite said talking circuit with a trunk line leading to a desired connector, a testing conductor leading from said connector through the distributor, the continuity of said testing conductor being interrupted at both said distributor and connector, means actuated when the connector is united with a desired line for completing the continuity of said testing conductor at both points, a relay in said testing conductor at the distributor unresponsive, on the completion of said testing conductor, in case the called line is busy, a busy test relay at said distributor, a circuit

- for said relay controlled by said first mentioned relay, a busy signal apparatus adapted to be applied by said relay to said talking circuit, and means actuated by said relay for effecting the restoration of said distributor and connector to normal condition.
11. In a telephone exchange system, the combination with telephone lines, of connectors adapted to serve said lines, a talking circuit, a distributor adapted to unite said talking circuit with a connector adapted to serve a desired line, a testing conductor extending from the connector to the distributor, said testing conductor being normally open at the connector and distributor, a relay 344 at the connector adapted to complete the continuity of said testing conductor at one point, a relay 232 at the distributor adapted to complete the testing conductor at said other point, means for operating said relays when the connector has united with the desired line, a relay 340 in the testing conductor and unresponsive in case the called line is busy, and busy signal apparatus applied to said talking circuit by said relays 340 and 232 when the first mentioned relay is inert and the second mentioned relay energized.
12. In a telephone exchange system, the combination with telephone line terminals, of connectors for said terminals, a talking circuit, a distributor, trunk conductors leading from the distributor to the different connectors, said distributor being adapted to unite said talking circuit with a trunk conductor leading to a desired connector, contact brushes at the connector adapted to sweep over the terminals of the lines, a local conductor leading from the testing brush of said connector to a trunk conductor leading from said distributor, normally open contacts in said local conductor at the distributor leading to said talking circuit, normally open contacts in said last mentioned conductor, said local and trunk conductors and talking circuit forming a testing conductor, means actuated when the connector brushes engage the terminals of a desired line for completing the continuity of said testing conductor at both said points, mechanism within said testing conductor, actuated in case the called line is busy, for applying a busy signal to said talking circuit, and means actuated, in case said line is free, for disconnecting said local conductors from said trunk line and talking circuit.
13. In a telephone exchange system, the combination with telephone lines and their terminals, of connectors adapted to serve said lines, a talking circuit, a distributor, trunk conductors leading from the distributor to the different connectors, said distributor being adapted to unite said talking circuit with a trunk line leading to a desired connector, contact brushes at the connector adapted to sweep over the terminals of the lines, a local conductor leading from the testing brush of said connector to a trunk conductor leading from said distributor, normally open contacts in said local conductor at the distributor leading to said talking circuit, normally open contacts in said last-mentioned conductor, said local and trunk conductors and talking circuit forming a testing conductor, means actuated when the connector brushes engage the terminals of a desired line for completing the continuity of said testing conductor at both said points, mechanism within said testing conductor, actuated in case the called line is busy, for applying a busy signal to said talking circuit, and means actuated, in case said line is free, for disconnecting said local conductors from said trunk line and talking circuit.
14. In a telephone exchange system, the combination with telephone lines and their terminals, of connectors adapted to serve said lines, a talking circuit, a distributor, trunk conductors leading from the distributor to the different connectors, said distributor being adapted to unite said talking circuit with a trunk conductor leading to a desired connector, contact brushes at the connector adapted to sweep over the terminals of the lines, a local conductor leading from the testing brush of said connector to a trunk conductor leading from the distributor, normally open contacts in said local conductor, a conductor at the distributor leading to said talking circuit, normally open contacts in said last-mentioned conductor, said local and trunk conductors and talking circuit forming a testing conductor, means actuated when the connector brushes engage the terminals of a desired line, and mechanism within said testing conductor at the distributor adapted to apply a busy signal to the talking circuit in case the called line is busy.
15. In a telephone exchange system, the combination with telephone lines and their terminals, of connectors adapted to serve said lines, a talking circuit, a distributor, trunk conductors leading from the distributor to the different connectors, said distributor being adapted to unite said talking circuit with a trunk conductor leading to a desired connector, contact brushes at the connector adapted to sweep over the terminals of the lines, a local conductor leading from the testing brush of said connector to a trunk conductor leading from said distributor, normally open contacts in said local conductor, a conductor at the distributor leading to said talking circuit, normally open contacts in said last-mentioned conductor, said local and trunk conductors and talking circuit forming a testing conductor, means actuated when the connector brushes engage the terminals of a desired line for completing the continuity of said testing conductor at both said points, mechanism within said testing conductor, actuated in case the called line is busy, for applying a busy signal to said talking circuit, and means actuated, in case said line is free, for disconnecting said local conductors from said trunk line and talking circuit.
16. In a telephone exchange system, the combination with telephone lines and their terminals, of connectors adapted to serve said lines, a talking circuit, a distributor, trunk conductors leading from the distributor to the different connectors, said distributor being adapted to unite said talking circuit with a trunk line leading to a desired connector, contact brushes at the connector adapted to sweep over the terminals of the lines, a local conductor leading from the testing brush of said connector to a trunk conductor leading from the distributor, normally open contacts in said local conductor, a conductor at the distributor leading to said talking circuit, normally open contacts in said last-mentioned conductor, said local and trunk conductors and talking circuit forming a testing conductor, means actuated when the connector brushes engage the terminals of a desired line for completing the continuity of said testing conductor at both said points, mechanism within said testing conductor, actuated in case the called line is busy, for applying a busy signal to said talking circuit, and means actuated, in case said line is free, for disconnecting said local conductors from said trunk line and talking circuit.

engage the terminals of a desired line for completing the continuity of said testing conductor at both said points, a relay 340 at the distributor and a relay 404 at the connector, both included in the testing conductor, means controlled by relay 404 in case the called line is free for disconnecting the first mentioned local conductor from the trunk conductor, and means operated by said relay 340 at the distributor in case the called line is free for disconnecting the last-mentioned conductor from the talking circuit.

16. In a telephone exchange system, the combination with telephone lines and their terminals, of connectors having brushes adapted to engage the terminals of said lines, a talking circuit, a distributor, trunk conductors leading from said distributor to said connectors, said distributor being adapted to unite said talking circuit with a trunk line leading to a given connector, operating mechanism for the connector brushes adapted to unite said trunk line with a desired line, a relay 404, normally closed contacts for said relay and conductors leading from the trunk conductors through said contacts to said operating mechanism, a local conductor leading from one of the test brushes of said connector through said relay and said normally closed contacts to one of said trunk conductors, normally open contacts in said local conductor, a relay 344 controlling the said contacts, said local conductor and trunk conductor forming part of a testing conductor adapted to have its continuity completed at the distributor and at the normally open contacts of relay 344, means actuated when the connector brushes engage the terminals of the desired line for operating relay 344 to complete the testing conductor at the connector, means for completing the continuity of said test conductor at the distributor, and means operated by the relay 404 in said testing conductor in case the called line is free, for actuating its contacts and disconnecting said conductors of the connector from the trunk conductors.

17. In a connector, the combination with a contact member, of stepping magnets thereto, a trunk line leading to said contact member, conductors leading from said trunk line through said stepping magnets, normally closed contacts controlling the connection of said conductors with the trunk line, relay 404 controlling said contacts, a normally open local conductor including said relay 404, said local conductor leading from the test brush of the connector, a battery having one pole connected to said conductor, and the other pole connected with the local terminals of the lines, a relay 344 adapted to be operated when the connector brushes engage the desired line terminals, means controlled by said relay for completing the continuity of said local conductor,

said relay 404 operating in case the called line is free to actuate its contacts and disconnect the stepping magnets from the line, a locking circuit for said relay 344 completed by itself when operated under the control of relay 404, and means controlled by said relay 404 in operating for opening the locking circuit of relay 344.

18. The combination with telephone lines, of connectors adapted to unite with said lines, a distributor adapted to select a connector serving given lines, a talking circuit adapted to be united by said distributor and the selector connector with the desired line, a source of ringing current at the distributor, a relay 340, a testing conductor leading from the connector through the distributor and adapted to have its continuity completed when the connector unites with a desired line, a relay 340 in said testing conductor at the distributor responsive in case the called line is free, a relay 234 at the distributor adapted to apply ringing current to the called line, a circuit for said relay completed by relay 340 when operated and a relay 449 in said ringing circuit responsive when the called subscriber answers, adapted to open the circuit of the relay 234.

19. The combination with telephone lines, of connectors adapted to unite with said lines, a distributor adapted to select a connector serving given lines, a talking circuit adapted to be united by said distributor and the selected connector with a desired line, a source of ringing current at the distributor, a testing conductor leading from the connector through the distributor and adapted to have its continuity completed when the connector unites with a called line, a relay 340 in said conductor at the distributor responsive in case the called line is free, a relay 234 at the distributor adapted when operated to apply said ringing current to the called line, a relay 232, normally closed contacts controlled thereby, a circuit for said relay 234 completed by relay 340 when operated and including said normally closed contacts, a relay 449 in said ringing circuit responsive when the called subscriber answers, and a circuit for relay 232 completed by said relay 449 when operated, whereby said normally closed contacts are opened to break the circuit of the ringing relay.

20. The combination with telephone lines, of connectors adapted to unite with said lines, a distributor adapted to select a connector serving given lines, a talking circuit adapted to be united by said distributor and the selected connector with a desired line, a source of ringing current at the distributor, a testing conductor extending from the connector through the distributor and adapted to have its continuity completed when the connector unites with the called line, retaining mechanism for the distributor, a

- relay 340 in said testing conductor responsive in case the called line is free, a locking circuit for said relay 340 completed by itself under the control of the said retaining mechanism, a relay 234 adapted when operated to apply said ringing current to the called line, a relay 232 having normally closed contacts, a circuit for relay 232 completed by relay 340 when operated and including said normally closed contacts, a relay 449 in said ringing circuit responsive when the called subscriber answers, a circuit for relay 232 completed by relay 449 when operated, whereby said normally closed contacts are opened to break the circuit of the ringing relay 234, and a locking circuit for relay 232 completed by said relay when energized under the control of said retaining mechanism.
21. The combination with a single and multi-station telephone lines, of connectors adapted to reach different groups of said lines, a distributor adapted to select a connector capable of reaching a given group of lines, sources of current of different polarity at the distributor, and mechanism, at the distributor, automatically operated in case the connector unites with a party-line, for applying current of proper character to signal the desired station of such line.
22. The combination with single and multi-station telephone lines, of connectors adapted to unite with given lines, a distributor adapted to select a given connector, sources of ringing current at the distributor, a relay 234 at the distributor operated when the connector unites with a line, for applying ringing current to a called line, and a relay 422 at the distributor, governed by the character of the called line, for controlling the source of current to be applied by said relay 234 to a called line, to signal a single-station line, or a desired station on a party-line.
23. The combination with single and multi-station telephone lines, of connectors adapted to reach different groups of said lines, a distributor adapted to select a connector capable of reaching a given group of lines, sources of current of different polarity at the distributor, a relay 234 at the distributor operative when the connector unites with the called line to apply ringing current to the called line, a relay 422 at the distributor, said relay being unresponsive if the called line is a single station line, or a similar station of a party line, means controlled by said relay, if unresponsive, for bringing one of said sources of current under the control of said relay 234, said relay responding in case a dissimilar station of a party line is called, and means actuated by said relay in operating for bringing said other source of ringing current under the control of relay 234.
24. The combination with a relay having a main and a holding winding, of a second relay, means for momentarily applying currents of different strength to said main winding and said second relay, said main winding operating in response to a current of higher strength, an armature for said first mentioned relay, a short circuit about said holding winding normally completed by said armature, and a circuit for said holding winding and said second relay whereby said holding winding will be energized upon the attraction of said armature. 70
25. The combination with a relay 422 having a main and a holding winding, of a relay 340, means for momentarily applying currents of different strength to said main winding and relay 340, said main winding operating in response to current of greater strength, said relay 340 responding to either 80 current, an armature for relay 422, a short circuit about the holding winding of said relay 422 normally completed by said armature, and a locking circuit for relay 340 completed by said relay, said circuit including 90 the holding winding of said relay 422 in case said armature is operated. 85
26. The combination with a relay 422 having windings 421, 484, of a relay 340, a source of current, a conductor 419 extending through winding 421 of said relay and the relay 340 to one pole of said source, means for momentarily connecting the other pole of said source with the other terminal of said conductor, a conductor 485 leading 95 from said conductor 419 between said relays through the winding 484 of relay 422, an armature for relay 340 adapted when attracted to connect said conductor 485 with the pole of said source momentarily applied to said conductor 419, and an armature for said relay 422 normally completing a short circuit about said winding 484, said armature being attracted when said winding 421 receives a momentary current, to include 100 said winding 484 in locking circuit with relay 340. 100
27. The combination with telephone lines, of connectors adapted to unite with said lines, a distributor adapted to select a connector capable of reaching a desired line, a testing conductor leading from the connector to the distributor adapted to have its continuity established when said connector unites with the called line, a relay at the distributor operated when the connector unites with the free line, sources of current of different character, a relay 422 in said testing conductor controlling the source of current to be applied to the called line, said relay 422 responding to current in the testing conductor in case the called line requires current of one character, and being unresponsive if current of another character is required, and means controlled by said relays 115 120 125 130

422 and 234 for applying such current to the called line.

28. The combination with telephone lines, of connectors adapted to unite with said lines, a distributor adapted to select a connector capable of reaching a desired line, a testing conductor leading from the connector to the distributor and adapted to have its continuity established when said connector unites with the called line, sources of ringing current of different character, a relay 234 at the distributor operated when the connector unites with a free line, a relay 422 at the distributor controlling the application of current of proper character to party lines, said relay being included in the testing conductor and responsive to current therein if ringing current of one character is required, and unresponsive if current of another character is required, means controlled by relays 422 and 234 for applying the selected source of current to the called line, and means at the distributor, automatically operated when the called subscriber responds, for discontinuing the application of such current.

29. The combination with telephone lines, of connectors adapted to unite with said lines, a distributor adapted to select a connector capable of reaching a desired line, a testing conductor leading from the connector to the distributor adapted to have its continuity established when the connector unites with the called line, sources of ringing current of different character, a relay 234 at the distributor operated when the connector unites with a free line, a relay 422 at the distributor in said testing conductor controlling the application of current of proper character to party lines, said relay responding if current of one character is required, and being unresponsive if current of another character is required, means controlled by relays 422 and 234 for applying the selected current to the called line, retaining mechanism for the distributor, a relay 340 at the distributor operated if the called line is free, and a locking circuit completed by relay 340 for itself under the control of said retaining mechanism, said locking circuit including the relay 422 in case said relay has responded.

30. The combination with telephone lines, of connectors adapted to unite with said lines, a distributor adapted to select a connector capable of reaching a desired line, a testing conductor leading from the connector to the distributor, adapted to have its continuity established when the connector unites with the called line, a relay 234 at the distributor operated when the connector unites with a free line, sources of current of opposite polarity at the distributor, a relay 422 at the distributor having a winding 421 included in said testing conductor, said relay controlling the application of current of different character to party lines, said relay

operating in case current of one polarity is required, and being unresponsive if current of opposite polarity is required, means controlled by said relays 422 and 234 for applying the selected current to the called line, 70 means automatically operated when the called subscriber answers for discontinuing the application of said current to the line, a winding 484 for said relay 422, retaining mechanism for the distributor, a locking circuit for the relay 340 completed by said relay when operated and including the winding 484 of said relay 422, said circuit being under the control of the retaining mechanism, an armature 421' for said relay 422, 80 and a short circuit about said winding 484 normally maintained by said armature; whereby said winding 484 is operatively included in said locking circuit only in case the relay 422 has responded to the current 85 in the testing conductor.

31. The combination with a line switching device having terminals arranged in groups, of contact members for said device, a magnet to advance said members from 90 group to group, a magnet to advance said members along the terminals of a selected group, line conductors leading to said contact members, a bridge of said line conductors, a polarized relay in said bridge, 95 means controlled by said relay in response to currents of different character for selectively operating said magnets, and means for opening said bridge.

32. The combination with a line switching device having a pair of stepping magnets, of line conductors leading to said switching device, a bridge of said conductors, a relay included in said bridge and responsive to currents of different character, 105 means controlled by said relay in response to said differing currents for selectively actuating said stepping magnets, and means for opening said bridge.

33. The combination with a line switching device having a pair of stepping magnets, of line conductors leading to said switching device, a bridge of said line conductors, a polarized relay in said bridge, means controlled by said relay in response 115 to current of one polarity for selectively actuating one of said stepping magnets, means controlled by said relay in response to current of opposite polarity for actuating said other stepping magnet and means for 120 opening said bridge.

34. The combination with a line switching device, of a contact member therefor, a rotary stepping magnet for said device, a lifting magnet for said device, line conductors leading to said switching device, a bridge of said line conductors, a polarized relay in said bridge, an armature for said relay, a circuit for said rotary stepping magnet controlled by said armature when 125 180

rocked in one direction, a circuit for said lifting magnet controlled by said armature when rocked in the opposite direction, and means for opening said bridge.

35. The combination with a line switching device having rows of terminals, of contact members for said device, a magnet adapted to advance said members from row to row, a magnet adapted to advance said members along the terminals of a selected row, line conductors leading to said contact members, a bridge of said line conductors, a polarized relay in said bridge, means controlled by said relay in response to currents of different character for selectively operating said magnets, and means for opening said bridge after said magnets have been operated.

36. The combination with a line switching device having rows of terminals, of contact members for said device, a magnet 221 adapted to rotate said contact members into operative relation to a desired row of terminals, a magnet 222 adapted to move said members along a selected row to idle terminals therein, a relay 236, a circuit for magnet 222 controlled by said relay, line conductors leading to said contact members, a bridge of said conductors, a polarized relay 221 in said bridge, a circuit for said relay 221 adapted to be completed by said polarized relay in response to current of one character, to bring the contact members into operative relation to the desired row, a momentary circuit for said relay 236 completed by said polarized relay in response to current of different character, and means for maintaining said relay 236 energized until the magnet 222 has advanced the contact members to an idle set of terminals in the selected row.

37. The combination with line connectors, of operating mechanism therefor, a distributor adapted to select a desired connector, line conductors leading to said distributor and adapted to be united thereby with a desired connector, a bridge of the line conductors at the distributor, a pair of polarized relays 229, 228, in said bridge, means controlled by the relay 229 in response to currents of different polarity for selectively operating the mechanism of the distributor to select a desired connector, and means controlled jointly by said relays 229 and 228 for selectively actuating the operating mechanism of the selected connector.

38. The combination with line connectors, of operating mechanism therefor, a distributor adapted to select a desired connector, line conductors leading to said distributor and adapted to be united thereby with a desired connector, a bridge of the line conductors at the distributor, relays 228 and 229 in said bridge, said relay 229 being unresponsive to current required to operate the relay 228, means controlled by

relay 229 in operating or rendering said relay 228 ineffective, means controlled by relay 229 for selectively operating the distributor to select a desired connector, and means controlled by both of said relays 229 and 228 to selectively operate the stepping mechanism of the selected connector.

39. The combination with line connectors, of operating mechanism therefor, a distributor adapted to select a desired connector, line conductors leading to said distributor and adapted to be united thereby with a desired connector, a bridge of the line conductors at the distributor, a pair of polarized relays 229 and 228 in said bridge, said relay 229 being unresponsive to the current operating relay 228, said relay 229 in operating rendering ineffective the relay 228, a pair of stepping magnets for the distributor, means actuated by relay 229 in response to currents of different polarity for selectively actuating said stepping magnets to select a desired connector, a pair of stepping magnets for the selected connector, means controlled by relay 229 for selectively actuating one of said magnets, and means controlled by relay 228 for selectively actuating said other magnet.

40. The combination with telephone lines, of connectors adapted to serve said lines, a distributor, line conductors leading thereto, said distributor being adapted to reach the desired line, a bridge of said line conductors, a polarized relay in said bridge, a stepping magnet for the connector, means controlled by said relay when supplied with current of one polarity for operating said magnet, a testing conductor extending from the connector through the distributor, and mechanism controlled by said relay, in response to current of opposite polarity, for completing the continuity of said testing conductor.

41. The combination with telephone lines, of connectors adapted to serve said lines, a distributor, line conductors leading thereto, said distributor being adapted to unite said line conductors with a connector adapted to reach a desired line, a bridge of said line conductors at the distributor, a polarized relay in said bridge, a stepping magnet for said connector, means controlled by said polarized relay when supplied with current of one polarity for selectively operating said stepping magnet, a testing conductor extending from the connector through the distributor, a relay at the connector and a relay at the distributor controlling the continuity of said test conductor, and means actuated by said polarized relay when the connector unites with the desired line, in response to current of opposite polarity, for actuating said continuity relays.

42. The combination with telephone lines, of connectors adapted to serve said lines, a

distributer, line conductors leading thereto, said distributer being adapted to unite said line conductors with a connector adapted to reach a desired line, a bridge of said line conductors, a relay in said bridge, a testing conductor extending from the connector, through the distributer, and means controlled by said relay, when the connector has united with the desired line, for establishing the continuity of said testing conductor.

43. The combination with telephone lines extending from substations to a central office, of an operator's connecting circuit at the central office, means for uniting said circuit with a calling line, a source of current and a signaling device in said circuit, automatic line switching mechanism for said connecting circuit and a trunk line leading thereto, a bridge of the trunk line, controlling mechanism for said switching mechanism included in said bridge, means adapted to be associated with said connecting circuit for selectively operating said controlling mechanism, to unite the connecting circuit with a called line, said signaling device and source of current being adapted to find a circuit through the called line when the subscriber answers, means for testing the called line, and means for maintaining said bridge open during the test of the called line.

44. The combination with telephone lines extending from substations to a central office, of an operator's connecting circuit at the central office, a source of current and a signaling device in said circuit, automatic line switching mechanism for said connecting circuit and a trunk line leading from said circuit thereto, a bridge of the trunk line, controlling mechanism for said switching mechanism included in said bridge, means adapted to be associated with said connecting circuit for selectively operating said controlling mechanism, to unite the connecting circuit with a called line, said signaling device and source of current being adapted to find a circuit through the called line when the subscriber answers, means for signaling the called line, and means for maintaining said bridge open while said called line is being signaled.

45. The combination with telephone lines extending from substations to a central office, of an operator's connecting circuit at the central office, means for uniting said circuit with a calling line, a source of current and a signaling device in said circuit, automatic line switching mechanism for said connecting circuit and a trunk line leading from said circuit to said mechanism, a bridge of the trunk line, controlling mechanism for said switching mechanism included in said bridge, means adapted to be associated with said connecting circuit for

operating said controlling mechanism, to selectively operate said switching mechanism and unite the connecting circuit with a called line, said signaling device and source of current being adapted to find a circuit through the called line when the subscriber answers, and means for maintaining said bridge open during conversation.

46. The combination with telephone lines extending from substations to a central office, of an operator's connecting circuit at the central office, means for uniting said connecting circuit with a calling line, a source of current and a signaling device in said circuit, automatic line switching mechanism for said connecting circuit and a trunk line leading from said circuit thereto, a bridge of the trunk line, controlling mechanism for said switching mechanism included in said bridge, means adapted to be associated with said connecting circuit for operating said controlling mechanism to selectively operate said switching mechanism and unite the connecting circuit with a called line, said signaling device and source of current being adapted to find a circuit through the called line when the subscriber answers, means for maintaining said bridge open during the test of the called line, a source of ringing current adapted to be connected with the called line when said line switching mechanism unites therewith, means for maintaining said bridge open during the signaling of the called line, and means for maintaining the same open during conversation.

47. The combination with telephone lines extending from substations to a central office, of an operator's connecting circuit at the central office, a manual connection switch for uniting said connecting circuit with a calling line, a source of current and a signaling device in said circuit, automatic line switching mechanism for said connecting circuit and a trunk line leading from said circuit thereto, a bridge of the trunk line, controlling mechanism for said switching mechanism included in said bridge, means adapted to be associated with said connecting circuit for operating said controlling mechanism to unite the connecting circuit with a called line, said signaling device and source of current being adapted to find a circuit through the called line when the subscriber answers, a source of ringing current, a relay 234, operated when the switching mechanism unites with a desired line, adapted to apply said ringing current thereto, means controlled by said relay in operating for opening said bridge, a relay 232 operated upon the response of the called subscriber, means controlled by said relay for rendering said relay 234 inert, and means controlled by said relay 232 for

maintaining the said bridge open during conversation.

48. The combination with telephone lines extending from substations to a central office, of an operator's connecting circuit at the central office, means for uniting said circuit with a calling line, a source of current and a signaling device in said circuit, automatic line switching mechanism for said connecting circuit and a trunk line leading from said circuit thereto, a bridge of the trunk line, controlling mechanism for said switching mechanism included in said bridge, means adapted to be associated with said connecting circuit for operating said controlling mechanism to selectively operate said switching mechanism and unite the connecting circuit with a called line, said signaling device and source of current being adapted to find a circuit through the called line when the subscriber answers, a source of ringing current, a relay 234, a circuit through said relay completed when connection is made with the called line, said relay being adapted to connect said source of ringing current with the called line, a relay 449 in said circuit and responsive when the called subscriber answers, a relay 232, a circuit for said relay 232 completed by said relay 449 when operated, means controlled by said relay 232 for opening the circuit of relay 234, means controlled by said relay 234 while operated adapted to maintain said bridge open, a locking circuit for said relay 232 maintained for said relay during conversation, and means controlled by relay 232 for maintaining the said bridge open.
49. The combination with a line switching device having rows of terminals, of a contact carrying arm for said device, a magnet 221 adapted to advance said arm from row to row, a magnet 222 adapted to move said arm along a selected row, line conductors leading to said arm, a bridge of said conductors, electromagnetic mechanism within said bridge, a circuit for magnet 221 controlled by said mechanism, a relay 236 controlling the circuit of magnet 222, a momentary circuit for relay 236 controlled by said mechanism, whereby the arm is advanced to the first terminals of the selected row, means for maintaining said relay 236 energized, from the busy terminals in said row, and means controlled by said relay for maintaining said bridge open.

50. The combination with line connectors, of a distributor having rows of terminals, the terminals of each row representing connectors serving a given group of lines, a contact carrying arm for said distributor, line conductors leading to said arm, a bridge of said line conductors, electromagnetic mechanism within said bridge, controlling the advance of said arm from row to row, said mechanism being adapted to start said arm

along a selected row, means controlled by the busy condition of terminals in the selected row for effecting the continued advance of said arm to an idle connector terminal, means actuated during the finding of an idle connector terminal in the selected row for maintaining said bridge open, and mechanism for operating the selected connector, actuated upon the reestablishment of said bridge.

51. The combination with line connectors each having groups of line terminals and a contact-carrying arm, of a distributor having rows of terminals, the terminals of each row representing connectors serving a given group of lines, trunk lines leading from said terminals to the connector arms, a contact-carrying arm for the distributor, line conductors leading to said arm, a bridge of said line conductors, electromagnetic mechanism within said bridge controlling the advance of said arm from row to row, said mechanism being adapted to start said arm along a selected row, means controlled by the busy connector terminals in said row for continuing the advance of said arm to an idle connector terminal, means actuated during the finding of an idle connector terminal in the selected row for maintaining said bridge open, and mechanism actuated upon the reestablishment of said bridge for effecting the advance of the connector arm to the group of terminals containing the terminals of the desired line.

52. The combination with a line switching device having movable contact carrying arms, of trunk line conductors leading to said arms, retaining mechanism for said arms, stepping means therefor, a bridge of said conductors, electromagnetic mechanism in said bridge for controlling the operation of said stepping means, a sender associated with the trunk for causing the actuation of said mechanism, and means actuated during the return of the said arms from an operated to normal position for maintaining said bridge open to prevent access to the switching device.

53. The combination with a line switching device having a movable contact carrying arm, of line conductors leading to said arm, retaining mechanism for said arm, stepping means therefor, a bridge of the line conductors, controlling mechanism in said bridge adapted to operate said stepping means, a relay adapted when operated to open said bridge, a circuit for said relay completed when said retaining mechanism releases the said arm, and means actuated when said arm reaches normal position, for opening said circuit, whereby said bridge is maintained open until the switching device is in normal position.

54. The combination with a line switching device having a movable contact carry-

- 5 ing arm, of line conductors leading to said arm, a retaining magnet adapted when energized to maintain said arm in an operated position, stepping means for said arm, a bridge of the line conductors, controlling mechanism for said stepping means included in said bridge, contacts closed while the arm is away from normal position, a relay adapted to open said bridge, and a circuit 10 for said relay including said contacts, completed by said retaining magnet when de-energized, whereby the said bridge is maintained open until the contact carrying arm reaches normal position.

15 55. The combination with telephone lines leading from substations to a central office, of trunk lines leading from a branch exchange to said central office, said telephone and trunk lines being arranged in groups, 20 connectors serving different groups of said lines, terminals for said groups upon the connectors, a contact member for each connector adapted to sweep over the terminals thereof, a distributor adapted to select a desired connector, means for advancing the contact member of said connector to a desired telephone line terminal, said means being adapted to advance the contact member to the terminal of the first trunk line 25 leading to a private branch exchange, and mechanism at the distributor automatically operated in case said first trunk line is busy, for advancing said connector to the next trunk line terminal.

30 56. The combination with telephone lines leading from substations to a central office, of a group of trunk lines leading from a private branch exchange to said central office, said telephone and trunk lines being 35 arranged in groups, connectors serving different groups of said lines, terminals for said groups upon the connectors, a contact member for each connector, adapted to sweep over the terminals thereof, a distributor adapted to select a desired connector, means for advancing the contact member of said connector to a desired telephone line terminal, said means being adapted to advance the contact member to the terminal of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal, and means operated in case all said trunk lines are busy for applying a busy signal to the talking circuit.

40 57. The combination with telephone lines leading from substations to a central office, of trunk lines leading from private branch exchanges to said central office, said telephone and trunk lines being arranged in groups, connectors serving different groups of said lines, terminals for said lines upon the connectors, a contact member for each connector adapted to sweep over the terminals thereof, a talking circuit, a distributor adapted to unite said talking circuit with a desired connector, means for advancing the contact member of said connector to the terminal of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal.

45 58. The combination with telephone lines leading from substations to a central office, of a group of trunk lines leading from a private branch exchange to said central office, said telephone and trunk lines being arranged in groups, connectors serving different groups of said lines, terminals for said lines upon the connectors, a contact member for each connector adapted to sweep over the terminals thereof, a talking circuit, a distributor adapted to unite said talking circuit with a desired connector, means for advancing the contact member of such connector to the desired telephone line terminal, said means being adapted to advance the contact member to the terminals of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal.

50 59. The combination with telephone lines leading from substations to a central office, of trunk lines leading from private branch exchanges to said central office, said telephone and trunk lines being arranged in groups, connectors serving different groups of said lines, terminals for said lines upon the connectors, a contact member for each connector adapted to sweep over the terminals thereof, a talking circuit, a distributor adapted to unite said talking circuit with a desired connector, means for advancing the contact member of said connector to the terminal of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal.

55 60. The combination with telephone lines leading from substations to a central office, of trunk lines leading from a private branch exchange to said central office, said telephone and trunk lines being arranged in groups, connectors serving different groups of said lines, terminals for said lines upon the connectors, a contact member for each connector adapted to sweep over the terminals thereof, a talking circuit, a distributor adapted to unite said talking circuit with a desired connector, means for advancing the contact member of said connector to the terminal of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal.

65 61. The combination with telephone lines leading from substations to a central office, of trunk lines leading from a private branch exchange to said central office, said telephone and trunk lines being arranged in groups, connectors serving different groups of said lines, terminals for said lines upon the connectors, a contact member for each connector adapted to sweep over the terminals thereof, a talking circuit, a distributor adapted to unite said talking circuit with a desired connector, means for advancing the contact member of said connector to the terminal of the first trunk line leading to a private branch exchange, relays 340 and 423 at the distributor, relay 340 being unresponsive in case the first trunk line is busy, relay 423 responding, means, operated upon the response of relay 423 and the quiescence of relay 340, for advancing said connector member to the next trunk line terminal.

- trunk line terminals, means operated in case all said trunk lines are busy for applying a busy signal to the talking circuit, and means at the distributor, operated in case all said 6 trunk lines are busy, for restoring said distributor and connector to normal condition.
60. The combination with telephone lines leading from substations to a central office, of trunk lines leading from private branch exchanges to said central office, said telephone and trunk lines being arranged in groups, connectors serving different groups of said lines, terminals for said lines upon the connectors, a contact member for each 10 connector adapted to sweep over the terminals thereof, a distributor adapted to select a desired connector, means for advancing the contact member of said connector to a desired telephone line terminal, said means being adapted to advance the contact member to the terminal of the first trunk line leading to a private branch exchange, a test conductor leading from the connector to the distributor and adapted to have its continuity completed when the connector member reaches the terminal of a telephone line or the first trunk line terminal, relays 340 and 423 in said testing conductor, relay 340 being unresponsive if the line is busy, the relay 423 being responsive in case of a busy trunk line, and means controlled by said relays in such condition for advancing the connector arm to the next trunk line terminal.
61. The combination with telephone lines leading from substations to a central office, of trunk lines leading from private branch exchanges to said central office, said telephone and trunk lines being arranged in groups, connectors serving different groups of said lines, terminals for said lines upon the connectors, a contact member for each connector adapted to sweep over the terminals thereof, a distributor adapted to select a desired connector, means for advancing the contact member of said connector to a desired telephone line terminal, said means being adapted to advance the contact member to the terminals of the first trunk line leading to a private branch exchange, a testing conductor extending from the connector member through the distributor and adapted to have its continuity completed when the connector member unites with a desired telephone or the first trunk line of a group, relays 340 and 423 in said testing conductor at the distributor, relay 340 being unresponsive in case of all busy telephone or trunk lines, relay 423 being polarized and responsive only to current in said testing conductor when a trunk line is tested, and means actuated upon the inert condition of relay 340 and the responsive condition of relay 423, when a busy trunk line is tested, for advancing a connector member to the next trunk line terminals.
62. The combination with telephone lines extending from substations to a central office, and trunk lines leading from a private branch exchange to said central office, of an operator's connecting circuit at the central office, a manually-operable switch for uniting said connecting circuit with the line, connectors at the central office adapted to unite with telephone lines or groups of trunk lines, terminals for said lines upon the connectors, a distributor, trunk lines leading to said distributor adapted to be connected with said connecting circuit, said distributor being adapted to select a connector adapted to reach a desired line, sending apparatus adapted to be associated by the operator with the connecting circuit, to selectively actuate said distributor and unite the connecting circuit with a desired connector, a contact member for said connector, said sending apparatus being also adapted to advance said contact member to the terminal of a desired telephone line or to the terminals of the first trunk line leading to a private branch exchange, and mechanism at the distributor automatically operated in case the first trunk line is in use for advancing the connector member to the next trunk line terminal.
63. In a telephone exchange system, the combination with a calling telephone line extending from a number of stations to a central office, of a connecting circuit at the central office, a manually-operable connection switch for uniting said connecting circuit with such line, mechanical line switching mechanism adapted to unite said connecting circuit with a telephone line, a relay 46, means for momentarily operating said relay when said switching mechanism unites with a line, means actuated by said relay in case a station of the calling line is desired for causing said switching mechanism to remain in connection with the calling and busy line, means thereupon operated for maintaining said relay operated, and a reverting call signal actuated by said relay.
64. In a telephone exchange system, the combination with a telephone line extending from a number of substations to a central office, of a connecting circuit at the central office, a manually operable connecting switch for uniting said connecting circuit with the line, mechanical switching mechanism adapted to unite said connecting circuit with a desired line, a relay 46 having a pair of windings, a circuit for one of said windings momentarily established when said mechanism unites with a called line, means actuated by said relay in its momentary operation, in case a station of the calling line is desired, for causing said mecha-

nism to remain in connection with said calling and busy line, a circuit for said other winding completed through said switching mechanism, calling line and connection switch, adapted to maintain said relay operated, and a reverting call signal apparatus operated by said relay.

65. In a telephone exchange system, the combination with a telephone line extending from a number of substations to a central office, of a connecting circuit at the central office, a manually operable connection switch for uniting said connecting circuit with the line, mechanical switching mechanism adapted to unite said connecting circuit with a desired line, a relay 46 having a pair of windings, a circuit for one of said windings momentarily established when said mechanism unites with a called line, means actuated by said relay in its momentary operation, in case a station of the calling line is desired, for causing said mechanism to remain in connection with said calling and busy line, an armature for said relay adapted to connect said other winding with the connecting circuit, a circuit for said winding completed when said switching mechanism unites with the calling line, to maintain said relay operated, and a reverting call signal operated by said relay.

66. In a telephone exchange system the combination with single and multi station telephone lines terminating in an exchange, of a plurality of groups of automatic connectors, each connector serving to connect a calling line to one of a particular group of lines, a plurality of distributor by means of which the circuit of a calling line may be extended to a connector in which the line desired terminates, and means associated with each said distributor for selectively ringing the desired station upon a multi-station line with which connection is made by the selected connector.

67. In a telephone exchange system, the combination with telephone lines terminating in an exchange, of a plurality of groups of automatic connectors, each connector of a group serving to connect a calling line to one of a particular group of lines, a plurality of distributor by means of which the circuit of a calling line may be extended to a connector in which the line desired terminates, and means associated with and individual to each said distributor for testing and ringing the line with which connection is made by the selected connector.

68. The combination with a relay having two windings, of a second relay, means for momentarily applying currents of different character to one of said windings and said second relay, said winding operating only in response to current of one character, an armature for said first mentioned relay, a short circuit about the other wind-

ing of said relay normally completed by said armature, and a circuit for said latter winding and said second relay whereby said latter winding will be energized upon the attraction of said armature for maintaining the actuation of said relay.

69. The combination with telephone lines arranged in groups on a non-decimal basis, the total number of lines in each group being evenly divisible into one thousand, of digit keys representing the digits of subscribers' lines arranged on a decimal basis, and means operated directly by the keys representing the digits of a desired line for selecting the group of lines containing said line.

70. The combination with telephone lines arranged in groups on a non-decimal basis, the total number of lines in each group being evenly divisible into one thousand, of digit keys representing the digits of subscribers' lines arranged on a decimal basis, and means operated directly by the keys representing the thousands and hundreds digits of a line for selecting the group containing such line.

71. The combination with telephone lines arranged in groups on a non-decimal basis, the total number of lines of each group being divisible into one thousand without a remainder, the quotient being a multiple of ten, of an operator's connecting circuit adapted to be connected with a line in response to a call, digit keys representing subscribers' lines, arranged on a decimal basis, and switching mechanism operated directly by the keys representing the highest digits of a subscriber's line for bringing said connecting circuit into operative relation to the group containing the desired line.

72. In a telephone exchange system having lines arranged in groups on a non-decimal basis, each group containing five hundred lines, keys representing the digits of subscribers' lines, and means operated by a key of a hundreds digit in combination with a key of a thousands digit to determine the selection of a line in the first five hundred or the second five hundred of the thousand corresponding to the key depressed.

73. The combination with telephone lines, arranged in groups on a non-decimal basis, each group containing five hundred lines, of digit keys representing the digits of subscribers' lines, and means operated by the thousands and hundreds keys representing the thousands and hundreds digits of a called line, in case such line is in the second group of five hundred of the thousands digit, for selecting the group containing such line.

74. The combination with a talking circuit, of connectors adapted to unite with telephone lines, a distributor adapted to connect said talking circuit with any desired

connector, keys representing digits of subscribers' lines, and means actuated directly by operated keys representing digits of a desired line for operating said distributor 5 to connect said talking circuit with a connector serving the called line.

75. In a telephone exchange system, the combination with connectors each serving a particular group of lines in the exchange, 10 of a distributor having terminals representing said connectors, a primary controller having terminals corresponding to said distributor terminals, manually operated means for changing the electrical condition of the 15 controller terminal representing the group desired, and mechanism controlled jointly by said altered controller terminal and said manual means, for operating said distributor to unite the talking circuit with the 20 proper connector.

76. In a telephone exchange system, the combination with connectors each adapted to unite with a different group of lines in the exchange, of a talking circuit, a distributor having terminals connected with 25 said connectors, digit keys representing the digits of subscribers' lines, a primary controller having terminals representing terminals of said distributor, means actuated by 30 a key representing a high digit of a subscriber's line for changing the electrical condition of the terminal of said primary controller corresponding to the distributor terminal connected with the connector serving 35 the desired line, and mechanism actuated by said key and the said altered terminal for operating said primary controller and distributor to unite the talking circuit with a connector adapted to reach the desired line.

77. In a telephone exchange system, the combination with a number of connectors each adapted to unite with a group of lines in the exchange, of a talking circuit, a distributor having terminals connected with 40 said connectors, said distributor being adapted to unite said talking circuit therewith, digit keys representing the digits of subscribers' lines, a primary controller having terminals representing the terminals of 45 said distributor, means actuated by the digit key representing the highest digit of a called line for changing the electrical condition of the terminal of said primary controller representing the distributor terminal of a connector adapted to unite with said desired 50 line, and means controlled by the digit key representing the next highest digit of said line, in conjunction with said altered controller terminal, for operating said distributor to unite the talking circuit with said connector terminal.

78. In a telephone exchange system, the combination with a number of connectors adapted to unite with groups of lines in 65 the exchange, of a talking circuit, a distrib-

utor having terminals representing said connectors, said distributor being adapted to unite said talking circuit with a desired terminal, a primary controller having terminals representing the terminals of said distributor, digit keys representing digits of subscribers' lines, means actuated by the key representing the highest digit of a called line for changing the electrical condition of the controller terminal 70 representing the distributor terminal of a connector adapted to unite with said line, means controlled jointly by said key and the digit key representing the next highest digit of the called line for operating said 75 primary controller to cause the same to actuate said distributor, and means controlled by said altered controller terminal for stopping the operation of said distributor, when the talking circuit is united thereby with 80 the desired terminal.

79. In a telephone exchange system, the combination with a distributor provided with rows of terminals, of a talking circuit adapted to be united by said distributor with a terminal of any row, a primary controller having terminals representing said rows, manually operated mechanism for changing the electrical condition of a controller terminal representing a particular row of terminals of said distributor, and means operating under the control of said altered controller terminal for actuating said controller, to cause the same to actuate said distributor and thereby unite the talking circuit 95 with a terminal in said row.

80. The combination with a distributor having a number of rows of terminals, of a contact member for said distributor, a controller having terminals representing said rows, manually operated means for altering the electrical condition of a controller terminal representing a particular distributor row, mechanism controlled jointly by said altered controller terminal and said manual means for causing said controller to advance said contact member into operative relation to the selected row, and means for advancing said contact member along the said row to the desired terminal.

81. The combination with a line switching device having rows of terminals, of a contact member for said device, a primary controller having terminals corresponding to said rows, digit keys representing such controller terminals, means controlled by a digit key representing a given controller terminal for changing the electrical condition thereof, means controlled by said altered controller terminal for advancing said contact member to the selected row, and means for moving said contact member along said row to the desired terminal therein.

82. In a telephone exchange system, the combination with a distributor having main 130

and intermediate rows of terminals, of a contact member for said distributor, a primary controller having main and intermediate terminals corresponding to said rows, a series of digit keys, means controlled by each of said keys for changing the electrical condition of a corresponding main controller terminal or its associated intermediate terminal, a second series of digit keys representing the intermediate terminals, means controlled by the said intermediate terminal whose electrical condition has been altered by the key of the first series, and the corresponding key of the second series, for actuating said distributor to select a desired intermediate row, and means automatically operated when said contact member is in operative relation to a particular row for moving said member along said row to an idle terminal therein.

83. The combination with a distributor having main and intermediate terminals, of a contact member for said distributor, a primary controller having main and intermediate terminals corresponding to said distributor terminals, digit keys corresponding to said main terminals, each key when operated being adapted to change the electrical condition of its corresponding controller terminal, and means actuated by said key in case a main distributor terminal is desired for operating said primary controller under the control of said altered terminal to bring said contact member into operative relation to the selected main terminal.

84. The combination with a distributor having main and intermediate terminals, of a contact member for said distributor, a primary controller having main and intermediate terminals corresponding to said distributor terminals, digit keys corresponding to said main terminals, each key when operated being adapted to change the electrical condition of its corresponding main and intermediate controller terminals, digit keys representing said intermediate terminals, and means controlled by the key representing the altered intermediate terminal for operating said primary controller under the control of the altered intermediate terminal thereof to bring said contact member into operative relation to the corresponding intermediate terminal thereof.

85. The combination with a distributor having a series of main and intermediate terminals, of a contact member of said distributor, a primary controller having main and intermediate terminals corresponding to said distributor terminals, a series of keys representing said main controller terminals, each key being adapted when operated to change the electrical condition of its corresponding main terminal and the intermediate terminal associated therewith, means operated by said depressed key in

case a main distributor terminal is desired for operating said controller to cause said distributor member to advance to the corresponding main distributor terminal, and switching mechanism operated in case an intermediate terminal is desired for operating with the altered intermediate controller terminal to actuate said primary controller and advance the distributor member to the desired intermediate terminal.

86. The combination with a distributor having a row of terminals representing groups of lines, said terminals being divided into sets representing a given section of said lines, a contact member for said distributor, an operating magnet therefor, digit keys representing digits of lines, and means operated by the digit keys of a line represented by a given set and a particular terminal in such set for applying a number of impulses to the said operating magnet corresponding to the number of the desired terminal in the complete row, whereby the distributor member is given a corresponding number of steps to the proper terminal.

87. The combination with a telephone exchange system having the lines thereof divided into divisions of one thousand, each division having a number of groups, of a distributor having terminals representing the groups of such divisions, of digit keys representing the digits of subscribers' lines, and means controlled by the thousands key representing the thousands digit of a desired line for moving said distributor member to the desired group or division terminal.

88. The combination with a telephone exchange system having the lines thereof divided into divisions of one thousand, each division having a number of groups, of a distributor having terminals representing groups of each division, a contact member for said distributor, an operating magnet therefor, digit keys representing digits of subscribers' lines, and means controlled by the thousands and hundreds digit keys representing corresponding digits of a desired line, for applying a number of impulses to said magnet corresponding to the number of the desired terminal in the complete row of distributor terminals, whereby the distributor arm is advanced a corresponding number of steps to the desired terminal.

89. The combination with a telephone exchange having its lines divided into divisions of one thousand, subdivided into groups of five hundred, of a distributor having two terminals for the two groups of each division, a contact member for said distributor, digit keys representing the digits of subscribers' lines, and means controlled by the thousands digit key representing the thousands digit of a desired line for advancing the distributor to the terminals of the

first group of a division in which the called line is located.

90. The combination with a telephone exchange having its lines divided into divisions of one thousand, subdivided into groups of five hundred, of a distributor having two terminals for the two groups of each division, a contact member for said distributor, an operating magnet for said distributor, digit keys representing the digits of subscribers' lines, means actuated by a thousands key representing a given division for applying a number of impulses to the distributor magnet corresponding to the number of the first group terminal of the said division in the complete row of distributor terminals, whereby the distributor arm is advanced to the first group terminal of the selected division.
91. The combination with a telephone exchange having its lines divided into divisions of one thousand, subdivided into groups of five hundred, of a distributor having two terminals for the two groups of each division, a contact member for said distributor, digit keys representing digits of subscribers' lines, means controlled by the thousands digit key representing the thousands digit of a line in the first group of a division for advancing the distributor arm to the terminal of the first group of the said division, and means actuated by the thousands and hundreds digit keys of a line falling in the second group of the division represented by said thousands key, for bringing said distributor arm into operative relation to such group terminal.

92. The combination with a telephone exchange having its lines divided into divisions of one thousand, subdivided into groups of five hundred, of a distributor having two terminals for the two groups of each division, a contact member for said distributor, an operating magnet for said distributor, digit keys representing digits of subscribers' lines, means controlled by the thousands key representing the thousands digit of a line falling in the first group of the division corresponding to said key for applying a number of impulses to the distributor corresponding to the number of the distributor terminal in the complete row of distributor terminals, whereby the distributor arm is advanced to the first group terminal of the selected division, and means controlled by the thousands and hundreds keys representing such digits of a line falling in the second group of the division represented by the thousands key, for applying a number of impulses to said magnet corresponding to the number of the desired terminal in the distributor row.

93. In a telephone exchange system, the combination with a distributor having terminals representing groups of telephone

lines, said group terminals being arranged in divisions, of a contact member for said distributor, a primary controller having rows of terminals representing correspondingly located group terminals of the divisions of the distributor, manual means for altering the electrical condition of a controller terminal representing the desired group terminal of the distributor, a brush adapted to move along the selected controller row, means operated in the movement of said brush to the altered terminal, for advancing the distributor member to the selected group terminal, and means actuated as said brush reaches the altered terminal for stopping the operation of said brush.

94. In a telephone exchange system, the combination with a distributor having a series of terminals representing different groups of telephone lines, said group terminals being arranged in divisions, each having a like number of group terminals, of a contact member for said distributor, a primary controller having a row of terminals for each set of correspondingly located group terminals in the said divisions of the distributor, manual means for altering the electrical condition of a controller terminal in the proper row representing a desired group terminal, a brush adapted to move over such controller row to the altered terminal thereof, and means controlled by said brush and altered controller terminal for advancing said distributor member to the desired group terminal.

95. In a telephone exchange system, the combination with a distributor having a series of terminals representing different groups of telephone lines, said group terminals being arranged in divisions, each having a like number of group terminals, of a contact member for said distributor, a primary controller having a row of terminals for each set of correspondingly located distributor group terminals in said divisions, keys representing the digits of subscribers' lines, means controlled by the digit key representing the highest digit of a desired line for altering the electrical condition of the controller terminal of a row corresponding to the group terminal of the distributor representing the group of telephone lines containing the desired line, brushes for said rows, means controlled by the digit key representing the next highest digit of the called line for advancing the brush of the selected row to the altered terminal therein, and means controlled by said brush in advancing to said altered terminal for advancing the contact member of the distributor to the desired group terminal.

96. In a telephone exchange system, the combination with a distributor having a series of terminals representing different groups of telephone lines, said group terminals

nals being arranged in divisions, each having a like number of group terminals, of a contact member for said distributer, a primary controller having a row of terminals for each set of correspondingly located distributer group terminals in said divisions, keys representing the digits of subscribers' lines, means controlled by the digit key representing the highest digit of a desired line 10 for altering the electrical condition of the controller terminal of a row corresponding to the group terminal of the distributer representing the group of telephone lines containing the desired line, brushes for said rows, an operating magnet for said brushes, a circuit for said magnet, a relay adapted when operated to open said circuit, means controlled by the digit key representing the next highest digit of the called line, for associating said relay with the brush of the row containing the altered terminal, means operated in the advance of said brush to the altered terminal for advancing said distributer contact member to the desired 25 group terminal, and a circuit for said relay completed when said brush engages the altered terminal.

97. A controlling apparatus comprising rows of terminals, representing groups of 30 lower digits associated with higher digits, digit keys representing the higher digits, any key, when operated being adapted to change the electrical condition of a terminal representing a group of digits associated 35 with said higher digit, contact brushes for said rows, a movable arm therefor, digit keys representing the said lower digit, means controlled by a lower digit key when operated for rendering operative the brush 40 serving the row having the altered terminal, means for advancing said arm, means operated as said brush engages the altered terminal for stopping said arm, and current impulse mechanism operated under the control of the selected brush.

98. A controlling apparatus comprising rows of terminals, representing groups of lower digits associated with higher digits, digit keys representing the higher digits, 50 any key when operated being adapted to change the electrical condition of a terminal representing a group of terminals associated with said higher digit, contact brushes for said rows, a movable arm therefor, an operating magnet for said arm, a circuit therefor, a cut-off relay for said circuit, said relay being normally associated with the brush traveling over the row representing the first 55 groups of lower digits associated with higher digits, means operated in case a succeeding group terminal is altered electrically for transferring the relay to the brush representing the row of terminals containing such group terminals, a circuit for said relay completed when said brush engages such

altered terminal, and current impulse mechanism operated in the advance of said arm under the control of the selected brush and said altered terminal.

99. A controlling apparatus comprising 70 rows of terminals representing groups of lower digits associated with higher digits, digit keys representing the higher digits, a source of current, any key when operated connecting the terminals of the digits associated with said higher digit with one pole of said source of current, contact brushes for said rows, a movable arm carrying said brushes, an operating magnet for said arm, a circuit therefor, a cut-off relay for opening said circuit, a conductor including said relay and connected with the opposite pole of said source, said conductor being normally connected with the brush traveling over the row of terminals representing the 75 first groups of lower digits, digit keys representing said lower digits, contacts operated by a lower digit key representing a digit in a succeeding group, for switching said conductor to the branch traveling over the row of terminals containing said group contact, said relay operating when the selected brush engages the terminal connected with said source, to open the circuit of said operating magnet, and current impulse 80 mechanism operating in the advance of said arm under the control of the brush selected.

100. A controlling apparatus comprising rows of terminals representing groups of hundreds digits associated with thousands digits, brushes for said rows, a movable arm carrying said brushes, the said arm requiring different steps to reach the different group terminals of a thousands digit, digit keys, means controlled by a thousands digit 100 key for altering the electrical condition of the terminals in said rows representing the said groups associated with such digit, means controlled by any hundreds digit key representing a hundreds digit associated 105 with said thousands digit, for bringing into operative relation the brush of the row containing the terminal of the group containing such hundreds digit, means for advancing said arm until said brush reaches the 110 altered terminal, and distinctive current impulse mechanism operated in the advance of said arm according to the brush selected.

101. A controlling apparatus comprising two rows of terminals representing two groups of hundreds digits associated with thousands digits, a pair of brushes for said rows, a movable arm carrying said brushes, the second group terminal of each thousands digit key being located beyond the first 120 group terminal one step of the said arm, means controlled by a thousands key for changing the electrical condition of the two group terminals associated therewith, means controlled by a hundreds digit key represent- 125 130

- ing a hundreds digit for bringing into operative relation the brush of the group, in which such digit is located, means for operating said arm, means actuated when the 5 selected brush engages the altered terminal for stopping said arm, a common wire, and means actuated by said arm in its advance for delivering current impulses to said wire.
102. In a telephone exchange system, the 10 combination with connectors capable of uniting with telephone lines in the exchange, of a talking circuit, a distributor adapted to connect said talking circuit with any desired connector, keys representing digits of telephone lines, a primary controller, actuated directly by the thousands and hundreds digit keys representing a desired line for operating said distributor to unite the talking circuit with a connector capable of uniting with 15 the desired line, and means controlled by the tens and units digit keys representing the tens and units digits of the called line for operating the selected connector to unite the talking circuit with the desired line.
103. In a telephone exchange system, the 20 combination with connectors adapted to unite with lines in the exchange, of a talking circuit, a primary selector adapted to unite said talking circuit with a desired connector, keys representing the digits of subscribers' lines, and a primary controller, operated directly by the depressed thousands key representing the thousands digit of a called line, for operating said selector to unite the talking circuit with a connector adapted to reach the line desired.
104. In a telephone exchange system, the 25 combination with connectors each adapted to unite with several groups of telephone lines, a talking circuit, a distributor adapted to unite said talking circuit with a desired connector, thousands, hundreds, tens and units digit keys representing the digits of subscribers' lines, means controlled directly by a depressed thousands key representing the thousands digit of the called line, for operating said distributor to unite said talking circuit with a connector adapted to reach the called line, means controlled by the hundreds 30 key representing the hundreds digit of the called line for operating the selected connector to select the group of lines in which is located the called line, and means controlled by the tens and units keys representing the tens and units digits of the called line for operating said connector to unite said talking circuit with the called line terminating in said selected group.
105. In a telephone exchange system, the 35 combination with connectors each adapted to serve several groups of one hundred lines, of a talking circuit, a selector adapted to unite said talking circuit with a desired connector, a keyboard having thousands, hundreds, tens and units digit keys representing 40 the digits of subscribers' lines, means controlled by the thousands and hundreds keys representing such digits of the called line for operating said selector to unite the talking circuit with a connector adapted to unite with the line desired, means controlled by the said hundreds key for operating said connector to select the group of one hundred lines containing the line desired, and means controlled by the tens and units keys representing such digits of a called line for operating said connector to unite the talking circuit with a desired line in said selected group. 45
106. The combination with connectors adapted to unite with telephone lines, each connector being adapted to serve a number of groups of lines, a talking circuit, a distributor adapted to connect said talking circuit with a desired connector, a keyboard having thousands, hundreds, tens and units digit keys representing digits of subscribers' lines, a primary controller operated directly by a depressed thousands key representing the thousands digit of a called line for operating said distributor to unite the talking circuit with a connector adapted to unite with a desired line, means controlled by the depressed hundreds key for operating said connector to select the group of lines of the connector containing the called line, means for causing the primary controller to coöperate with the depressed tens key to operate said connector and select a row of the said group containing the desired line terminals, and means controlled by the units key representing the units digit of the called line for causing said connector to unite with a desired line terminating in said row. 50
107. The combination with a connector adapted to unite with telephone lines, each connector serving several groups of lines, each group being divided into rows, a contact member for each connector adapted to sweep over the terminals thereof, a talking circuit, a distributor adapted to unite said talking circuit with a contact member of a desired connector, a keyboard comprising thousands, hundreds, tens and units digit keys, a primary controller operated by a depressed thousands key, for operating said distributor to select a connector adapted to reach a desired line, an auxiliary controller, operated by the depressed hundreds key representing such digit of the called line, to bring the contact member of the selected connector into operative relation to the group of terminals thereof in which is located the terminals of a desired line, means actuated by the depressed tens key for moving said connector arm along the selected group to the row in which the desired line terminals are located, and means for causing said auxiliary controller to cooperate with the depressed units key representing 55 60 65 70 75 80 85 90 95 100 105 110 115 120 125 130

the units digit of the called line, for moving said connector arm along said row to the desired line terminals.

108. The combination with a connector 5 adapted to unite with telephone lines, each connector serving several groups of lines, each group being divided into rows, a contact member for each connector adapted to sweep over the terminals thereof, a talking 10 circuit, a distributor adapted to unite said talking circuit with the contact member of a desired connector, a keyboard comprising thousands, hundreds, tens and units digit 15 keys, a primary controller operated by a depressed thousands key representing such 20 digit of the called line, for operating said distributor to select a connector adapted to reach a desired line, an auxiliary controller 25 operated by the depressed hundreds key representing such digit of the called line to bring the contact member of the selected connector into operative relation to the group of terminals thereof in which is located the terminals of a desired line, means 30 actuated upon the operation of said auxiliary controller, for switching the primary controller into the service of the depressed tens key, representing the tens digit of the called line, to effect the movement of the 35 connector arm to the row of said group containing the desired line terminals, and means thereupon operated for switching said auxiliary controller into operative relation to the depressed units key representing the units digit of a called line for moving 40 said arm to the desired terminals.

109. The combination with a connector having groups of line terminals, of a contact member for said connector, an auxiliary controller, keys representing digits of 45 subscribers' lines; and means controlled by a key corresponding to a high digit of a called subscriber's line for operating said auxiliary controller to advance the connector arm in long steps to the group containing such line.

110. The combination with a connector having groups of line terminals, of a contact member for said connector, an auxiliary controller having terminals representing 50 said groups, digit keys representing digits of subscribers' lines, means actuated by a key representing a digit of a called line when operated for changing the electrical 55 condition of a controller terminal representing the connector group containing such line, means for actuating said controller under the control of said terminal, and means actuated by said controller for advancing said connector member to the 60 proper group.

111. The combination with a connector having groups of line terminals, of a contact member for said connector, an auxiliary controller having terminals represent- 65

ing said groups, digit keys representing digits of subscribers' lines, means controlled by the digit keys of lines falling in a particular connector group for changing the electrical condition of the corresponding controller terminals, means for actuating said controller under the control of said terminal, and means actuated by said controller for advancing said connector member to the proper group. 70

112. The combination with a connector having groups of line terminals, of a contact member for said connector, an operating magnet for said connector, an auxiliary controller having terminals representing 80 said groups, digit keys representing digits of subscribers' lines, means controlled by the digit keys of lines falling in a particular group for changing the electrical condition of the corresponding controller 85 terminals, a contact brush adapted to sweep over said controller terminals, means for advancing said brush, means actuated in the advance of said brush for applying impulses to the operating magnet of said connector arm to advance the same from group to group, and means actuated when said brush engages the altered controller terminal and the connector arm reaches the proper groups for stopping the movement 90 of said brush. 95

113. The combination with a connector having five groups of one hundred line terminals, of a contact member for said connector, an auxiliary controller having five 100 terminals representing five groups of a connector, hundreds digit keys representing hundreds digits of subscribers' lines, connections between the keys, representing digits of lines falling in the same group of connectors, and the controller terminal representing such group, means whereby a key when depressed changes the electrical condition of a controller terminal representing the connector group containing the line 105 110 whose hundreds digit is represented by said key, a primary controller, and means actuated under the control of said altered terminal for operating said primary controller and connector to bring said connector arm 115 into operative relation to the group containing said line.

114. The combination with selecting mechanism, of a plurality of rows of keys, and means controlled by the operation of 120 any combination of keys of said rows, comprising one key of each row, for selectively actuating said mechanism, said mechanism remaining unresponsive till a key of each 125 row is operated.

115. The combination with a line switching device, of a controller therefor, two rows of digit keys, means controlled by any two keys of said rows for selectively operating said controller, said controller being 130

unresponsive until both selected keys are operated.

116. The combination with connectors adapted to unite with groups of lines, of a mechanism for selecting a desired connector, digit keys representing the digits of telephone lines reached by said connectors, and means controlled by the keys representing the higher digits of subscribers' lines for operating said mechanism to select a connector adapted to unite with said line, said mechanism remaining unresponsive until said selected digit keys are operated.

117. The combination with connectors adapted to unite with groups of lines, of a talking circuit, a distributor adapted to unite said circuit with a desired connector, thousands, hundreds, tens and units digit keys representing the digits of subscribers' lines, mechanism controlled by the thousands and hundreds keys representing such digits of subscribers' lines for operating said distributor to unite said circuit with a connector adapted to unite with such line, said mechanism remaining unresponsive until both keys are operated, and means controlled by the tens and units keys representing such digits of said line for operating said selected connector to unite said talking circuit with the desired line.

118. The combination with a connector having a group of line terminals, of a talking circuit, keys representing the digits of subscribers' lines, mechanism controlled by the keys representing digits of a desired line for operating said connector to unite the talking circuit with a desired line terminal, said mechanism remaining unresponsive until all said selected keys are operated.

119. The combination with connectors adapted to unite with groups of lines, of a talking circuit, a distributor adapted to unite said talking circuit with a desired connector, a primary controller governing the operation of said distributor, digit keys representing the digits of telephone lines, operating mechanism for said controller, a circuit therefore, closed when the keys representing the higher digits of a desired line are operated, whereby said controller operates said distributor to unite said talking circuit with a proper connector, and means controlled by keys representing the remaining digits of the called line for operating said selected connector to unite the talking circuit with the line desired.

120. The combination with a talking circuit, of line switching mechanism therefor, thousands, hundreds, tens and units keys representing digits of telephone lines, and a pair of controllers adapted to be operated by the digit keys representing any desired line to selectively actuate said line switch-

ing mechanism and unite said talking circuit with said line.

121. The combination with a talking circuit, of line switching mechanism adapted to unite the same with a desired line, a keyboard comprising keys representing telephone lines, and a pair of controllers adapted to be operated by the keys representing any desired line for actuating said line switching mechanism to unite said talking circuit with a desired line.

122. The combination with connectors adapted to unite with telephone lines, of a talking circuit, a distributor adapted to unite said talking circuit with a desired connector, thousands, hundreds, tens and units digit keys representing digits of subscribers' lines, and a pair of controllers adapted to coöperate with the digit keys representing the digits of a called line, for operating said distributor and a connector selected thereby to unite the talking circuit with a desired line.

123. The combination with a talking circuit, of line switching mechanism therefor, a keyboard having keys representing subscribers' lines, and a pair of controllers adapted to be operated by keys representing any line to actuate said switching mechanism and unite the talking circuit with such line, the controllers being operated alternately and each controller being operated twice.

124. The combination with a talking circuit, of line switching mechanism adapted to unite said talking circuit with a desired line, a keyboard comprising thousands, hundreds, tens and units digit keys representing the digits of subscribers' lines, and a pair of controllers adapted to be operated by the digit keys representing any desired line for operating said switching mechanism to unite the talking circuit therewith, each controller operating in the service of two digit keys representing separated digits of the number and being adapted to switch the other into service.

125. In a telephone exchange system, the combination with a talking circuit, of line switching mechanism adapted to unite the same with a desired line, keys representing the digits of telephone lines, and a controller adapted to be operated successively by the keys representing non-consecutive digits of a given line for selectively operating said switching mechanism.

126. The combination with line switching mechanism, of two rows of digit keys, a controller having two rows of terminals corresponding to said rows of keys, contact brushes for said rows, a movable arm carried by said brushes, electromagnetic mechanism for operating said arm, means controlled by a given key of the first row for

- operating said electromagnetic mechanism, means actuated when said brush reaches the terminal corresponding to said operated key for restoring the said arm to normal position, means for bringing said electromagnetic mechanism under the control of an operated key of the second row, whereby said arm is again advanced, means operated when the brush of the second row reaches 10 the terminal representing the operated key of said second row of keys for stopping the movement of said arm, and means controlled in the advance of said arm for selectively actuating said switching mechanism.
127. The combination with line switching mechanism, of digit keys arranged in rows, a controller adapted to selectively operate said switching mechanism, electromagnetic mechanism for operating said controller, and means for bringing said magnetic mechanism successively under the control of depressed keys of non-adjacent rows.
128. The combination with line switching mechanism, of digit keys arranged in rows, a controller adapted to selectively operate said switching mechanism, electromagnetic mechanism for operating said controller, and means for bringing said electromagnetic mechanism successively under the control of 30 depressed keys of non-adjacent rows, and means whereby said controller must reach normal position before it can be operated under the control of another key.
129. The combination with a connecting circuit, of subscribers' lines, line switching mechanism therefor, a common operator's sending apparatus for selectively operating said line switching mechanism, means automatically operated by joining said connecting circuit to a line for associating said sending apparatus therewith, and means automatically operated when said line switching mechanism has operated for disassociating said sending apparatus from said connecting circuit, thereby rendering said sending apparatus again available for common use.
130. The combination with a telephone line extending from a substation to a central office, of a connecting circuit at the central office, an operator's connecting switch for uniting said connecting circuit with said line, line switching mechanism for uniting said connecting circuit with other telephone lines, a sending apparatus for selectively actuating said line switching mechanism, a relay, a circuit therefor completed through said connecting switch, and means controlled by said relay for associating said sending apparatus with said connecting circuit.
131. The combination with a telephone line extending from a substation to a central office, of a connecting circuit at the central office, an operator's connecting switch for uniting said connecting circuit with said line, line switching mechanism for uniting said connecting circuit with other telephone lines, a sending apparatus for selectively actuating said line switching mechanism, a relay, a circuit therefor completed through said connecting switch, means controlled by said relay for associating said sending apparatus with said connecting circuit, office, an operator's connecting switch for 65 uniting said connecting circuit with said line, line switching mechanism for uniting said connecting circuit with other telephone lines, and sending apparatus for selectively actuating said line switching mechanism, a 70 relay, a circuit therefor completed through said connecting switch, means controlled by said relay for associating said sending apparatus with said connecting circuit, and means automatically operated when connection is made by the line switching mechanism with a desired line for cutting off said sending apparatus from said connecting circuit.
132. The combination with a telephone line extending from a substation to a central office, of a connecting circuit at the central office, an operator's connecting switch for 80 uniting said connecting circuit with said line, line switching mechanism for uniting 85 said connecting circuit with other telephone lines, and sending apparatus adapted to selectively operate said line switching mechanism, a relay adapted when operated to associate said sending apparatus with said connecting circuit, a circuit for said relay completed by the closure of said connecting switch, and means actuated when a connection is completed for opening the circuit of 90 said relay.
133. The combination with a telephone line extending from a substation to a central office, of an operator's connecting circuit at said central office, a connection switch for 95 uniting said connecting circuit with said line, line switching mechanism for uniting said connecting circuit with other telephone lines, a sending apparatus adapted to selectively actuate said switching mechanism, a relay, a circuit for said relay completed upon 100 the closure of said connection switch, a second relay adapted to associate said sending apparatus with said connecting circuit, a circuit for said second relay completed by 105 said first mentioned relay when operated, and means actuated when said 110 connecting mechanism has operated for opening the circuit of said second relay.
134. The combination with a telephone line extending from a substation to a central office, of a connecting circuit at the central office, a connection switch for 115 uniting said connecting circuit with said telephone line, line switching mechanism for uniting said connecting circuit with telephone lines, a controlling relay for said sending apparatus, a second relay adapted to associate said sending apparatus with said connecting circuit, a circuit for said second relay completed upon 120 the closure of said connection switch, a locking circuit for said second relay, including the said controlling relay, closed by said second relay when operated, and means for 125

opening said circuit, automatically operated when said sending apparatus has operated the switching mechanism.

135. The combination with a telephone line extending from a substation to a central office, a connecting circuit at the central office, a connection switch for uniting said connecting circuit with the line, line switching mechanism for uniting said connecting circuit with other telephone lines, a controlling relay for said sending apparatus, a relay for associating said sending apparatus with said connecting circuit, a locking circuit for said relays completed upon the closure of said connection switch, a third relay in said circuit irresponsive to the current flowing therein, means actuated when the line switching mechanism has completed its work for increasing the flow of current in said locking circuit to operate said third relay, and means controlled by said relay for opening said locking circuit.

136. The combination with a telephone line extending from a substation to a central office, of a connecting circuit at the central office, a connection switch for uniting said connecting circuit with said line, line switching mechanism for uniting said connecting circuit with other telephone lines, a sending apparatus, a relay adapted to associate said sending apparatus with said connecting circuit, a circuit for said relay completed by the closure of said connection switch, a relay adapted to disassociate said sending apparatus from said connecting circuit, and a circuit for said relay completed when the sending apparatus has served said connecting circuit.

137. The combination with a telephone line extending from a substation to a central office, of a connecting circuit at the central office, a connection switch for uniting said connecting circuit with said line, line switching mechanism for uniting said connecting circuit with other telephone lines, a sending apparatus adapted to selectively operate said switching mechanism, a relay adapted to associate said sending apparatus with said connecting circuit, a circuit for said relay completed upon the closure of said connection switch, a second relay, an operating circuit for said relay established after the sending apparatus has operated, and means controlled by said second relay for opening the circuit of the first mentioned relay.

138. The combination with a telephone line extending from a substation to a central office, of a connecting circuit at the central office, a connection switch for uniting said connecting circuit with said line, line switching mechanism for uniting said connecting circuit with other telephone lines, a relay 27, a circuit thereto completed upon the closure of said connection switch, a relay

34 adapted to associate said sending apparatus with said connecting circuit, an initial circuit for said relay 34 completed by said relay 27, a locking circuit for said relay 34 completed by itself when operated, a relay 46 in said locking circuit responsive to said current, means for increasing the current in said circuit, when the sending apparatus has operated, to energize said relay 46, and means controlled by said relay for short-circuiting said relay 34 to disassociate said sending apparatus from said connecting circuit.

139. The combination with a telephone line extending from a substation to a central office, of a connecting circuit at the central office, a connection switch for uniting said connecting circuit with said line, line switching mechanism for uniting said connecting circuit with other telephone lines, a relay 34 adapted to associate said sending apparatus with said connecting circuit, an initial circuit for said relay completed upon the closure of said connection switch, a controlling relay for said sending apparatus, a locking circuit completed by said relay 34 for itself, said circuit also including said controlling relay, a relay 46 in said circuit irresponsive to current therein, means actuated when said sending apparatus has operated for short-circuiting said controlling relay to increase the flow of current in said circuit to operate said relay 46, and means controlled by said relay for opening said locking circuit.

140. The combination with a telephone line extending from a substation to a central office, of a connecting circuit at the central office, a connection switch for uniting said connecting circuit with said line, line switching mechanism for uniting said connecting circuit with other telephone lines, a relay 34, adapted to associate said sending apparatus with said connecting circuit, a relay 27, a circuit thereto completed upon the closure of said connection switch, and an initial circuit for said relay 34 completed by said relay 27, a controlling relay for said sending apparatus, a locking circuit including the relay 34 and the controlling relay 110 completed by the said relay 34 when energized, a relay 46 in said circuit irresponsive to the normal current therein, means actuated when said sending apparatus has operated for short-circuiting the controlling relay thereof, whereby sufficient current flows in said locking circuit to operate relay 46, and a short circuit about said relay 34 closed by relay 46 when operated to disassociate said sending apparatus from said connecting circuit.

141. In a telephone exchange system, the combination with subscribers' lines, of a selector, an operator's connecting circuit, an operator's sender apparatus adapted to con-

- trol said selector, a connection switch adapted to extend the circuit of a calling line to said connecting circuit, automatic switching mechanism adapted to bring said selector into operative relation to said sending apparatus, and an operating circuit for said automatic switching mechanism controlled by said connection switch.
142. In a telephone exchange system, the combination with subscribers' lines, of a selector and an operator's connecting circuit terminating in said selector, a sender apparatus adapted to control said selector, a connection switch adapted to unite said connecting circuit with a calling line, automatic switching mechanism adapted to bring said selector into operative relation to said sending apparatus, and an operating circuit for said automatic switching mechanism controlled by said connection-switch. ²⁰
143. The combination with a telephone line having a springjack, of an operator's cord circuit having an answering plug, a selector adapted to unite said cord circuit with a line wanted, a relay in a local circuit controlled by said plug and springjack, and means controlled by said relay for governing the operative condition of said selector. ²⁵
- In witness whereof, I, hereunto subscribe my name this 28th day of March A. D., 1907. ³⁰

ALBERT M. BULLARD.
